UNITED STATES PATENT OFFICE.

FRANKLIN A. STEARN, OF PATERSON, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed April 25, 1921. Serial No. 464,242.

To all whom it may concern:

Be it known that I, FRANKLIN A. STEARN, a citizen of the United States, residing at Paterson, in the county of Passaic, State of New Jersey, have invented certain new and useful Improvements in Telephone-Exchange Systems, of which the following is a full, clear, concise, and exact description.

This application relates to a telephone exchange system and more particularly to an office sending mechanism for controlling the establishment of connections through the medium of automatic switching mechanism.

In systems employing automatic switches of the power-driven reverte impulse type, it is the usual practice to provide a plurality of common central office sending mechanisms for controlling the automatic switches, any idle one of which may be employed by a calling subscriber. Each office sending mechanism is provided with a set of code registers and a set of numerical registers upon which the calling subscriber registers the office designation and the numerical designation of a desired distant point, through the operation of his impulse dial. The sending mechanisms thereafter function to govern the selective movements of automatic switches in accordance with such registration. Since the office sending mechanism must replace the directing mind of the usual manual operator, it is necessary that the sending mechanism be so constituted that it is enabled to care for any contingency that may arise.

It is, therefore, the object of the present invention to provide an office sending mechanism of improved construction which is efficient and reliable in operation.

One feature of the present invention resides in the provision of means associated with the office sending mechanism for automatically maintaining the resistance of the fundamental or switch controlling circuit extending between the sending mechanism and the various switches or apparatus controlled thereby within specified working limits, regardless of the destination of the initiated call for the purpose of insuring that the reciprocal control exercised between the sending mechanism and the connection extending apparatus shall be efficient under all conditions. This is accomplished by means of a

special sequence switch which assumes a position determined in accordance with the proposed routing of an initiated call as registered on the code registers of the sending mechanism, and which, in its several positions, connects resistance elements of different ohmic values into the fundamental circuit.

A second feature of the invention resides in the provision of means for cancelling the routing as designated by the code registers of the sending mechanism and for prescribing a special routing for extending a calling subscriber's line to a zero or special operator's position, if the calling subscriber is entitled to restricted service only and attempts to establish a connection to which he is entitled only upon the payment of an extra rate. This is accomplished by a special route switch which is positioned by zone or route register relays and which re-routes the attempted call in such a manner that the district and office selector switches function under the control of the route switch to extend a connection from the calling line to the operator's position rather than to the zone or zones of the exchange into which the calling subscriber attempted to extend the connection.

A further feature resides in the provision of means for enabling the office sending mechanism to send relay call indicator impulses to distant manual offices to indicate the designations of subscribers' lines which have numbers less than or greater than 10,000, by changing the order in which the several series of relay call indicator impulses are transmitted.

A still further feature of the invention relates to means for increasing or decreasing the speed of operation of the sending mechanism dependent upon whether it is necessary for the calling subscriber to dial extra digits for obtaining party line or automatic branch exchange lines. This is accomplished by means of relays which are operated in accordance with the setting of the code registers and which are instrumental in introducing a delay in the functioning of the sending mechanism if the code dialed indicates that the subscriber will dial extra stations digits.

A still further feature of the invention relates to means for restoring the sending

mechanism to normal condition and for insuring that all seized apparatus shall be properly restored in the event that a calling subscriber abandons a call before obtaining a desired connection.

Such other features as are contemplated by the present invention will become more apparent from the following description and the appended claims. The invention 10 will now be described in connection with one specific embodiment of the genus thereof. In the accompanying drawings Fig. 1 shows one of a group of lines terminating in a full mechanical office of the exchange and a 15 rotary line switch individual to such line by means of which the subscriber's line may be connected to an idle district selector switch; Fig. 2 shows a district selector and a sender finder switch together with the circuits 20 and controlling mechanism associated therewith; Fig. 3 shows an office selector together with the circuits and controlling mechanism associated therewith; Fig. 4 shows an incoming selector switch provided with mechanism 25 for applying ringing current to the terminals of a called line, together with the circuits and mechanism for controlling such switch; Fig. 5 shows the mechanism and circuits of a final selector switch and the 30 line of a subscriber to which the selector switch has access; Fig. 6 shows the signaling circuits associated with the office sender and terminating before the monitoring position of the trouble desk, and the circuits 35 and apparatus for controlling the collection and refunding of coins deposited in the coin boxes of calling subscribers' lines; Fig. 7 shows a time measure switch and translator control sequence switch associated with the 40 office sending mechanism; Fig. 8 shows a portion of the circuit of the sending mechanism comprising a stepping relay, a group of counting relays, a synchronizing relay and a sequence switch for controlling the 45 circuits of the sender; Fig. 9 shows a class switch, route switch and compensating resistance switch for altering the circuits of the sender in accordance with the class and desired routing of initiated calls; Fig. 10 50 shows the circuits and apparatus of an impulsing switch for transmitting relay call indicator impulses to manual relay call indicator offices; Fig. 11 shows the code registers of the sender and the thousands and 55 hundreds numerical registers which are set in accordance with the first three code or office designation digits dialed by the calling subscriber and the first two numerical digits, and the steering switch which successively associates the registers shown in Figs. 11 and 12 with the impulse circuit extending to the calling subscriber's line; Fig. 12 60 shows the tens and units numerical registers and three stations registers, which registers 65 are under the control of the steering switch

and impulse circuit disclosed in Fig. 11; Figs. 13 and 14 show groups of translator register relays which are selectively operated by the translator switch and pulse machine shown in Fig. 15 in accordance with 70 the setting of the code registers for determining the setting of the class, route and compensating resistance switches shown in Fig. 9, the setting of the district selector and office selector switches shown in Figs. 2 and 75 3 for setting the sequence switch of the district selector to determine the talking path through the repeating coil of the district selector; Fig. 15 shows a translator switch and a development of the pulse machine 80 drum for setting the register relays; Fig. 16 shows diagrammatically some of the various types of connections which may be established by a calling subscriber by means of the office sending mechanism and Fig. 17 85 is a diagram showing the manner in which the several sheets of the drawing should be arranged to show as much of a complete organization of circuits as is necessary to illustrate the manner in which connections 90 may be established.

The calling subscriber's line K is of the usual type provided with a transmitter, receiver and call-bell, and since it is assumed to be of the coin box type and terminates 95 in a full mechanical exchange, it is also equipped with a coin box and with an impulse sending dial S, both of the usual type.

The subscriber's line terminates in an individual trunk finding switch 100 of the well-known rotary step-by-step type, which through a plurality of wipers has access to a group of trunk lines terminating in district selector switches. The switch is provided with a stepping magnet for advancing the wipers over terminals of trunk lines in search of an idle trunk and for advancing the wipers around to normal position upon the release of the established connection.

The district selector switch 250, office selector 350, incoming selector 450 and final selector 550 diagrammatically disclosed in Figs. 2 to 5 inclusive, are of the type shown and described in the patent to E. B. Craft and J. N. Reynolds, No. 1,123,696, issued January 5, 1915. Each of the switches has a vertically disposed switch shaft provided with five sets of brushes, each brush set having access to a bank of one hundred terminals. For driving the switch shaft upwardly, an updrive magnet is provided, which, when energized, presses the switch shaft against a constantly driven power drum, and for restoring the switch shaft to normal position a second downdrive magnet is provided, which, when energized, presses the switch shaft against a second constantly driven power drum. For determining the particular set of brushes on the 110 115 120 125 130

lector at her position extends the connection to an intermediate recording toll office, from which office the toll connection is obtained in the usual manner.

If subscribers in manual offices or distant toll offices desire connections with subscribers in the full mechanical exchange, such connections are established through a cordless "B" position in the full mechanical office, the cordless operator receiving the number of the desired subscriber from the calling subscriber, and through her keyboard and sender causing the setting of cordless incoming selectors and final selectors to select the line of the desired subscriber. With this brief description of the manner in which various connections may be established from and to subscribers' lines in a full mechanical exchange, the method of establishing certain of these connections by means of the office sending mechanism associated with the full mechanical exchange will be described more in detail.

It will first be assumed that the calling subscriber K desires to establish a connection with a subscriber's line L in his own office. The calling subscriber upon initiating a call removes his receiver from the switchhook and closes a circuit for the line relay 101 of the trunk hunting switch 100, which circuit may be traced from battery through the right-hand winding of relay 101, the innermost lower armature and back contact of cut off relay 102, over line conductor 103, through the substation of subscriber's line K and thence back over line conductor 104 to ground at the upper armature and back contact of relay 102. The line relay energizes in this circuit and closes a circuit for the stepping magnet 105, which circuit may be traced from battery, through the winding and armature contacts of magnet 105, conductor 106, the lowermost armature and back contact of relay 102, the right-hand armature and front contact of relay 101, conductor 107 and thence to ground through the wiper 108 and the normal terminal of the bank upon which this wiper is resting. Magnet 105, upon energizing, advances the wipers 108, 109, 110, 111, 112 and 113 to the second terminals of the respective banks to which they have access. As the second terminal which wiper 108 now engages is permanently connected to ground, magnet 105 continues to step the wipers to the third set of terminals leading to the first of the group of trunks to which the switch has access.

If the first trunk of the group is busy, there will be ground potential on the test terminal thereof appearing in the lowermost bank of the switch, and the switch will therefore continue stepping until an idle trunk is found, upon the test terminal of which, battery potential appears. When this bat-

tery potential is encountered, a circuit is closed from battery through the contacts of sequence switch cam 202 (1) of the district selector to which the first idle trunk extends, through the inner left-hand armature and back contact of the sleeve relay 226, over test conductor 114, wiper 108, conductor 107, the left-hand armature, front contact and left-hand winding of relay 101, conductor 115 and thence to ground through both 70 windings of relay 102. Relays 101 and 102 are then energized in this circuit. The energization of relay 102 opens the circuit of stepping magnet 105 at its lowermost armature and back contact, and at its upper armature and front contact and intermediate armature and front contact, this relay extends the conductors 103 and 104 of the subscriber's line to the wipers 111 and 113 and thence to the trunk conductors 116 and 117 leading 80 to the selected district selector. Relay 102, at its intermediate armature and front contact, closes a circuit extending through the left-hand winding of sleeve relay 226, the normal contacts of the left-hand armature 90 of slow releasing relay 227, the lower right-hand contact of cam 203 (1 to 2½), sleeve conductor 118, wiper 109, winding of message register magnet 119, conductor 120, the intermediate armature and front contact of 95 relay 102 and thence to ground through the upper winding of relay 102. The sleeve relay 226 energizes in this circuit, but magnet 119 being marginal does not energize at this time. 100

For making the calling subscriber's line busy to all calls incoming thereto, battery potential is connected to the multiples of test terminal 121 appearing in the banks of all final selector switches having access to this line, over conductor 122, through wiper 110 and the off-normal segment 123 to grounded battery. Wiper 112, through the grounded off-normal segment 124, prepares a circuit extending over conductor 125 preparatory to restoring the finder switch 100 to normal when relay 102 becomes deenergized upon the termination of the connection. 110

Upon the energization of sleeve relay 226, 115 a circuit is established for the line relay 228 of the district selector switch 250, which circuit extends from battery, through the right-hand winding of this relay, the upper contacts of cam 204, the right-hand armature and front contact of relay 226 and thence to ground through the upper right-hand contact of cam 205 (17 to 15). At its inner left-hand armature and front contact, relay 226 connects ground potential to the test conductor 114 of the selected trunk to mark the trunk busy to other line switches, and at the back contact of this armature, disconnects the source of battery potential, which up to the time the selector switch was 125 130

switch shaft to be employed, a tripping spindle is provided as described in the patent hereinbefore referred to. The final selector switch differs from the other selector switches in being provided with additional means comprising a second updrive magnet and driving drum for driving the switch shaft upwardly. The two updrive drums rotate at different speeds whereby the switch shaft is moved upwardly rapidly during brush selection and group selection and more slowly during terminal selection.

The translator switch TS shown in Fig. 15 is of the same type as the switch shown in the aforesaid patent, but is equipped with ten sets of brushes arranged in five pairs, the brush sets comprising each pair being arranged to be tripped together.

The sender finder switch SF shown in Fig. 2, the monitoring switch M shown in Fig. 6, the time measure switch TM shown in Fig. 7, the register steering switch RS and the registers A, B, C, TH, H, T, U, ST, ST' and ST² shown in Figs. 11 and 12 are of the well-known step-by-step type, the wipers of which are advanced by stepping magnets. These switches are all restored by being stepped forwardly into normal position, with the exception of sender finder switch SF, which switch has no normal position, the wipers thereof resting in contact with the bank terminals last employed when the switch is not in use.

The pulse machine PM shown in Fig. 15 comprises a drum of insulating material in which a plurality of circumferential rows of contact segments are embedded, these segments being connected to a source of current through a common slip-ring. A plurality of brushes engage the several rows of segments and are arranged to be variously connected to the contacts in the ten banks of translator switch TS, through suitable distributing blocks (not shown) for conducting impulses of current from the several segments to the bank terminals of the translator switch.

For controlling the circuits associated with the several selector switches and the circuits of the office sender, auxiliary switches are provided. These switches may be of the type described in the patent to J. N. Reynolds and C. F. Baldwin, No. 1,127,808, issued February 9, 1915 and known in the art as "sequence switches". With the exception of sequence switch 900 which serves as a class switch and switch 950 which serves as a compensating resistance switch, all sequence switches are restored to normal position when not in use. The switches 900 and 950 however, are maintained in the position in which they were last used.

The different pieces of apparatus employed in the system having now been briefly described, it is thought that a clearer under-

standing of the invention may be had from a description of the method of establishing connections. Referring to Fig. 16, certain of the mechanism of an originating office of a full mechanical exchange is disclosed to the left and above the dot-and-dash lines, and a plurality of terminating offices and lines terminating therein have been represented within the dotted rectangles at the extreme right of the figure. Some of the terminating offices have been represented as mechanical offices and some as manual offices, some of which offices are within the local area, while others are at distant points. Where offices are located at distant points, a subscriber in the originating office obtains connections with such distant offices through tandem offices which have been represented within dotted rectangles in the middle portion of the figure. Throughout the figure the arrowheads indicate the direction of progress to and from the various substations disclosed therein.

If, for example, the calling subscriber K desires to establish a connection with a subscriber in his own office, he may do so by operating the district, office, incoming and final selector switches of his own office. In a similar manner, connections may be established with other full mechanical offices in the local area by means of the district and office selector switches of the originating office, and the incoming and final selector switches of the terminating full mechanical office. Connections to manual office in the local area are made through the operation of the district and office selectors of the originating office, the line desired in the terminating manual office being indicated on a relay call indicator at such office. If the calling subscriber desires to establish a connection with a subscriber in a distant office, it is then necessary to first establish a connection through the district and office selector switches of the originating office with a mechanical tandem office, from which latter office the connection is then further extended through a district selector at such tandem office to the terminating office which may be either a manual or full mechanical office. If the intermediate office is a manual office, then the calling subscriber through his district and office switches first extends the connection to the intermediate manual tandem office where the designation of the desired line is registered upon a relay call indicator. The operator at the tandem office then extends the connection to the distant manual office in accordance with the usual manual practice. For establishing connections to toll points, the calling subscriber first causes the extension of a connection through his district selector to a special "A" operator's position and the "A" operator through a sender and district se-

110
105
115
120
125
130

seized, marked the selector switch as idle. The locking circuit of line relay 101 is now opened and the line relay deenergizes.

Relay 228, upon energizing, closes a circuit for driving sequence switch 200 out of normal position 1 and into position 2, this circuit extending from battery through the magnet winding of sequence switch 200, the lower right-hand contact of cam 206 (1), the inner right-hand armature and front contact of relay 228 and thence to ground at the upper right-hand contact of cam 207 (7½ to 6). The sequence switch magnet energizes in this circuit and under the control of master cam 201 drives the sequence switch into position 2, in which position a circuit is closed from battery through the left-hand winding of relay 227 and thence to ground through the upper left-hand contact of cam 205 (2 to 11). Relay 227, upon energizing, closes a locking circuit for relay 226 extending through the left-hand winding of relay 226, the alternate contact of the left-hand armature of relay 227 and thence to the sleeve conductor 118, over the upper right-hand contact of cam 203 (1¾ to 16). Upon reaching position 2, the sequence switch connects a new holding ground to the test conductor 114 at the lower left-hand contact of cam 205, which holding ground is maintained through position 18½ of the sequence switch.

As soon as the sequence switch reaches position 1¾, a circuit is closed for the stepping magnet 229 of the sender finder SF extending from battery through the interrupter contacts and winding of magnet 229, the lower left-hand contact of cam 208 (1¾ to 2), the inner right-hand armature and front contact of relay 228 and to ground at the right-hand contact of cam 207. A circuit is also closed at this time through the winding of magnet 229, the winding of cut-in relays 230 and 244 in parallel and thence to ground at the upper left-hand contact of cam 209 (2 to 11). Relays 230 and 244 do not energize at this time, however, since their windings are shunted by ground connected through the armature of relay 228.

As soon as sequence switch 200 leaves position 1, the initial energizing circuit of relay 228 is opened at the upper contacts of cam 204, but this relay remains locked over a circuit extending from battery through its left-hand winding, its left-hand armature and front contact, the lower right-hand contact of cam 210 (1 to 6), the lower left-hand contact of cam 211 (1 to 2½), the outer left-hand armature and front contact of relay 226, test wiper 231 of the sender finder switch and to ground on busy terminals of the bank over which this wiper moves. As soon, however, as an idle sending mechanism is found, the wiper 231 will find no ground potential on the terminal corresponding to

said idle sending mechanism and relay 228 will thereupon deenergize opening at its inner right-hand armature and front contact, the circuit extending through stepping magnet 229 and closing at its inner right-hand armature and back contact, a circuit for driving sequence switch 200 out of position 2 and into position 3. This circuit may be traced from battery through the magnet winding of sequence switch 200, the upper left-hand contact of cam 206 (2), the inner right-hand armature and back contact of relay 228 and thence to ground at the right-hand contact of cam 207.

As soon as the line relay 228 deenergizes, the shunt around the windings of relays 230 and 244 is removed at the inner right-hand armature and front contact of relay 228 and these relays thereupon energize in series with magnet 229, the current flowing through the circuit, however, not being sufficient to cause the energization of the stepping magnet. Relay 230, upon energizing, closes a circuit extending from ground through its inner right-hand armature and front contact, wiper 231, and the terminal upon which it is resting, conductor 702, the outer left-hand armature and back contact of relay 703, the left-hand armature and back contact of relay 704, the outer left-hand armature and back contact of relay 705, the normal contacts associated with the inner right-hand armature of relay 706 and thence to battery through the winding of relay 706. Relay 706 energizes in this circuit and at its inner right-hand armature and front contact closes a locking circuit for itself independent of the armature contact of relay 705, and at its inner left-hand armature and front contact establishes an energizing circuit for relay 705. Relay 705, upon energizing, connects ground to the test conductor 702 for marking the seized sending mechanism as busy to all other sender finders over a circuit which may be traced from ground at the right-hand armature and front contact of relay 705, through the operating winding of relay 704, thence to conductor 702 through the outer left-hand armature and back contact of relay 703. At its inner left-hand armature and front contact, relay 705 connects battery to one terminal of relay 704 and at its right hand armature and contact connects ground to the other terminal thereof, but since relay 704 is shunted at this time, this relay does not energize. Should, however, the ground potential be removed from conductor 702 at the armature contact of relay 230 prior to the time the seized sending mechanism is restored to normal condition, the shunt around relay 704 would be opened at the armature contact of relay 230 and relay 704 would immediately energize, connecting busy ground potential to the test conductor 702 through its right-hand armature.

As soon as sequence switch 200 leaves position 2, the initial energizing circuit of relay 228 is opened at the upper contacts of cam 204, but this relay remains locked over a circuit extending from battery through its left-hand winding, its left-hand armature and front contact, the lower right-hand contact of cam 210 (1 to 6), the lower left-hand contact of cam 211 (1 to 2½), the outer left-hand armature and front contact of relay 226, test wiper 231 of the sender finder switch and to ground on busy terminals of the bank over which this wiper moves. As soon, however, as an idle sending mechanism is found, the wiper 231 will find no ground potential on the terminal corresponding to

ture and front contact and winding, which busy potential is maintained on the conductor 702 until the sender is entirely restored to normal condition.

- 5 Relay 706, upon energizing, also establishes a circuit for relay 707 which may be traced from ground through the outer left-hand armature and front contact of relay 706, the right-hand operating winding and 70
10 the left-hand non-inductive winding of relay 707, the outer left-hand armature and back contact of advance-relay 708, conductor 709, wiper 232, the lower contact of cam 215, the right-hand armature and front contact of relay 244, the upper contact of cam 214 and thence to battery through the right-hand winding of differential relay 227. Due to the resistance of the non-inductive winding of relay 707, sufficient current does not 75
20 flow through the right-hand winding of relay 227 to cause this relay to be differentially balanced and, therefore, relay 227 is maintained energized and relay 707 energizes. Upon the energization of relay 707, 80
25 a circuit is closed for advancing the time measure switch TM into position 1 under the influence of interrupter 710, over a circuit which may be traced from battery through the winding of stepping magnet 85
30 711, wiper 792 and the normal terminal of the bank with which it is associated, interrupter 710, the outer left-hand armature and back contact of relay 712, the inner armature and front contact of relay 707 and 90
35 thence to ground at the outer left-hand armature and front contact of relay 706.

As soon as the time measure switch reaches position 1, a circuit is established for relay 712 which may be traced from 95
40 battery through the winding of relay 712, bank terminal 713, wiper 714 and thence to ground. Relay 712, upon energizing closes a locking circuit for itself independent of wiper 714, through its winding, its 100
45 outer right-hand armature and front contact and thence to ground at the outer left-hand armature and front contact of relay 706. A new circuit for magnet 711 may now be traced from magnet 711, wiper 715, 105
50 the outer left-hand armature and front contact of relay 712, the inner armature and front contact of relay 707 to ground at the outer left-hand armature of relay 706. Stepping magnet 711, under the influence of 110
55 its own self-interrupting armature contacts, advances the wipers of the time measure switch to position 6 in which position the circuit of magnet 711 is opened at wiper 715.

60 *Setting the code registers.*

Relay 712, upon energizing, also closes a dialing circuit for associating the register controlling mechanism of the sender with the calling subscriber's line, which circuit 115
65 may be traced from battery through the

winding of stepping relay 1100, conductor 1101, the outer left-hand armature and back contact of relay 600, the outer left-hand armature and back contact of relay 601, conductor 602, the inner right-hand armature and front contact of relay 712, wiper 236, the inner left-hand armature and front contact of relay 230, conductor 235, the lower left-hand contact of cam 213, the winding of relay 234, trunk conductor 116, wiper 111 of the trunk finding switch 100, the innermost lower armature and front contact of relay 102, line conductor 103, through the calling subscriber's sending dial S and substation loop, line conductor 104, the upper armature and front contact of relay 102, wiper 113, trunk conductor 117, the lower left-hand contact of cam 212, conductor 233, the outer left-hand armature and front contact of relay 230, wiper 245, the inner left-hand armature and front contact of relay 712, conductor 603, the outer right-hand armature and back contact of relay 601, the outer right-hand armature and back contact of relay 600, conductor 604 and thence to ground through the left-hand winding of retardation coil 716. The stepping relay 1100 energizes in this circuit and at its armature and front contact closes a circuit for the slow-releasing relay 1102, this circuit extending from battery through the winding of relay 1102 and thence to ground through the armature and front contact of relay 1100. A circuit is 120
90 now closed for sending a dialing tone to the calling subscriber's line, which circuit may be traced from ground through the make-contacts of the right-hand armature of relay 1102, wiper 1103 and normal terminal of the bank upon which it is resting, conductor 1104, the right-hand winding of retardation coil 716 and thence to ground through the secondary winding of the tone coil 717. The tone current flowing in this 125
95 circuit is inductively transmitted to the substation of the calling subscriber through the left-hand winding of coil 716 and over the circuit previously traced.

Upon the initial energization of relay 706, a circuit was also established for initiating the operation of the monitoring time measure switch M. The starting circuit for starting the switch M may be traced from battery through the winding of starting relay 605, the normally closed contacts associated with its inner left-hand armature, wiper 606 of the switch M and the normal bank terminal upon which it is resting, conductor 607, the inner left-hand armature and back contact of relay 708 and thence to ground through the inner left-hand armature and front contact of relay 706. Relay 605, upon energizing in this circuit, establishes a locking circuit for itself independent of the wiper 606, which may be traced 130
100
105
110
115
120
125

through its winding, the make-contact of its inner left-hand armature, conductor 608 and thence to ground at the armature and front contact of relay 706. At its intermediate 5 right-hand armature, relay 605 establishes a circuit for slow-to-release relay 609 which may be traced from ground through the intermediate right-hand armature and front contact of relay 605, the inner left-hand armature and back contact of relay 610, wiper 677, the normal bank terminal upon which it is resting, the winding of relay 609, conductor 611, the right-hand armature and back contact of coin register relay 1400, 10 conductor 1401 and thence to battery through the outer right-hand armature and back contact of zone relay 907. Relay 609, upon energizing, closes a locking circuit for itself extending from battery on conductor 611, through its winding, its left-hand armature and front contact, the outer right-hand armature and back contact of coin collect relay 612, conductor 613, the armature and back contact of coin test relay 614, the 15 inner left-hand armature and back contact of relay 615 and thence to ground at the outer right-hand armature and front contact of relay 605. At its right-hand armature and front contact, relay 609 establishes a circuit for relay 616 which may be traced from battery on conductor 611, through the winding of relay 616 and thence to ground at the right-hand armature and front contact of relay 609, and a circuit for relay 610 20 which may be traced from battery through the right-hand winding of relay 610, wiper 617 of the switch M, the normal bank terminal upon which the wiper is resting, and thence to ground at the right-hand armature and front contact of relay 609. The energization of relay 616 is without effect at this time.

Relay 610, upon energizing, establishes a stepping circuit for stepping magnet 618 of the switch M which may be traced from battery through the winding of magnet 618, the right-hand armature and front contact of relay 610, wiper 617 and the normal bank terminal upon which it is resting and thence to ground at the right-hand armature and front contact of relay 609. Stepping magnet 618 advances the wipers of switch M one step when the energizing circuit of relay 610 is opened at the switch wiper 617 and the previously traced circuit through the winding of magnet 618 is opened at the armature contact of relay 610. With relay 610 deenergized and switch M in position 1, a new driving circuit is 45 established through the winding of magnet 618 and the slow interrupter 619, which may be traced from battery through the winding of magnet 618, the right-hand armature and back contact of relay 610, interrupter 619, the inner left-hand armature and back contact of relay 620, the No. 1 terminal in the bank with which wiper 677 is associated, wiper 677, the inner left-hand armature and back contact of relay 610 and thence to ground at the intermediate right-hand armature and front contact of relay 605. Under the influence of interrupter 619, switch M is advanced into position 3 measuring off time sufficient to enable the calling subscriber to dial the first digit. If 50 the calling subscriber fails to dial the first digit within the time measured by the advance of switch M to position 3, a circuit is established for displaying a signal on the sender monitoring lamp 621, which may be traced from battery through the lamp 621, the outer left-hand armature and back contact of relay 615, bank terminal 622, wiper 623, the outer left-hand armature and back contact of relay 610 and thence to ground 55 at the intermediate right-hand armature and front contact of relay 605. At the same time a signal is displayed by the pilot lamp 624, the lamp 624 being illuminated over a circuit which may be traced from battery through lamp 624, the right-hand armature and back-contact of relay 620, bank terminal 625, wiper 677, the inner left-hand armature and back contact of relay 610 and thence to ground at the intermediate right hand armature and front contact of relay 605. The monitoring operator noting the illumination of lamps 621 and 624 takes the necessary steps to ascertain the trouble on the calling line, or the reason why the calling subscriber has failed to commence 60 dialing.

Assuming that the calling subscriber dials the first digit of the number of the desired connection within the specified time interval, and further, assuming that the subscriber desires a connection with a subscriber's line L which is listed in the directory as "L I S penard 9539" and that the calling line is to be reached through a district selector switch 105 625, an office selector switch 350, an incoming selector 450 and final selector 550, the subscriber proceeds to dial three letters corresponding to the office designation of the desired line and then dials four digits representing the number of the line of such office. In the case assumed, the calling subscriber will dial the letters L I S and will then dial the numerals 9539. The three letters which represent the office code will not 110 only cause the setting of the district selector switch and office selector switch to choose the desired office, but will also cause an adjustment of the circuits of the office sender in accordance with the class of the call which 115 is being extended.

Setting the code and numerical registers.

In response to the first impulse dialed by the calling subscriber in accordance with 120 130

the first letter L of the office designation, the stepping relay 1100 deenergizes and closes a circuit for the stepping magnet 1105 of the first code register A, which stepping circuit may be traced from battery through the winding of magnet 1105, the right-hand armature and back contact of preliminary-pulse relay 1106, conductor 1107, normal bank-terminal and wiper 1108 of the register steering switch RS, conductor 1109, the upper contacts of route switch cam 908 (1), conductor 910, the winding of slow-to-release relay 1190, the left-hand armature and front contact of relay 1102 and thence to ground at 5 the armature and back contact of stepping relay 1100. In response to this impulse, the stepping magnet 1105 advances the wipers of register A one step, as soon as the circuit of the stepping magnet 1105 is again opened 10 upon the reenergization of the stepping relay 1100, and in response to successive impulses of the first code letter L, the register A advances its wipers into contact with the fifth set of terminals of its banks. To insure that 15 the stepping magnet 1105 shall remain energized long enough upon each deenergization of stepping relay 1100 to cause a complete step of the register, a circuit is closed through relay 1110 in parallel with the winding of stepping magnet 1105, which circuit may be traced from battery through the left-hand armature and back contact of relay 1106, the winding of relay 1110, wiper 1111, the normal terminal of the bank upon which it 20 is resting, the armature and back contact of stepping magnet 1105, the right-hand armature and back contact of relay 1106 and thence to ground at the armature and back contact of relay 1100 over the circuit previously traced. Relay 1110 energizes in this 25 circuit and closes a locking circuit for itself independent of the armature contact of relay 1100, which locking circuit extends through the winding of relay 1110, the armature and back contact of magnet 1105, the outer right-hand armature and back contact of relay 1106, wiper 1108, conductor 1109, contacts of cam 908, conductor 910, winding of relay 1190, the left-hand armature and 30 front contact of relay 1102 and thence to ground at the left-hand armature and front contact of relay 1110. Relay 1110 and stepping magnet 1105 are thus maintained energized until stepping magnet 1105 has 35 moved its armature to substantially the full extent of its movement, when the circuit of relay 1110 is opened at the armature contact of magnet 1105. Relay 1110 at its right-hand armature and front contact also 40 closes a holding circuit for slow releasing relay 1102 for holding this relay energized independent of the energization of relay 1100.

65 The slow releasing relay 1190 which was also energized in the circuit of stepping mag-

net 1105 of the register A maintains its armatures attracted until the series of impulses transmitted through magnet 1105 ceases, whereupon this relay deenergizes. Upon its initial energization, relay 1190 70 closes a circuit extending from battery through the winding of slow releasing relay 1112, the winding of stepping magnet 1113 of the steering switch RS, the right-hand armature and front contact of relay 1190 and thence to ground at the right-hand armature and front contact of relay 1102. As soon as relay 1190 deenergizes, upon the cessation of impulses flowing through the circuit of stepping magnet 1105, the circuit 80 previously traced through relay 1112 and stepping magnet 1113 is opened causing the deenergization of stepping magnet 1113 and the advancement of the wipers of the register steering switch from engagement with the normal terminals of the respective banks to which they have access into engagement with the No. 1 terminals of the banks. The movement of wiper 1108 now transfers the control circuit extending from the armature of stepping relay 1100 from the winding of stepping magnet 1105 of register A, through the winding of stepping magnet 1114 of register B. Relay 1112 which energized in 85 series with stepping magnet 1113 connects ground through its armature and front contact to conductor 718 and thence to the back contact of the inner left-hand armature of relay 706 to maintain relay 705 energized, and consequently, the energization of relay 100 90 95 100 105 110 115 120 125 130 135 140 145 150 155 160 165 170 175 180 185 190 195 200 205 210 215 220 M for advancing the wipers of the switch under the control of slow interrupter 619. This driving circuit may be traced from battery through the winding of magnet 618, 5 the right-hand armature and back contact of relay 610, interrupter 619, the inner left-hand armature and back contact of relay 620, Nos. 4, 5 and 6 terminals of the bank associated with wiper 677, the inner left- 10 hand armature and back contact of relay 610 and thence to ground at the intermediate right-hand armature and front contact of relay 605.

During the advancement of the wipers of switch M from position 3 into position 7, 15 an interval of time is measured sufficient to enable the calling subscriber to completely dial the number of the desired connection. If the subscriber has not completed dialing 20 at the time switch M reaches position 7, the switch stops in position 7 and a circuit is established through resistance for the sender monitoring lamp 621 for lighting the lamp dimly to indicate unfinished dialing. The 25 circuit of lamp 621 may be traced from battery through the lamp, the outer left-hand armature and back contact of relay 615, resistance element 627, the No. 7 terminal of the bank with which wiper 623 is associated, 30 wiper 623, the outer left-hand armature and back contact of relay 610 and thence to ground at the intermediate left-hand armature and front contact of relay 605. At the 35 same time the pilot lamp 624 is illuminated over the previously traced circuit. The operator noting the dim illumination of lamp 621 then proceeds to take necessary steps to ascertain the trouble.

With the register steering switch RS in 40 position 1, the second series of impulses corresponding to the second code letter of the office designation causes the setting of the code register B in a manner similar to the setting of register A. The stepping circuit 45 of the magnet 1114 of the register B extends from battery through the winding of magnet 1114, bank terminal 1115, wiper 1108, conductor 1109, route switch cam 908, conductor 910, winding of relay 1190, the left- 50 hand armature and front contact of relay 1102 and thence to ground at the armature and back contact of relay 1100. Under the assumption that the second code letter is I, the wipers of the code register B take a setting on the No. 4 terminals of the banks 55 with which the respective wipers are associated. Upon the termination of the impulses of the second code letter, the slow releasing relay 1190 deenergizes and in the 60 manner previously described causes the movement of the register steering switch RS into position 2, in which position the control circuit previously traced to the stepping magnet 1114 of the code register B is opened

and the control circuit is extended through 65 the stepping magnet 1116 of the code register C.

With the wipers of the register steering switch RS in engagement with the second position terminals of the respective banks 70 of the switch, a circuit is established for relay 1117 which may be traced from battery through the right-hand winding of this relay, conductor 1118, the inner left-hand armature and back contact of zone relay 911, 75 conductor 912, bank terminal 1119, wiper 1103, thence to ground at the right-hand armature and front contact of relay 1102. Relay 1117, upon energizing, closes a locking circuit for itself extending from battery 80 through its left-hand winding, inner left-hand armature and front contact, conductor 1120 and thence to ground through wiper 719 of switch TM and the off-normal terminal of the bank to which this wiper has access. At its inner left-hand armature and front contact, relay 1117 closes a circuit for the control relay 1500 of the translator switch TS. This circuit extends from battery through the left-hand winding of relay 90 1500, conductor 1501, the right-hand contact of cam 720 (1 to 2), conductor 721, the inner armature and back contact of synchronizing relay 802, conductor 803, the inner left-hand armature and front contact 95 of relay 1117 and thence to ground at wiper 719.

Setting the translator switch.

Relay 1500, upon energizing, closes a circuit for driving the translator control sequence switch 700 out of position 1 and into position 2, this circuit extending from battery through the magnet of sequence switch 700, the lower right-hand contact of cam 100 722 (1), conductor 723, and thence to ground at the left-hand armature and front contact of relay 1500. In its movement from position 1 to position 2, the sequence switch is under the control of master cam 701 which 105 insures that the sequence switch will move completely from position 1 to position 2. Upon reaching position 2, the sequence switch closes a circuit for relay 748 which may be traced from battery through the 110 left-hand winding of relay 748, the right-hand armature and back contact of advance relay 708 and to ground at the upper contacts of cam 747 (2 to 18). Relay 748 closes an obvious circuit for relay 737 which, at 115 120 its left-hand armature, connects a new holding ground to the armature contact of relay 706 and at its right-hand armature opens a normally closed shunt around contacts of cam 825 (1 to 4). A circuit is also established for the updrive magnet 1502 of the translator switch TS, which circuit extends from battery through the winding of mag-

net 1502, conductor 1503, the contact of cam 724 (2), conductor 723 and thence to ground over the circuit previously traced at the armature and front contact of relay 1500. 5 In response to its energization, magnet 1502 presses the depending portion of the switch shaft 1504 of the translator switch against the constantly rotating updrive drum 1505 thereby causing the switch shaft and the 10 brush sets carried thereby to be moved upwardly. This upward movement continues until the test brush 1506 encounters the terminal in the test bank 1507 which has been grounded through bank terminals of code 15 registers A and B. As soon as brush 1506 engages such terminal, a circuit is closed through the right-hand winding of the differentially wound control relay 1500, which may be traced from battery through the 20 right-hand winding of this relay, conductor 1508, the upper contacts of cam 725, conductor 726, brush 1506, terminal 1509, conductor 1510, terminal 1120 and wiper 1121 of code register A, terminal 1122 and wiper 25 1123 of register B and thence to ground at the lower left-hand contact of cam 727 (1 to 3). Current flowing through the right-hand winding of relay 1500 differentially balances the relay which thereupon deenergizes, opening at its armature and front contact the circuit previously traced through the updrive magnet 1502 to thereby arrest the upward movement of the switch. The 30 brush shaft of the switch is now positioned with a certain pair of brush sets in cooperative relation with tripping fingers on the tripping spindle 1511. Relay 1500, upon deenergizing, also closes a circuit for driving the translator control sequence switch 700 35 out of position 2 and into position 3, this circuit extending from battery through the magnet winding of sequence switch 700, the lower right-hand contact of cam 728, conductor 729, thence to ground at the left-hand armature and back contact of relay 1500. 40 Upon leaving position 2, the initial energizing circuit extending through the left-hand winding of relay 1500 is opened at the contact of sequence switch cam 720, but this circuit is again established as soon as the sequence switch reaches position 3 and relay 1500 therefore again energizes. Upon reaching position 3, a circuit is established 45 for the tripping magnet 1512 of the translator switch TS extending from battery through the winding of the tripping magnet 1512, conductor 1513 and thence to ground at the upper left-hand contact of cam 730 (3 to 5). The tripping magnet, upon energizing, rotates the tripping spindle 1511 preparatory to tripping the pair of brush sets of the switch TS which have been positioned in operative relation to a pair 50 of tripping fingers on the tripping spindle. 65 It will be assumed that the brush sets 1514 and 1515 shown in Fig. 15 on the drawing are the brush sets which are to be tripped. Control relay 1500, upon reenergizing with sequence switch 700 in position 3, again 70 closes the previously traced circuit for driving sequence switch 700 out of position 3 and into position 4. As soon as sequence switch 700 reaches position 4, a circuit is closed for the updrive magnet 1502 as previously traced. The updrive magnet is thus energized and the switch shaft 1504 is driven upwardly. During the first portion of its upward movement, since at this time the tripping spindle 1511 has been rotated, the selected pair of brush sets 1514 and 1515 is 75 tripped. During the subsequent upward movement of the switch shaft, the brushes of the tripped brush sets are caused to wipe over the terminals of the banks to which 80 they have access until the test brush 1506 engages a terminal in the test bank 1507 corresponding to the setting of the code registers. A circuit is now established extending from battery through the right-hand 85 winding of control relay 1500, over the circuit previously traced to the test brush 1506, bank terminal 1516, conductor 1517, terminal 1124 and wiper 1125 of register B, terminal 1126 and wiper 1127 of register A, conductor 1128, the inner left-hand armature and back contact of relay 913, conductor 914, conductor 1129 and thence to ground 90 at the lower left-hand contact of cam 730 (1 to 5). Upon the closure of this circuit through the right-hand winding of relay 1500, relay 1500 deenergizes, opening at its left-hand armature and front contact the 95 previously traced circuit extending through the updrive magnet 1502 to arrest the upward movement of the switch shaft and to position the selected set of brushes beneath the groups of bank terminals corresponding 100 to the code settings of code registers A and B. Relay 1500 also closes the previously 105 traced circuit extending through its armature and back contact for driving sequence switch 700 out of position 4 and into position 5. Upon leaving position 4, the initial 110 energizing circuit extending through the left-hand winding of relay 1500 is opened at the contact of cam 720, but this circuit is again established as soon as the sequence switch reaches position 5. Relay 1500, 115 upon reenergizing, closes the previously 120 traced circuit for driving the sequence switch 700 out of position 5 and into position 6. With the sequence switch 700 in position 6 and relay 1500 energized, the previously 125 traced circuit extending through the winding of updrive magnet 1502 of the switch TS is again established and the updrive

magnet again causes the upward movement of the switch shaft to move the selected sets of brushes over the selected groups of terminals in the bank to which the brushes have access, or until test brush 1506 engages a terminal in the bank 1507 upon which ground potential has been placed over a circuit extending through a wiper of the code register C. Upon the engagement of test brush 1506 with the terminal 1518, a circuit is established through the right-hand winding of relay 1500, which may be traced from battery through the right-hand winding of relay 1500, thence over the circuit previously traced to the test brush 1506, terminal 1518, conductor 1519, terminal 1130 and wiper 1131 of the code register C which was set by the calling subscriber in response to the third letter S in the same manner as the registers A and B, thence over conductor 1132 to ground at the upper left-hand contact of cam 731 (5 to 8). The current flowing through the right-hand winding of relay 1500 now differentially balances the relay causing its deenergization. Relay 1500, upon energizing, opens the previously traced circuit extending through the winding of updrive magnet 1502 to arrest the upward movement of the switch TS and at its left-hand armature and back contact closes the previously traced circuit for driving sequence switch 700 out of position 6 and into position 8. In passing out of position 6, the initial energizing circuit of relay 1500 is opened at the contact of cam 720 and in passing into position 7, a circuit is established for relays 1520 and 1521, which may be traced from battery through the windings of these relays in parallel, conductor 1522, the right-hand armature and back contact of relay 1523, conductor 1524 and thence to ground at the lower right-hand contact of cam 727 (7 to 14). Relays 1520 and 1521, upon energizing, connect the brushes of brush sets 1514 and 1515 to the windings of translator register control relays 1300, 1301, 1302, 1303, 1304 and 1305. During the setting of the translator switch TS and immediately following the setting of the code registers A, B and C, the calling subscriber has proceeded to dial the four numerical digits of the number of the desired line, causing the setting of the wipers of the thousands register TH upon the ninth set of terminals in the respective banks to which these wipers have access, the setting of the wipers of the hundreds register H upon the fifth set of terminals in the respective banks to which these wipers have access, the setting of the wipers of the tens register T upon the third set of terminals in the banks to which these wipers have access and the setting of the wipers of the units register U upon the ninth set of terminals in the banks to which these wipers

have access. Following the setting of the units register U, the steering switch RS moves its wipers to position 7.

Setting the translator register relays.

Upon the connection of register control relays 1300 to 1305 inclusive with the brushes of the brush sets 1514 and 1515 of the translator switch TS, impulses are transmitted thereto from the pulse machine drum 1523. In the case assumed, two impulses are transmitted from battery through the brush 1525, ring 1526, segments 1527, brush 1528, bank terminal 1529, brush 1530 of the translator switch, the inner left-hand armature and front contact of relay 1520, conductor 1531 and thence to ground through the winding of class register control relay 1300. Similarly, a circuit is established from battery through brush 1525, ring 1526, segment 1532, brush 1533, bank terminal 1534, brush 1535 of the translator switch, the inner right-hand armature and front contact of relay 1520, conductor 1537 and thence to ground through the winding of the district brush register control relay 1301. A circuit is closed for office brush register control relay 1302 which may be traced from battery through brush 1525, ring 1526, segments 1527, brush 1528, bank terminal 1540 and brush 1541 of the translator switch, the outer right-hand armature and front contact of relay 1520, conductor 1543 and thence to ground through the winding of relay 1302. The circuit of the district group register control relay 1303 may be traced from battery through brush 1525, ring 1526, segment 1538, brush 1539, bank terminal 1544 and brush 1545 of the translator switch, the inner right-hand armature and front contact of relay 1521, conductor 1547, and thence to ground through the winding of relay 1303. The circuit of office group register control relay 1304 may be traced from battery through brush 1525, ring 1526, segments 1527, brush 1528, bank terminal 1548 and brush 1549 of the translator switch, the inner left-hand armature and front contact of relay 1521, conductor 1551 and thence to ground through the winding of relay 1304. Talking selection register control relay 1305 is energized over a circuit extending from battery through brush 1525, ring 1526, segment 1532, brush 1533, bank terminal 1552 and brush 1553 of the translator switch, the outer left-hand armature and front contact of relay 1521, conductor 1555 and thence to ground through the winding of relay 1305. Control relay 1300, upon energizing, closes a circuit for energizing relays 1306 and 1307 extending from battery through the windings of these relays in parallel and thence to ground through the armature and front contact of relay 1300, and the im-

pulses received from the drum of the pulse machine by the relay 1300 are thus transmitted to the windings of relays 1306 and 1307. Similarly each of the control relays 5 establishes a circuit for two relays as clearly shown in Fig. 18. As soon as the impulse machine has rotated its drum to a point where brush 1528 engages the first segment 1527 and relays 1300, 1306 and 1307 are thus 10 energized, a circuit will be closed for the class register relay 1402 which may be traced from battery through brush 1525, ring 1526, segment 1556, brush 1557, conductor 1558, the inner left-hand armature and front contact of relay 1306, conductor 1308 and thence to ground through the 15 right-hand winding of class register relay 1402 to ground. This relay, upon energizing, closes a locking circuit for itself extending from ground through its left-hand winding, left-hand armature and front contact, conductor 1403, conductor 1309 and thence to battery through the left-hand contact of cam 736 (7 to 14 $\frac{1}{4}$). When the pulse 20 machine drum rotates to a position in which the second segment 1527 engages with brush 1528, a circuit is established for class register relay 1404 which may be traced from battery through brush 1525, ring 1526, segment 1559, brush 1560, conductor 1561, the outer left-hand armature and front contact of relay 1306, conductor 1310 and thence to ground through the right-hand winding of 25 relay 1404. Relay 1404, upon energizing, locks through its left-hand winding and left-hand armature and front contact to the locking conductor 1403 in the same manner as described in connection with relay 1402. 30 In view of the fact that the office in which the assumed call is being extended is reached through both a district selector and an office selector switch, the skip office register relay 1405 is not energized at this time. 35 In a manner similar to that above described, the other register relays are selectively set by the pulse machine through the operation of control relays 1301 to 1305 inclusive and the pairs of relays corresponding to relays 1306 and 1307 controlled thereby. The district brush register relay 1406 40 which was energized through the cooperation of the control relay 1301 and the pulse machine drum 1523, upon energizing, closes a locking circuit for itself extending from ground through its left-hand winding, inner left-hand armature and front contact, conductor 1407, conductor 1311 and thence to battery through the lower contact of cam 736 (7 to 13). The office brush register relay 1408 which was energized through the 45 cooperation of relay 1302 and the pulse machine drum 1523 closes a locking circuit for itself extending to the battery lead 1311. The compensating resistance register relay 1416 which was energized through the op-

eration of relay 1302 locks itself to the battery lead 1309. The district group register relay 1312 and the office group register relays 1409 and 1435 are also energized. Relays 1312 and 1409 close locking circuits for 50 themselves, extending through their respective left-hand windings and inner left-hand armatures and front contacts to locking conductor 1311, and relay 1435 locks to conductor 947. The talking selection register relay 1410, which was energized through the operation of control relay 1305 and the pulse machine drum, closes a locking circuit for itself through its left-hand winding and inner left-hand armature and front contact 55 to the battery lead 1309.

At the beginning of the transmission of impulses from the pulse machine to the translator register control relays, the translator control sequence switch 700 being in 60 position 8, a circuit is established from battery through brush 1525, ring 1526, timing segments 1562 of the pulse machine, brush 1563, conductor 1564, the lower contacts of cam 725 (8), conductor 735, the windings of 65 sender stepping relay 804, the armature and back contact of relay 805, the upper right-hand and lower left-hand contacts of cam 824, the upper contact of cam 745, the lower contacts of cam 825 (1 to 4) and thence to 70 ground through resistance element 807. At this time a circuit is also closed from the No. 6 counting relay 808 extending from battery through the inner left-hand armature and front contact of relay 705, conductor 739, the winding of relay 808, the armature and back contact of the upper No. 6' counting relay 809, lead 810, lead 810 75 Fig. 15, the outer right-hand armature and front contact of relay 1521, conductor 1565, conductor 811, the normally closed contacts of the inner left-hand armature of relay 812, the upper contacts of cam 818, the armature and front contact of armature 804 80 and to ground through the lower right-hand contact of cam 819 (1). In response to the first timing impulse through the stepping relay 804, the circuit just traced through counting relay 808 is closed and counting relay 808 energizes, closing a locking circuit for itself extending from battery through its winding, the winding of upper counting relay 809, the armature and front contact of relay 808 and thence to ground 85 over conductor 813 and the upper right-hand contact of cam 731 (8). Counting relay 809 does not energize in this locking circuit in view of the fact that its winding is shunted by ground connected to one terminal of its winding over lead 810 and the contact of stepping relay 804. As soon, however, as relay 804 deenergizes following the transmission of the first timing impulse, the shunt is opened and relay 809 energizes, 90 extending the circuit from lead 810 through 95 lead 810, lead 810 Fig. 15, the outer right-hand armature and front contact of relay 1521, conductor 1565, conductor 811, the normally closed contacts of the inner left-hand armature of relay 812, the upper contacts of cam 818, the armature and front contact of armature 804 100 and to ground through the lower right-hand contact of cam 819 (1). In response to the first timing impulse through the stepping relay 804, the circuit just traced through counting relay 808 is closed and counting relay 808 energizes, closing a locking circuit for itself extending from battery through its winding, the winding of upper counting relay 809, the armature and front contact of relay 808 and thence to ground 105 over conductor 813 and the upper right-hand contact of cam 731 (8). Counting relay 809 does not energize in this locking circuit in view of the fact that its winding is shunted by ground connected to one terminal of its winding over lead 810 and the contact of stepping relay 804. As soon, however, as relay 804 deenergizes following the transmission of the first timing impulse, the shunt is opened and relay 809 energizes, 110 extending the circuit from lead 810 through lead 810 Fig. 15, the outer right-hand armature and front contact of relay 1521, conductor 1565, conductor 811, the normally closed contacts of the inner left-hand armature of relay 812, the upper contacts of cam 818, the armature and front contact of armature 804 115 and to ground through the lower right-hand contact of cam 819 (1). In response to the first timing impulse through the stepping relay 804, the circuit just traced through counting relay 808 is closed and counting relay 808 energizes, closing a locking circuit for itself extending from battery through its winding, the winding of upper counting relay 809, the armature and front contact of relay 808 and thence to ground 120 over conductor 813 and the upper right-hand contact of cam 731 (8). Counting relay 809 does not energize in this locking circuit in view of the fact that its winding is shunted by ground connected to one terminal of its winding over lead 810 and the contact of stepping relay 804. As soon, however, as relay 804 deenergizes following the transmission of the first timing impulse, the shunt is opened and relay 809 energizes, 125 extending the circuit from lead 810 through lead 810 Fig. 15, the outer right-hand armature and front contact of relay 1521, conductor 1565, conductor 811, the normally closed contacts of the inner left-hand armature of relay 812, the upper contacts of cam 818, the armature and front contact of armature 804 130 and to ground through the lower right-hand contact of cam 819 (1). In response to the first timing impulse through the stepping relay 804, the circuit just traced through counting relay 808 is closed and counting relay 808 energizes, closing a locking circuit for itself extending from battery through its winding, the winding of upper counting relay 809, the armature and front contact of relay 808 and thence to ground over conductor 813 and the upper right-hand contact of cam 731 (8). Counting relay 809 does not energize in this locking circuit in view of the fact that its winding is shunted by ground connected to one terminal of its winding over lead 810 and the contact of stepping relay 804. As soon, however, as relay 804 deenergizes following the transmission of the first timing impulse, the shunt is opened and relay 809 energizes, extending the circuit from lead 810 through

the armature and front contact of relay 809, the armature and back contact of the upper No. 5' counting relay 814 to battery through the winding of the lower No. 5 counting relay 815. In a similar manner, counting relay 815 and the remaining counting relays of the series energize and lock up on succeeding impulses from the timing segments of the pulse machine until the lower No. 0 counting relay 816 and the upper No. 0' counting relay 817 energize. At this time seven impulses have been counted out, thus insuring a complete revolution of the pulse machine drum for transmitting the necessary impulses to set the translator register relays before relay 817 by its energization, initiates the movement of the sender sequence switch 800 out of normal position 1 into position 2 preparatory to closing the fundamental circuit for controlling the first selecting movement of the district selector 250.

Setting of class and compensating resistance switches.

Upon the energization of counting relay 817, a circuit is closed for control relay 915 of the class switch which may be traced from battery through the right-hand winding of relay 915, conductor 916, the outer left-hand armature and front contact of relay 1520, conductor 1566, conductor 740 and thence to ground at the armature and front contact of relay 817. Relay 915, upon energizing, closes a circuit for relay 924. With relays 915 and 924 energized, circuits are established for advancing class switch 900 out of the position in which it is standing into a position determined by the energized and deenergized condition of class register relays 1314, 1317, 1402 and 1404. It has been assumed that the subscriber has dialed the code of a full mechanical office and that, therefore, it is necessary to move class switch 900 into position 4. It will further be assumed that at this time the class switch is standing in position 12. A circuit is now established for driving the class switch out of position 12 and into position 14, which may be traced from battery through the winding of the driving magnet of class switch 900 and the left-hand winding of relay 915 in parallel, through the lower right-hand contact of cam 920 (6 to 13), the right-hand armature and back contact of class relay 1314, conductor 1315, conductor 1316, the contacts of route switch cam 918 (1) and thence to ground at the armature and front contact of relay 915. Class switch 900 upon reaching position 14 is driven through position 18 into position 1 over a circuit extending from battery through the magnet winding of switch 900 and the left-hand winding of relay 915 in parallel, the upper left-hand contact of cam 920 (13 to

18), conductor 919, the right-hand armature and back contact of class relay 1317 and thence to ground over conductor 1316 as previously traced. Upon reaching position 1, the class switch is driven into position 3 over a circuit extending from battery through the magnet winding of switch 900, the upper right-hand contact of cam 921 (1 and 2), conductor 922, the right-hand armature and front contact of class relay 1402 and thence to ground over conductor 1316 as previously traced. In position 3 a circuit is closed for driving the class switch into position 4 which circuit may be traced from battery through the magnet winding of switch 900, the lower left-hand contact of cam 921 (3), conductor 923, the right-hand armature and front contact of class relay 1404 and thence to ground as previously traced over conductor 1316. Upon reaching position 4, no circuit is closed through armature contacts of the class register relays for further advancing the class switch and the switch is therefore arrested in position 4.

It is to be noted in this connection that the class switch is wired to control the sender circuits for ten different classes of connections in ten of its resting positions and five of its resting positions are provided as spare positions for caring for classes of connections which may be necessary in the future.

During the stepping of the class switch, it is to be noted that the slow-to-release relay 915 is maintained energized in parallel with the winding of the driving magnet of class switch 900 and does not retract its armature until after the class switch has become arrested in a position corresponding to the class of the call which the subscriber has initiated.

Simultaneous with the setting of the class switch, the compensating resistance switch 950 is set in accordance with the energized or deenergized condition of the compensating resistance register relays 1413, 1414, 1415 and 1416, which relays are variously energized through the operation of control relays 1301 and 1302 and the operation of the pulse machine drum 1523 at the time the district brush and office brush register relays are operated.

The compensating resistance switch is provided for variously connecting resistance elements into the fundamental circuit during office selection and during selection beyond the originating office to maintain the resistance of the switch controlling or fundamental circuit approximately constant. For this purpose, the switch is divided into two sections, each section comprising a plurality of cam contacts and a series of resistance elements. By reference to Fig. 9 of the drawing, it will be noted that in positions 1 to 5 of the switch, a resistance element of

1200 ohms is connected into the fundamental circuit during office selection and that in the first five positions, either no resistance or resistance elements of 300, 600, 900 and 5 1200 ohms may be connected into the fundamental circuit during selection beyond the originating office dependent upon the particular route over which the connection is to be established. Similarly, in positions 6 to 10 9 inclusive, a resistance element of 900 ohms may be connected into the fundamental circuit during office selection and either no resistance or a resistance element of 300, 600, 900 or 1200 ohms may be connected into the 15 fundamental circuit during selection beyond the originating office. Thus, by moving the compensating resistance switch into any one of sixteen positions any one of five resistance values, 0, 300, 600, 900 or 1200 ohms may 20 be connected into the fundamental circuit both during office selection and selection beyond the originating office. It is to be understood that while resistances of certain values have been specified herein, that the 25 invention is not to be considered as limited to the use of any specific resistance values.

In the present description it has been assumed that the calling subscriber has initiated a call to an office designated, for example, "Lispenard", and it will be further assumed that the trunk line leading from the originating office to the Lispenard office is of such resistance that it is necessary to add 600 ohms resistance to the circuit to 30 raise the resistance of the circuit to 1200 ohms, which has been taken as the efficient working resistance for the fundamental circuit. Since the office selector 350 is located in the originating office and the resistance 35 of the circuit extending from the sender to the office selector is therefore negligible, it is, therefore, necessary to add 1200 ohms resistance to the fundamental circuit during office selection. In order to add 1200 ohms 40 to the fundamental circuit during office selection and 600 ohms during selection beyond the originating office, it is necessary to move the compensating resistance switch 950 from the position in which it is resting into 45 position 4.

Assuming that the switch 950 at the time the sender is seized is resting in position 5 and that the office code that the calling subscriber has dialed has caused the energization 55 of compensating resistance relay 1416 for driving the switch 950 into position 4, the switch 950 is advanced from position 5 into position 4 by the following circuits: Switch 950 is advanced from position 5 into 60 position 9 over a circuit which may be traced from battery through the magnet winding of switch 950 and the winding of relay 952 in parallel, the upper left-hand contact of cam 926 (5 to 8), conductor 1417, the right-hand armature and back contact of com-

pensating resistance relay 1414, conductor 1002, the contacts of route switch cam 925 (1) and thence to ground at the inner left-hand armature and front contact of relay 924. Upon reaching position 9, switch 950 70 is driven into position 1 by a circuit extending in parallel through the winding of magnet 950 and the winding of relay 952, the lower left-hand contact of cam 926 (9 to 18), conductor 1418, the right-hand armature and front contact of compensating resistance relay 1416 and thence to ground over the circuit previously traced at the inner left-hand armature and front contact of relay 924. Upon reaching position 1, switch 950 is advanced into position 3 over a circuit extending through the magnet winding of switch 950, the lower right-hand contact of cam 927 (1 and 2), conductor 1419, the right-hand armature and back contact of relay 1413 and thence to ground at the contact of relay 924, over the circuit previously traced. From position 3, switch 950 is advanced into position 4 over a circuit extending through the upper left-hand contact of cam 927, conductor 1420, the right-hand armature and back contact of compensating resistance relay 1415 and thence to ground at the armature and front contact of relay 924 over the circuit previously traced. When the switch reaches position 4, there is no circuit available through contacts of the compensating resistance register relays for further advancing the switch and it is therefore arrested in position 4, in which position the 1200 ohm resistance element 930 is connected through the lower left-hand contact of cam 928 (4) and the 600 ohm resistance element 931 is connected through the lower right-hand contact of cam 929 (4).

Since the connection assumed is a full mechanical connection, the route switch 990 is not moved out of its normal resting position 1, since at this time the route relays 1421 and 1422 have not been operated by the code which the calling subscriber dialed. As the calling subscriber is also attempting to establish a connection to a zone of the exchange with which he is entitled to establish connections for a single unit message rate, neither of the zone relays 1423 and 1424 will be energized at this time for advancing the route switch 990.

Restoration of translator switch.

Relay 915, upon energizing at the time the setting of the class switch was initiated, establishes a circuit for relay 1523 Fig. 15, which may be traced from battery through the winding of relay 1523, conductor 1567 and thence to ground at the armature and front contact of relay 915. Relay 1523, upon energizing, closes a locking circuit for itself extending through its right-hand ar-

mature and front contact, over conductor 1524 and thence to ground at the right-hand contact of cam 727 (7 to 14). At its right-hand armature and back contact relay 1523 5 opens the energizing circuit of relays 1520 and 1521 which thereupon deenergize, disconnecting the pulse machine from the windings of translator register control relays 1300 to 1305 inclusive. Upon the deenergization of relay 1520, the initial energizing circuit of relay 915 is opened and as soon as the driving circuit of the class switch 900 is 10 opened when the switch reaches position 4, relay 915 deenergizes and at its armature and front contact opens the initial energizing circuit of relay 1523 and at the back contact of its armature establishes a circuit for advancing control sequence switch 700 out of position 8 and into position 9. This latter 15 circuit may be traced from battery through the magnet winding of switch 700, the upper right-hand contact of cam 722 (8), conductor 741, the left-hand armature and front contact of relay 1523, conductor 1568, the 20 left-hand armature and back contact of relay 917 and thence to ground at the armature and back contact of relay 915. It is to be noted that sequence switch 700 cannot be advanced into position 9 during the setting 25 of either the class switch 900 or the route switch 990, that is, while either relays 915 or 917 are energized.

When the control sequence switch 700 reaches position 9, a circuit is established for 30 release relay 1569 of the translator switch TS, which may be traced from battery through the right-hand non-inductive winding of relay 1569 through the left-hand operating winding of this relay, conductor 1570 35 and thence to ground through the lower right-hand contact of cam 730 (9 to 18). Relay 1569, upon energizing, closes a circuit for the downdrive magnet 1571, extending from battery through the winding of magnet 40 1571 and thence to ground through the armature and front contact of relay 1569. The energization of magnet 1571 presses the 45 depending portion of the switch shaft 1504 against the constantly rotating downdrive drum 1572, thereby driving the switch shaft 50 downwardly into its normal position. When the switch shaft 1504 reaches normal position, the off-normal contacts 1573 are closed connecting ground potential through the 55 lower left-hand contact of cam 742 (2 to 18), over conductor 1574, contacts 1573 to a point between the right-hand non-inductive and left-hand operating windings of relay 1569, shunting out the operating winding of this 60 relay thereby causing the relay to deenergize. Through the restoration of the translator switch shaft 1504, the tripped brush sets 1514 and 1515 are again restored to their 65 normal untripped positions in the well-known manner. The translator switch TS

and the circuits associated therewith are now in normal condition.

With control sequence switch 700 in position 9, a circuit is now established for moving sender sequence switch 800 out of position 1 and into position 2 preparatory to the establishment of a fundamental circuit between the district selector switch 250 and the office sending mechanism. This circuit may be traced from battery through the 70 winding of the magnet of sequence switch 800, the lower left-hand contact of cam 820 (1), conductor 821, the outer right-hand armature and front contact of office brush register relay 1406, the outer right-hand armature and front contact of energized district brush register relay 1408, conductor 1411, the outer left-hand armature and front contact of energized district group register relay 1312, conductor 1313, the outer right-hand armature and front contact of energized office group register relay 1409, the outer right-hand armature and front contact of energized talking selection register relay 1410 and thence over conductor 1412 to 75 ground at the lower right-hand contact of cam 731 (8 3/4 to 9).

With control sequence switch 700 in position 9, sender sequence switch 800 in position 2, class switch 900 in position 4, compensating resistance switch 950 in position 4, route switch 990 in position 1 and translator register relays locked up in accordance with the office code dialed by the calling subscriber, the sending mechanism proceeds to 80 operate the district selector 250 in its brush selection movement.

If the calling subscriber has finished dialing at this time, steering switch RS will be 85 in position 7 and a circuit is now closed for buzzing the time measure switch TM from position 6 into position 11. This circuit may be traced from battery through the winding and armature contacts of magnet 711, wiper 715, terminals Nos. 6 to 10 of the 90 bank with which wiper 715 is associated, conductors 773, 1218, and 1328, the lower contacts of class switch cam 953 (4), conductor 954 and thence to ground at the lower right-hand contact of cam 756 (9 to 13).

District brush selection.

A fundamental circuit is now established from battery through the left-hand winding 100 of relay 228 of the district selector, the left-hand contacts of cam 210, conductor 262, the outer right-hand armature and front contact of relay 230, wiper 237, conductor 743, the outer left-hand armature and back contact of relay 802, the left-hand contact of cam 744 (9 to 12), the right-hand contact of cam 834 (2), the left-hand winding of polarized overflow relay 823, the windings of sending stepping relay 804, the armature and back contact of relay 805, the upper right-hand 105

and lower left-hand contacts of cam 824, the upper contact of cam 745 (5 to 9), the lower contacts of cam 825 (1 to 4) and to ground through resistance element 807. Resistance element 807 is of such resistance that the approximate resistance of the fundamental circuit just traced aside from the resistance of relay 228, is 1200 ohms. Line relay 228 of the district selector switch and the stepping relay 804 of the office sender are energized in this circuit.

Relay 228, upon energizing, closes a circuit for driving sequence switch 200 of the district selector out of position 3 and into position 4. This circuit extends through the magnet winding of sequence switch 200, the lower right-hand contact of cam 206 (3), the inner right-hand armature and front contact of relay 228 and thence to ground at the right-hand contact of cam 207. With the district selector sequence switch 200 in position 4, relay 228 is locked to the fundamental circuit through its left-hand armature and front contact and the lower right-hand contact of cam 210 (1 to 6), and a circuit is closed for the updrive magnet 238 which extends from battery through the winding of magnet 238, the right-hand contact of cam 208 (4) and thence to ground through the inner right-hand armature and front contact of relay 228 and the right-hand contact of cam 207. Magnet 238, upon energizing, presses the depending portion of the switch shaft 239 against the constantly rotating updrive drum 240 thereby causing the upward movement of the switch shaft.

As the switch shaft 239 approaches its first brush selection position, the brush 241 engages the first conducting portion of the commutator segment 242 and a shunt circuit is established around the windings of the sender stepping relay 804 which may be traced from battery through the left-hand winding, left-hand armature and front contact of relay 228, the lower right-hand contact of cam 210, the upper left-hand contact of cam 211 (3 to 4), conductor 243, segment 242, brush 241 and thence to ground at the lower contact of cam 209 (9 to 7). Relay 228 is maintained energized over the shunt circuit, but sender stepping relay 804 is caused to deenergize. As the switch shaft 239 continues in its upward movement, the brush 241 engages an insulating portion of the segment 242 and the shunt circuit previously traced is opened, whereby the sender stepping relay 804 again energizes. Thus, during the upward movement of the switch shaft, relay 804 is intermittently energized and deenergized.

Under the assumption that the district brush translator register relays have been so set by code impulses dialed by the calling subscriber as to energize and lock up only

the district brush relay 1406, a circuit is established upon the first energization of stepping relay 804 following the establishment of the fundamental circuit which may be traced from battery on conductor 739 through the lower No. 2 counting relay 826, the armature and back contact of the upper No. 2' counting relay 827, lead 828, lead 829 Fig. 14, the inner right-hand armature and front contact of relay 1406, conductor 1427, the right-hand armature and back contact of relay 1321, route switch cam 932 (1), the upper right-hand contact of cam 829 (2), conductor 830, the right-hand contact of cam 746 (9 to 12), conductor 811, the normally closed contacts associated with the inner left-hand armature of relay 812, the upper right-hand and lower left-hand contacts of cam 818, the armature and front contact of stepping relay 804 and thence to ground through the upper right-hand contact of cam 819 (2). The upper counting relay 827 does not energize until stepping relay 804 deenergizes at the time the brush 241 of the district switch engages the first conducting portion of segment 242. Upon the energization of relay 827, lead 828 is extended through the armature and front contact of relay 827, the armature and back contact of the No. 1' counting relay 832 and thence to battery through the winding of the No. 1 counting relay 831. Upon the second deenergization of stepping relay 804, relay 832 becomes energized and connects lead 828 to the counting relay 816 and in response to the next deenergization of relay 804, the No. 0' counting relay 817 is energized, closing a circuit for driving the sender sequence switch 800 out of position 2 and into position 4. This circuit may be traced from battery through the winding of the magnet of sequence switch 800, the upper right-hand contact of cam 820 (2), conductor 833 and thence to ground at the armature and contact of counting relay 817. Sequence switch 800, upon leaving position 2, opens the locking circuits of all counting relays which have been locked up at the upper left-hand contact of cam 819 (2).

At the time the upper No. 0' counting relay 817 energized in response to the last deenergization of stepping relay 804, relay 805 was energized in parallel therewith, opening at its armature and back contact the previously traced fundamental circuit. As soon thereafter as the brush 241 engages the next insulating portion of commutator segment 242, the circuit of relay 228 now being opened, this relay deenergizes, closing a circuit for driving the sequence switch 200 out of position 4 and into position 5, this circuit extending from battery through the magnet winding of sequence switch 200, the upper left-hand contact of cam 206 (4),

the inner right-hand armature and back contact of relay 228 and thence to ground at the right-hand contact of cam 207. As soon as relay 228 deenergizes, the circuit 5 previously traced through the winding of updrive magnet 238 is opened at the inner right-hand armature and front contact of relay 228 and the upward movement of the switch shaft is arrested. With sequence 10 switch 200 in position 5 and the sender sequence switch 800 in position 4, the previously traced fundamental circuit is again established and relays 228 and 804 again energize. Relay 228, upon energizing, 15 causes the movement of the district selector sequence switch 200 from position 5 into position 6, the initial energizing circuit of relay 228 being opened as previously described at the lower left-hand contact of cam 210 as soon as the sequence switch 20 10 leaves position 5. Relay 228 remains energized, however, over the fundamental circuit through its left-hand winding, left-hand armature and front contact and the 25 lower right-hand contact of cam 210.

District group selection.

When sequence switch 200 reaches position 6, the circuit previously traced for the 30 updrive magnet 238 is again established through the upper right-hand contact of cam 208 (6) and the inner right-hand armature and front contact of relay 228 and in the manner previously described, the switch 35 shaft 239 is again driven upwardly. Since at this time, however, the tripping spindle 246 has been rotated by the tripping magnet 247 in position 5 of sequence switch 200 over a circuit extending from battery through 40 the winding of magnet 247 and to ground through the lower right-hand contact of cam 205 (5 to 7), the third set of brushes is now tripped upon the initial upward movement of the switch shaft 239, and during 45 the continued upward movement of the shaft, the brushes travel over the bank with which they are associated. The remaining four sets of brushes on the switch shaft are not tripped at this time and are therefore 50 functionless. As the switch shaft approaches its first group selection position, the brush 248 engages the first metallic portion of the group selection segment of the commutator and a circuit is closed in shunt 55 of the windings of the sending stepping relay 804, which may be traced from battery through the left-hand winding, left-hand armature and front contact of relay 228, the right-hand contacts of cam 210, segment 249 60 and thence to ground at the lower contact of cam 209. Relay 228 is maintained energized over this circuit, but sender stepping relay 804 becomes deenergized. As the switch shaft continues in its upward movement 65 and the brush 248 engages the first

insulating portion of segment 249, the shunt circuit is opened and sending stepping relay 804 again energizes. In this manner during the upward movement of the switch shaft in its group selection movement, the 70 sender stepping relay 804 intermittently energizes and deenergizes.

Upon the first energization of stepping relay 804, a circuit is closed for the No. 0 counting relay 816, it being assumed that 75 the calling subscriber has dialed such a code as to energize only the district group register relay 1312. This circuit may be traced through the winding of counting relay 816, conductor 835, the inner right-hand armature and back contact of district group register relay 1428, conductor 1429, the upper left-hand contact of cam 836 (3 to 4), conductor 837, the No. 0 lead 838, lead 838 Fig. 13, the outer left-hand armature and 80 back contact of district group register relay 1318, conductor 1319, the outer left-hand armature and back contact of district group register relay 1425, conductor 1426, the right-hand armature and front contact of 85 register relay 1312, conductor 1320, the lower contact of route switch cam 934 (1), the lower left-hand contact of cam 829 (4), conductor 830, the left-hand contact of cam 746 (9 to 12), the normally closed contacts 90 associated with the inner left-hand armature of relay 812, the upper contacts of cam 818, the armature and front contact of stepping relay 804 and thence to ground through the lower right-hand contact of cam 819 (4). 100 Counting relay 816, upon energizing, closes a locking circuit for itself extending through the winding of the No. 0' counting relay 731, through the armature and front contact of relay 816 and thence to ground through the lower left-hand contact of cam 819 (4). Upon the first deenergization of sending stepping relay 804, relay 817 energizes in parallel with relay 805 and closes at its 105 armature and front contact the previously traced circuit for driving sequence switch 800 out of position 4 and into position 6. Upon leaving position 4, the locking circuit extending through the windings of counting relays 816 and 817 is opened at the 110 contact of cam 819 and these relays thereupon deenergize. Relay 805, upon energizing, opens the fundamental circuit at its armature and back contact thereby causing the deenergization of line relay 228 of the 115 district selector switch, as soon as brush 248 engages the next insulating portion of segment 249.

Relay 228, upon deenergizing, opens at its inner right-hand armature and front contact the previously traced circuit of the updrive magnet 238, thereby arresting the upward movement of the switch shaft for positioning the tripped set of brushes in engagement with the first set of terminals of the 120 130

first group in the bank. At its inner right-hand armature and back contact, relay 228 closes the previously traced circuit for driving sequence switch 200 out of position 6 and into position 7. In position 7, relay 228 again energizes over a circuit extending from battery through its right-hand winding, the upper contacts of cam 204, the right-hand armature and front contact of relay 226 and thence to ground at the upper right-hand contact of cam 205 (17 to 15). Relay 228, upon energizing, closes a circuit for driving sequence switch 200 out of position 7 and into position 8, which circuit may be traced from battery through the magnet winding of the sequence switch, the lower right-hand contact of cam 206, the inner right-hand armature and front contact of relay 228, the upper left-hand contact of cam 207 (7 to 8) and thence to ground at the right-hand armature and front contact of relay 227.

As soon as sequence switch 200 leaves position 7, the initial energizing circuit of relay 228 is opened at the contacts of cam 204, but relay 228 remains locked over a circuit extending from battery through its left-hand winding, its left-hand armature and front contact, the upper left-hand and lower right-hand contacts of cam 216, the outer right-hand armature and front contact of relay 228, the lower contact of cam 224 (7 to 8) to the test brush 252 and if the first trunk of the selected group is busy, to ground at the test terminal 253 of such busy trunk. Upon reaching position 8 with relay 228 energized, a circuit is established for the updrive magnet 238 which may be traced from grounded battery through the magnet 238, the upper right-hand contact of cam 208 (8) the inner right-hand armature and front contact of relay 228 and to ground at the upper right-hand contact of cam 207. The updrive magnet 238 again causes the switch shaft to be driven upwardly in search of an idle trunk in the selected group. So long as the test brush 252 encounters the terminals of busy trunks, relay 228 remains locked up. When, however, an idle trunk is encountered, which it will be assumed is the trunk terminating in terminals 255, 256 and 257, the locking circuit of relay 228 is opened and relay 228 deenergizes as soon as brushes 252, 258 and 259 have been properly centered on the bank terminals 255, 256 and 257. Until the brushes are so centered, relay 228 remains locked over a circuit extending through its right-hand winding, right-hand contacts of cam 217, the brush centering segment 260, brush 261, the upper left-hand contact of cam 208 (8), the inner right-hand armature and front contact of relay 228 and thence to ground at the right-hand contact of cam 207.

Upon the deenergization of relay 228, the circuit of the updrive magnet 238 is opened

and the upward movement of the switch shaft is thereby arrested, and a circuit is closed at the inner right-hand armature and back contact of relay 228 for driving sequence switch 200 out of position 8 and into position 9. Upon reaching position 8½, busy ground potential is connected to the multiples of test terminal 255 of the selected trunk over brush 252, commutator brush 251, overflow segment 279 and to ground through the upper right-hand and lower left-hand contacts of cam 216.

Relay 228 again energizes when sequence switch 200 reaches position 9 over a circuit extending from battery through its right-hand winding, the upper contacts of cam 217, the upper contact of cam 218 (1 to 10) and thence to ground at the armature and front contact of relay 261. Relay 261 is at this time energized over a circuit extending from battery through its winding, the left-hand contacts of cam 215, wiper 232, conductor 709, the windings of relay 707 and thence to ground at the outer left-hand armature and front contact of relay 706. Relay 228, upon energizing the circuit previously traced, closes a circuit through its inner right-hand armature and front contact for driving sequence switch 200 out of position 9 and into position 10, in which position the fundamental circuit is extended through contacts of sequence switch cams 219 and 220, through brushes 258 and 259, respectively of the district selector switch 250 to the line relay 312 of the office selector switch 350.

This fundamental circuit may be traced from battery through the right-hand winding of relay 312, the lower contacts of cam 302, the upper trunk conductor 313, bank terminal 257 and brush 259 of the district selector, the upper left-hand and lower right-hand contacts of cam 220, conductor 262, the outer right-hand armature and contact of relay 230, wiper 237, conductor 743, the outer left-hand armature and back contact of relay 802, the left-hand contact of cam 744 (9 to 12), the right-hand contact of cam 834 (6), the left-hand winding of overflow relay 823, the windings of sender stepping relay 804, the armature and back contact of relay 805, the right-hand winding of overflow relay 823, the winding of trunk test relay 839, the lower contacts of cam 824, conductor 840, the lower left-hand contact of compensating resistance switch cam 928 (4); resistance element 930, conductor 935, the right-hand contact of cam 841 (6 to 10), conductor 842, the right-hand contact of cam 749, the left-hand armature and back contact of advance relay 750, conductor 751, wiper 263, the left-hand armature and front contact of relay 244, conductor 264, the lower right-hand and upper left-hand contacts of cam 219, brush 258 and bank terminal 256 of district selector

250, trunk conductor 314 and thence to ground through the left-hand contacts of cam 303.

If the calling subscriber had dialed a code such as to route a call through a group of the district selector above the fourth group, then the district group register relay 1428 would have become energized. Considering such a case and assuming that both district group register relays 1312 and 1428 are energized, then upon the energization of sender stepping relay 804 at the beginning of district group selection, a circuit is effective for the No. 9 counting relay 846 which may be traced from battery through the winding of relay 846, the armature and back contact of the No. 9' counting relay 847, conductor 1430, the inner right-hand armature and front contact of relay 1428, conductor 1429, the upper left-hand contact of cam 836 (3 and 4), conductor 837, lead 838, lead 838 Fig. 13, the outer left-hand armature and back contact of relay 1318, conductor 1319, the outer left-hand armature and back contact of relay 1425, conductor 1426, the right-hand armature and front contact of relay 1312, conductor 1320, the lower contact of cam 934, the lower left-hand contact of cam 829, conductor 830, the right-hand contact of cam 746, conductor 811, the normally closed contacts associated with the inner left-hand armature of relay 812, the upper contacts of cam 818, the armature and front contact of relay 804 and thence to ground at the lower right-hand contact of cam 819. In response to successive energizations and deenergizations of relay 804, the counting relays are operated in succession until the No. 5' counting relay 814 becomes operated. When the circuit just traced becomes extended through the armature and front contact of relay 814, the lower right-hand contact of cam 843, conductor 844, the outer right-hand armature and front contact of relay 1428, conductor 835 and thence to battery through the winding of the No. 0 counting relay 816. Thus, in response to six energizations and deenergizations of stepping relay 804, the No. 0' relay becomes operated and in the manner previously described, the sender sequence switch 800 is advanced into position 6. Thus, by the provision of relay 1428, five additional pairs of counting relays may be inserted in the chain of counting relays when it is necessary to set the district to select more than five groups of terminals.

Office brush selection.

Upon the extension of the fundamental circuit from the sender to the office selector switch 350, relay 312 of the office selector, sender stepping relay 804 and trunk testing relay 839 become energized. Relay 839, upon energizing, closes an obvious circuit

for relay 845, which at its outer left-hand armature and front contact establishes a circuit through the upper left-hand contact of cam 820 (6) for advancing the sender sequence switch 800 into position 8. When sequence switch 800 leaves position 8, the fundamental circuit previously traced through the winding of relay 839 and the right-hand winding of polarized relay 823 are shifted at the sender through the upper right-hand contact of cam 824 (7 to 11) and through the lower left-hand contact of this cam, thereby eliminating the winding of relay 839 and the right-hand winding of relay 823 from the fundamental circuit.

Relay 312, at the office selector upon energizing, closes a circuit for driving sequence switch 300 out of its normal position into position 2, this circuit extending from battery through the magnet winding of switch 300, the upper left-hand contact of cam 304 (1), conductor 315 and thence to ground through the left-hand armature and front contact of relay 312. Sequence switch 300, upon leaving position 1, opens the initial energizing circuit of relay 312 extending over the fundamental circuit as previously traced, but relay 312 locks itself in the fundamental circuit, through its right-hand winding, its inner right-hand armature and front contact and the upper left-hand contact of sequence switch cam 305 (1 to 4). When the sequence switch 300 reaches position 2, a circuit is closed for the updrive magnet 316 which may be traced from battery through the winding of this magnet, the upper right-hand contact of cam 304 (2), conductor 315, thence to ground at the left-hand armature and front contact of relay 312. The magnet 316, upon energizing, presses the depending portion of the switch shaft 317 against the constantly rotating updrive drum 318 and thereby causes the upward movement of the switch shaft. As the switch shaft approaches its first brush tripping position, the brush 322 engages a conducting portion of segment 320 of the commutator 321 and a circuit is closed in shunt of the windings of the sender stepping relay 804. This shunt circuit may be traced from battery through the right-hand winding and inner right-hand armature and front contact of relay 312, the left-hand contact of cam 305, the right-hand contacts of cam 302, conductor 319, brush selection segment 320, brush 322, conductor 323 and thence to ground at the left-hand contact of cam 306 (7 to 5). As the switch shaft continues to advance upwardly, the brush 322 engages an insulating portion of segment 320 and the previously traced circuit is opened. In this manner as the switch shaft 317 moves upwardly, the shunt circuit is intermittently established and upon each establishment of the shunt circuit, re-

lay 312 is maintained energized over the shunt and the sender stepping relay 804 becomes deenergized.

With the sender sequence switch in position 8 and the sender stepping relay 804 energized over the fundamental circuit and under the assumption that the code dialed by the calling subscriber has caused the energization of office brush register relay 1408, a circuit is established for the No. 2 counting relay 826. This circuit may be traced from battery through the winding of relay 826, the armature and back contact of the No. 2' counting relay 827, lead 828, lead 1431 Fig. 14, the inner right-hand armature and front contact of relay 1408, conductor 1432, the right-hand armature and back contact of relay 1322, conductor 1323, the lower contact of route switch cam 936 (1), the upper left-hand contact of cam 829 (8), conductor 830 and thence to ground through the armature and front contact of relay 804 and the contact of cam 819 as previously traced. In the manner previously described, the counting relays are successively energized until the No. 1' counting relay becomes energized when the previously traced circuit is extended from lead 828, through the armature and front contact of counting relay 832, the lower contact of cam 836 (5 to 8) and to battery through the winding of the No. 0 counting relay 816. Upon the energization of relay 816, a locking circuit is closed therefore through the winding of the No. 0' counting relay 817, which latter relay energizes in series with relay 816 upon the next deenergization of stepping relay 804. Relay 817, upon energizing, closes the previously traced circuit for driving sequence switch 800 out of position 8 and into position 10, thereupon opening the locking circuits of the counting relays at the upper left-hand contact of cam 819. Relay 805 energizes in parallel with relay 817 and at its armature and back contact opens the fundamental circuit.

As soon, following the opening of the fundamental circuit, as the brush 322 engages the next insulating portion of commutator segment 320, relay 312 deenergizes, opening at its left-hand armature and front contact the circuit previously traced through the winding of the updrive magnet 316 for arresting the upward movement of the switch shaft and at its left-hand armature and back contact closes a circuit for driving sequence switch 300 out of position 2 and into position 3. This circuit may be traced from battery through the winding of the magnet of sequence switch 300, conductor 324, the left-hand contact of cam 307 (2), conductor 325 and thence to ground at the left-hand armature and back contact of relay 312. The switch shaft of the office selector has now moved upwardly to position the

third set of brushes in such a position as to be tripped upon a subsequent upward movement of the switch shaft. With sequence switch 300 in position 3, a circuit is now closed for tripping magnet 326 for tripping the selected set of brushes, which circuit may be traced from battery through the winding of magnet 326 and thence to ground through the upper right-hand contact of cam 308 (3 to 4). 75

Office group selection.

With sequence switch 300 in position 3 and sender sequence switch 800 in position 10, the fundamental circuit previously traced is again closed and relay 312 of the office selector and stepping relay 804 of the office sender again energize over the fundamental circuit last traced. Relay 312, upon energizing, closes the circuit previously traced extending from the upper left-hand contact of cam 304 for driving sequence switch 300 out of position 3 and into position 4. Upon leaving position 3, the initial energizing circuit of relay 312 is opened, but relay 312 remains locked to the fundamental circuit through the left-hand contact of cam 305. Sequence switch 300, upon reaching position 4, again closes the circuit of the updrive magnet 316, which upon energizing, drives the switch shaft upwardly. During the initial upward movement of the switch shaft, the selected set of brushes, in this instance the third set of brushes, is tripped and the brushes thereafter wipe over the terminals of the bank to which they have access during the continued upward movement of the switch shaft. As the switch shaft approaches its first group selection position, the brush 329 engages a conducting portion of the commutator segment 328 and a circuit is closed in shunt of the windings of the sender stepping relay 804 which may be traced from battery through the right-hand winding, the inner right-hand armature and front contact of relay 312, the left-hand contact of cam 305, the lower right-hand and upper left-hand contacts of cam 302, conductor 327, segment 328, brush 329, conductor 323 and thence to ground at the left-hand contact of cam 306 (7 to 5). As the switch shaft continues in its upward movement, the brush 329 engages an insulating portion of segment 328 and the previously traced shunt circuit is again opened. In this manner, as the switch shaft moves upwardly, the shunt circuit around the windings of sender stepping relay 804 is intermittently established and opened and the sender stepping relay 804 is intermittently operated. Relay 312, however, is maintained energized over the previously traced shunt circuit. 115

Upon the first closure of the fundamental circuit with the sender sequence switch 800 in position 10 and under the assumption 130

that office group register relays 1409 and 1435 are at the time energized, a circuit is established for the No. 2 counting relay 826 extending from battery through the 5 winding of relay 826, the armature and back contact of relay 827, lead 828, lead 1433 Fig. 14, inner right-hand armature and contact of relay 1409, conductor 1434, the right-hand armature and back contact of relay 10 1324, conductor 1325, the lower contact of route switch cam 937 (1), the lower right-hand contact of cam 829 (10), conductor 830, the right-hand contact of cam 746 (9 to 12), conductor 811, the normally closed 15 contacts associated with the inner left-hand armature of relay 812, the upper right-hand and lower left-hand contacts of cam 818, the armature and front contact of relay 804 and thence to ground through the upper 20 right-hand contact of cam 819 (10). In response to successive operations of relay 804, the counting relays are operated and locked up until the No. 1' counting relay 832 becomes energized when lead 828 becomes extended 25 through the armature and front contact of relay 832, over conductor 837, the upper right-hand contact of cam 836 (9 to 10), conductor 1436, the inner right-hand armature and front contact of relay 1435, 30 conductor 1430, the armature and back contact of the No. 9' counting relay and to battery through the No. 9 counting relay 846. In response to further operations of 35 relay 804, the counting relays operate in succession until the No. 5' counting relay operates when lead 828 becomes extended over the path previously traced through the armatures and front contacts of counting relays 827, 832, 847, 866, 849, 809 and 814 40 through the lower left-hand contact of cam 843 (9 to 10), conductor 850, the outer right-hand armature and front contact of relay 1435, conductor 835 and thence to battery through the winding of counting relay 816. 45 Counting relay 816, upon energizing, locks up in the manner previously described through the winding of the No. 0' counting relay 817 and upon the next succeeding deenergization of stepping relay 804, 50 counting relay 817 becomes energized and at its armature and front contact closes the circuit previously traced for advancing sender sequence switch 800 out of position 10 and into position 12.

55 It is to be noted that seven impulses have been counted out for setting the brushes of the office selector upon the lowermost set of terminals of the seventh group of its bank. If it had been desired to select one of the 60 first five groups of the bank, then only a maximum of five pairs of counting relays would be employed and in such a case, the code dialed by the calling subscriber would not have energized the district group register relay 1435 and therefore the last five 65

pairs of counting relays Nos. 5 to 9 inclusive would not be interposed between the No. 1 pair of counting relays and the No. 0 pair of counting relays.

At the time counting relay 817 energized, 70 relay 805 energized in parallel therewith and at its armature and back contact opened the fundamental circuit. Upon the movement of sequence switch 800 into position 12, the counting relays which have been energized and locked up for controlling the group selection movement of the office selector are released through the opening of their locking circuits at the upper left-hand contact of cam 819. As soon following the 80 opening of the fundamental circuit as the brush 329 engages the next insulating portion of commutator segment 328, relay 312 of the office selector switch deenergizes, opening the circuit of the updrive magnet 316 and closing the previously traced circuit for driving sequence switch 300 out of position 4 and into position 5.

Upon reaching position 5, sequence switch 300 closes a local circuit for relay 312 which 90 may be traced from battery through the left-hand winding of relay 312 and to ground through the lower contacts of cam 303. Relay 312, upon energizing, closes a locking circuit for itself extending from its 95 right-hand winding through its right-hand armatures and front contacts, the lower contact of cam 309 (5 to 6), test brush 330 and to ground on the multiples of the test terminals of the first trunk in the group to 100 which the selecting set of brushes has been moved if this trunk is at the time busy. Relay 312, upon energizing, also closes the previously traced circuit for driving sequence switch 300 out of position 5 and into 105 position 6. Upon leaving position 5, the initial energizing circuit of relay 312 is opened at the contact of cam 303, but relay 312 is maintained energized over the previously traced locking circuit if the first 110 trunk in the selected group is busy. As soon as sequence switch 300 leaves position 6, the previously traced circuit is closed for energizing the updrive magnet 316, which thereupon causes the selected set of brushes to be driven upwardly over the selected group of trunk terminals to which it has access. As soon as test brush 330 engages the test terminal of an idle trunk, which 115 it will be assumed is the trunk 419 and 420 shown on the drawing, relay 312 deenergizes, opening at its left-hand armature and front contact the circuit of the updrive magnet 316, thereby arresting the upward movement of the switch shaft. Relay 312 does not 120 deenergize, however, until the brushes of the switch have been centered upon the terminals of the idle trunk, since it is held energized over a locking circuit extending from battery through its left-hand winding, the left- 125 130

hand contacts of cam 303, centering segment 331 of the commutator 321, brush 332, conductor 323, the lower left-hand contact of cam 304 (6), conductor 315 and thence to ground at the left-hand armature and front contact of relay 312.

Relay 312, upon deenergizing, closes a circuit extending from its left-hand armature and back contact over conductor 325 and the lower left-hand contact of cam 307 (6) for driving sequence switch 300 out of position 6 and into position 7. Upon reaching position 7, relay 312 is again energized over a circuit extending through its left-hand winding, the lower contacts of cam 303 and closes a locking circuit for itself extending through its right-hand winding, its inner right-hand armature and front contact, the lower right-hand contact of cam 305 and thence to ground at the lower contact of cam 308 (2 to 7½). As soon as sequence switch 300 leaves position 7½, relay 312 is maintained energized over a circuit extending over sleeve conductor 333, test terminal 255 and brush 252 of a district selector switch and thence to ground over the circuit previously traced at the lower left-hand contact of cam 216. Ground potential from conductor 333 is also connected over the right-hand contacts of cam 305 and test brush 330 to the multiples of test terminals 354 of the selected trunk circuit for marking the trunk circuit busy to all other office selector switches having access thereto. Relay 312, upon energizing, also closes a circuit for driving sequence switch 300 out of position 7 and into position 8, in which position the fundamental circuit is extended through contacts of cam 310 and 311 and brushes 334 and 335 to the selected trunk circuit terminating in an incoming selector switch 450.

The fundamental circuit may now be traced from battery through the left-hand winding of relay 421, the upper contacts of cam 402, resistance element 424, the upper contact of cam 403, bank terminal 336 and brush 334 of the office selector, the contact of cam 310 (8), trunk conductor 313, bank terminal 257 and brush 259 of the district selector, the upper left-hand and lower right-hand contacts of cam 220, conductor 262, the outer right-hand armature and front contact of relay 230, wiper 237, conductor 743, the outer armature and back contact of relay 802, the left-hand contacts of cam 744 (9 to 12), the right-hand contact of cam 834 (12), the left-hand winding of polarized relay 823, the windings of sender stepping relay 804, the armature and back contact of relay 805, the right-hand winding of relay 823, the winding of trunk test relay 839, the lower contacts of cam 824, conductor 840, the lower right-hand contact of compensating resistance switch cam 929

(9 to 4), resistance element 931, the left-hand contact of cam 841 (12 to 18), conductor 842, the upper right-hand contact of cam 749 (9 to 12), the left-hand armature and back contact of advance relay 750, conductor 751, wipers 263, the left-hand armature and front contact of relay 244, conductor 264, the lower right-hand and upper left-hand contacts of cam 219, brush 258 and bank terminal 256 of the district selector, trunk conductor 314, the contact of cam 311 (8), brush 335 and bank terminal 337 of the office selector, trunk conductor 420, the lower contact of cam 404 (1 to 10), resistance element 425, conductor 426 and thence to ground at the lower contact of cam 405 (1 to 8). Owing to the resistance of the right-hand winding of relay 823, relay 421 of the incoming selector switch does not energize over this fundamental circuit, but relay 839 at 75 the sender energizes and closes the circuit for relay 845. Relay 845, upon energizing, closes a circuit extending through the upper left-hand contact of cam 820 for advancing the sender sequence switch 800 into position 14. With sequence switch 800 in position 14, a circuit is established for relay 853 which may be traced from battery through the winding of relay 853, conductor 852 and thence to ground at the left-hand contacts of cam 851 (14). A circuit is now established for advancing sender sequence switch 800 from position 14 into position 16, which circuit may be traced from battery through the winding of the driving magnet of sequence switch 800, conductor 854, the upper contacts of cam 752 (9), conductor 753, the inner right-hand armature and front contact of relay 853 and thence to ground through the lower left-hand and upper right-hand contacts of class switch cam 938 (4).

Upon the movement of the sequence switch 800 into position 16, the fundamental circuit is extended through the lower left-hand and upper right-hand contacts of cam 824, thereby cutting the right-hand winding of relay 823 and the winding of relay 839 from the fundamental circuit. Sender stepping relay 804 and relay 421 of the incoming selector switch now energize over the fundamental circuit.

Relay 421, upon energizing, closes a circuit extending through its outer left-hand armature and front contact for driving sequence switch 400 out of its normal position into position 2, this circuit extending from battery through the magnet winding of sequence switch 400, the lower right-hand contact of cam 406 (1), the outer left-hand armature and front contact of relay 421, and thence to ground at the lower contact of cam 407, (1 to 10). As soon as sequence switch 400 leaves position 1, the initial energizing circuit of relay 421 is opened at the upper 120 125 130

right-hand contact of cam 402, but relay 421 remains energized over the fundamental circuit through its left-hand winding, upper left and lower right-hand contacts of cam 402, the right-hand armature and front contact of relay 421, conductor 429 and the left-hand contacts of cam 408 (1 to 4).

Incoming brush selection.

- 10 With sequence switch 400 in position 2, a circuit is closed for the updrive magnet 430 which may be traced from battery through the winding of this magnet, the upper right-hand contact of cam 409 (2), conductor 431, 15 the outer left-hand armature and front contact of relay 421 and thence to ground at the lower contact of cam 407. Magnet 430, upon energizing, presses the depending portion of the switch shaft 432 against the constantly rotating updrive drum 433 causing thereby the upward movement of the switch shaft. As the switch shaft approaches its first brush selection position, a circuit is established in shunt of the windings of the 20 sender stepping relay 804 which may be traced from battery through the left-hand winding of relay 421, the upper left-hand and lower right-hand contacts of cam 402, the right-hand armature and front contact of relay 421, conductor 429, the lower contacts of cam 408, segment 434 of commutator 435, brush 436, conductor 437 and thence to ground at the lower contact of cam 410 (7 to 5). As the switch shaft continues in 25 its upward movement, the brush 436 engages an insulating portion of commutator segment 434 and the previously traced shunt circuit is opened. In this manner, during the upward movement of the switch shaft, 30 the shunt circuit is intermittently established and opened whereby the sender stepping relay 804 is intermittently energized and deenergized. Relay 421, however, remains energized over the shunt circuit.
- 40 Upon the establishment of the fundamental circuit through the windings of the sender stepping relay with sender sequence switch 800 in position 16 and assuming that the calling subscriber has dialed the thousands digit 9, a circuit is closed upon the first energization of relay 804 for the No. 4 counting relay 856, this circuit extending from battery through the winding of relay 856, the armature and back contact of the 45 upper No. 4' counting relay 857, lead 858, lead 1134, No. 9 terminal 1135 of the thousands register TH, wiper 1136, conductor 1137, the lower right-hand contact of cam 859 (16), conductor 830 and thence as previously traced to ground at the lower right-hand contact of cam 819 (16). Counting relay 856, upon energizing, closes a locking circuit for itself extending through the winding of the No. 4' counting relay 857 50 in the manner previously described and re-

lay 857 becomes energized in this locking circuit as soon as relay 804 becomes deenergized upon the first upward step of the incoming selector switch shaft 432. In the manner previously described, the counting relays are 70 energized and locked up in succession until the upper No. 0' counting relay 817 energizes in parallel with relay 805 when a circuit is established for driving sequence switch 800 out of position 16 and into position 17, this circuit extending through the magnet winding of sequence switch 800, the lower right-hand and outer left-hand contacts of cam 860 (16), the upper contacts of cam 754 (9 to 12), conductor 740 and thence 80 to ground at the armature and front contact of counting relay 817. Relay 805, upon energizing, opens the fundamental circuit and as soon thereafter as the brush 436 engages the next insulating portion of commutator segment 434, the circuit of relay 421 is opened and relay 421 deenergizes.

Relay 421, upon deenergizing, opens at its outer left-hand armature and front contact the circuit of the updrive magnet 430 thereby arresting the upward movement of switch shaft 432 and at its inner left-hand armature and back contact closes a circuit for driving sequence switch 400 out of position 2 and into position 3, this circuit extending from grounded battery through the magnet winding of sequence switch 400, the upper left-hand contact of cam 406 (2) and thence to ground at the inner left-hand armature and back contact of relay 421. 100 Upon reaching position 3, sequence switch 400 closes a circuit for the trip magnet 438 extending from grounded battery through the winding of magnet 438 and thence to ground through the right-hand contacts of cam 405. Trip magnet 438, upon energizing, rotates the trip spindle 439 into such a position as will trip the selected set of brushes which, in the case assumed, is the fifth set of brushes, upon the subsequent upward movement of switch shaft 432.

As soon as sender sequence switch 800 reaches position 17, a local energizing circuit is established for sender stepping relay 804 for the purpose of reenergizing the windings of this relay in a reverse direction to remove any tendency for the relay to become polarized through its previous operation. This circuit may be traced from battery through the winding of relay 853, conductor 852, the right-hand contacts of cam 822, the left-hand winding of relay 823, the windings of stepping relay 804, the armature and back contact of relay 805, the upper contacts of cam 824 and thence to ground through resistance element 807. Relay 804, upon energizing, closes a circuit for advancing sequence switch 800 into position 18 which may be traced from battery through the driving magnet of sequence switch 800, 130

the lower contacts of cam 818, the armature and front contact of relay 804 and thence to ground through the upper right-hand contact of cam 819.

5 *Incoming group selection.*

With sequence switch 400 of the incoming selector in position 3 and the sender sequence switch 800 in position 18, the previously traced fundamental circuit is established through the windings of relay 421 and sender stepping relay 804. Relay 421 upon energizing in this circuit again closes the circuit previously traced for driving sequence switch 400 out of position 3 and into position 4 and at its right-hand armature and front contact closes the locking circuit previously traced for maintaining itself energized over the fundamental circuit after sequence switch 400 leaves position 3. With sequence switch 400 in position 4 and relay 421 energized, the circuit previously traced through the updrive magnet 430 is again closed and the switch shaft 432 is again driven upwardly. During the initial upward movement of the switch shaft, the fifth set of brushes is tripped by the tripping spindle 439 and during the subsequent upward movement of the switch shaft, the tripped set of brushes travels in engagement with the terminals of the bank with which it is associated. As the switch shaft approaches the first group selection position, a circuit is established in shunt of the windings of the sender stepping relay 804 which may be traced from grounded battery through the left-hand winding of relay 421, the upper left-hand and lower right-hand contacts of cam 402, the right-hand armature and front contact of relay 421, conductor 429, the upper contacts of cam 408, commutator segment 440, brush 441, conductor 437 and thence to ground at the lower contact of cam 410. As the switch shaft continues in its upward movement, brush 441 comes into engagement with an insulating portion of segment 440 and the previously traced shunt circuit is opened. Thus, during the continued upward movement of the switch shaft, the shunt circuit is intermittently established and opened and in consequence thereof, the sender stepping relay 804 is intermittently energized and deenergized. Relay 421, however, is maintained energized over the shunt circuit.

Upon the establishment of the fundamental circuit through the windings of relays 421 and 804, relay 804 becomes energized and under the assumption that the calling subscriber has dialed the second digit No. 5, a circuit is established for the No. 3 counting relay 861 which may be traced from battery through the winding of relay 861, the armature and back contact 65 of relay 862, lead 863, lead 1187, the left-

hand armature and front contact of relay 1138, which relay is energized at this time since the subscriber has dialed the hundreds digit 5, and wiper 1139 of hundreds register H is therefore positioned in the second half 70 of its bank of terminals, the No. 9 terminal 1182 of the thousands register TH, wiper 1183, conductor 1184, conductor 1142, the lower left-hand contact of cam 859 (18), conductor 830 and thence over the circuit 75 previously traced to ground at sequence switch cam 819. Counting relay 861 energizes in this circuit and locks up in the manner previously described through the winding of counting relay 862, which latter 80 relay energizes upon the first deenergization of stepping relay 804 in the well-known manner. The counting relays are successively energized through the intermittent operation of stepping relay 804 until the 85 No. 0' counting relay 817 energizes in parallel with relay 805, when a circuit is established for driving the translator control sequence switch 700 out of position 12 and into position 13 and the fundamental circuit 90 is opened at the armature and back contact of relay 805.

At the time the sender sequence switch 800 moved into position 18, the translator control sequence switch 700 was advanced 95 from position 9 into position 12 over a circuit extending from battery through the magnet winding of sequence switch 700, the upper left-hand contact of cam 722 (9 to 10) and thence to ground at the lower right-hand contact of cam 855 (15 to 18) and, therefore, upon the energization of counting relay 817, sequence switch 700 is advanced into position 13 over a circuit extending 100 through its magnet winding, the upper right-hand contact of cam 728 (12), the lower contacts of cam 864 (18), conductor 740 and thence to ground at the armature and front contact of relay 817. The purpose of driving the translator control sequence switch into position 13 at this time 105 is to prepare circuits for permitting a second rotation of sender sequence switch 800 for controlling the circuits of the sender during the final brush, final group and units selection movements of the final selector switch and the talking selection movement 110 of the district selector.

With the translator control sequence switch in position 13, a circuit is now closed 115 for driving the sender sequence switch 800 out of position 18 and into position 1, this circuit extending from battery through the magnet winding of switch 800, conductor 854, the contacts of cam 755 (13) and thence to ground at the lower right-hand contact of cam 855 (15 to 18). Upon reaching position 1, a circuit is closed through the lower left-hand contact of cam 820 (1) as 120 previously described for driving sequence 125 65 of relay 862, lead 863, lead 1187, the left-

switch 800 out of position 1 and into position 2, in which position the circuits of the sender are in condition for controlling brush selection at the final selector switch.

5 As soon following the opening of the fundamental circuit at the armature and back contact of relay 805 as the brush 441 engages an insulating portion of commutator segment 440, relay 421 deenergizes and opens the previously traced circuit for the updrive magnet 430 and closes the previously traced circuit for advancing the sequence switch 400 out of position 4 and into position 5. In position 5, relay 421 is again energized over a circuit extending from battery through its right-hand winding and thence to ground through the lower left-hand and upper right-hand contacts of cam 411. Relay 421 now closes a circuit extending from ground at cam 407 and through the outer left-hand armature and front contact of relay 421 for driving sequence switch 400 out of position 5 and into position 6. Upon leaving position 5½, the initial energizing circuit of relay 421 is opened at cam 411, but relay 421 remains energized over a locking circuit extending from battery through its left-hand winding, the upper left-hand and lower right-hand contacts of cam 402, the right-hand armature and front contact of relay 421, the right-hand contacts of cam 412 and thence through test brush 442 to ground on the test terminal of the first trunk of the group to which the brush set 30 has been moved during group selection movement of the switch shaft if the first trunk of the group is at the time busy. When sequence switch 400 reaches position 6, the previously traced circuit for the updrive magnet 430 is again established for driving the switch shaft upwardly in its trunk hunting movement. This movement continues so long as the test brush 442 encounters ground potential on the multiples 45 of the test terminals of the trunk circuit group over which this brush moves. As soon, however, as an idle trunk is found, which it will be assumed is the trunk disclosed, the locking circuit of relay 421 will be opened and relay 421 will be deenergized as soon as the brushes are properly centered on the terminals of the selected idle trunk, relay 421 being maintained energized until the brushes are so centered by an additional locking circuit extending from battery through the right-hand winding of relay 421, the left-hand contacts of cam 411, conductor 443, centering segment 444 of the commutator 435, brush 445, conductor 437, 50 the upper left-hand contact of cam 410 (6), conductor 431 and thence to ground through the cam 407. As soon as relay 421 deenergizes, the circuit of the updrive magnet is opened and the previously traced circuit is 55 closed for advancing sequence switch 400 out

of position 6 and into position 7. In position 7, relay 421 again energizes in a circuit extending through its right-hand winding and the contacts of cam 411 and closes a circuit for driving the sequence switch 70 out of position 7 and into position 8, in which position the tip conductor of the fundamental circuit is extended over the upper left-hand contact of cam 413 (8), brush 446 and bank terminal 447, trunk conductor 517, the lower left-hand contact of cam 502 (15 to 6), the lower left-hand contact of cam 503 (1), the right-hand winding of relay 518 and thence to battery through the upper left-hand contact of cam 80 504 (1 to 10), the ring conductor of the fundamental circuit extending as previously described to ground at the lower right-hand contact of cam 405 (1 to 8).

Upon the extension of the connection to 85 the final selector switch, relay 421 of the incoming selector switch which was energized in position 7 of sequence switch 400 is maintained energized in position 8 over a circuit extending from battery through 90 its left-hand winding, upper left and lower right-hand contacts of cam 402, the right-hand armature and front contact of relay 421, the lower right-hand contact of cam 414 (7 to 8), brush 448 and terminals 449 95 of the incoming selector switch, trunk conductor 519, the upper left-hand and lower right-hand contacts of cam 505, resistance element 520 and thence to ground through the lower left-hand contact of cam 506 (1 to 8½). Busy ground potential is placed on the multiples of test terminal 451 of the selected trunk over test brush 442 and the lower right-hand and upper left-hand contacts of cam 412. 100

At the office sender the fundamental circuit extends from tip conductor 743 through the outer left-hand armature and back contact of relay 802, the right-hand contact of cam 744 (13 to 18), the lower left-hand and upper right-hand contacts of cam 822, the left-hand winding of polarized relay 823, the windings of sender stepping relay 804, the armature and back contact of relay 805, the upper right-hand and lower left-hand contacts of cam 824, conductor 840, the lower right-hand contact of cam 929 (4), resistance element 931, the upper contacts of cam 864 (1 to 16), the upper left-hand contact of cam 749 (13 to 18), the left-hand armature and back contact of advance relay 750 to the ring conductor 751 of the fundamental circuit. 110 115 120

Final brush or hundreds selection.

Upon the extension of the fundamental circuit to the final selector switch 500 with the sender sequence switch 800 in position 2, relay 518 of the final selector switch and stepping relay 804 of the office sender both 130

energize. Relay 518 closes a circuit for relay 521 which may be traced from battery through the left-hand winding of this relay, conductor 522, the upper left-hand contact of cam 507 (1), conductor 523, the left-hand armature and front contact of relay 518 and thence to ground through the upper contact of cam 508 (1 to 11). Relay 521 energizes in this circuit and at 5 its left-hand armature and front contact closes a locking circuit for itself extending from battery through its left-hand winding, the armature and back contact of test relay 524, the left-hand armature and front 10 contact of relay 521, sleeve conductor 525, bank terminal 451 and brush 442 of the incoming selector switch and thence to ground at the contact of cam 412. Relay 521, upon energizing, closes a circuit for driving 15 sequence switch 500 into position 2, which circuit may be traced from battery through the magnet winding of sequence switch 500, the lower contacts of cam 509 to ground at the right-hand armature and front contact 20 of relay 521. When sequence switch 500 moves out of position 1, the initial energizing circuit of relay 518 is opened at the lower right-hand contact of cam 503, but relay 518 remains energized over the 25 fundamental circuit by reason of a locking circuit extending from battery through the upper left-hand contact of cam 504, the right-hand winding of relay 518, the lower right-hand contact of cam 510 (15 to 10), 30 the right-hand armature and front contact of relay 518, the lower right-hand contact of cam 503 (1 to 6) and thence to the lower left-hand contact of cam 502 and over the fundamental circuit as previously 35 traced. Relay 518, upon energizing with sequence switch 500 in position 2, closes a circuit for the high speed updrive magnet 526 which may be traced from battery through the winding of the updrive magnet, the upper right-hand contact of cam 511 (2), the left-hand armature and front 40 contact of relay 518 and thence to ground at the upper left-hand contact of cam 508. Magnet 526, upon energizing, presses the 45 depending portion of the switch shaft 527 against the constantly rotating high speed drum 528 thereby causing the switch shaft to be moved upwardly at a high speed in its brush selection movement. As the switch 50 shaft approaches its first brush selection position, the brush 532 engages a conducting portion of commutator segment 530 of commutator 531 and a circuit is established in shunt of the windings of the sender stepping relay 804 which may be traced from 55 grounded battery through the left-hand contact of cam 504, the right-hand winding of relay 518, the lower right-hand contact of cam 510, the right-hand armature 60 and front contact of relay 518, the lower 65 and front contact of relay 518, the lower right-hand contact of cam 503, the upper right-hand contact of cam 502 (14 to 2), conductor 529, segment 530, brush 532, conductor 533 and thence to ground at the upper left-hand contact of cam 506 (13 to 11). As the switch shaft continues in its upward movement, the brush 532 engages an insulating portion of segment 530 and the previously traced shunt circuit is opened. Thus, as the switch shaft continues in its upward movement, the previously traced shunt circuit is established and opened and in consequence thereof, the sender stepping relay 804 is intermittently energized and deenergized. Relay 518, however, is maintained energized over the shunt circuit. 70 75 80 85 90 95 100 105 110 115 120 125 130

On the initial closure of the fundamental circuit through the windings of sender stepping relay 804 with sequence switch 800 in position 2, a circuit is closed for the No. 4 counting relay 856 which circuit extends from battery through the winding of relay 856, the armature and back contact of the No. 4' counting relay 857, lead 858, lead 1140 Fig. 11 connected to the No. 5 terminal of the hundreds register H, wiper 1141, conductor 1142, the right-hand contact of cam 865, conductor 869, the contact of class switch cam 939 (4), the right-hand contact of cam 746 (13 to 18), conductor 811, the normally closed contacts associated with the inner left-hand armature of relay 812, the upper right-hand and lower left-hand contacts of cam 818, the armature and contact of stepping relay 804 and thence to ground at the upper right-hand contact of cam 819. Counting relay 856 energizing in this circuit closes a locking circuit for itself extending through the winding of counting relay 857 as previously described and in the well-known manner, under the control of stepping relay 804, the counting relays energize and lock up in succession until No. 0' counting relay 817 energizes in parallel with relay 805. Upon the energization of relay 817, the previously traced circuit is established for driving sequence switch 800 out of position 2 and into position 4. Upon leaving position 2, the locking circuits of the energized counting relays are opened at sequence switch cam 819 and the counting relays become deenergized. Upon the energization of relay 805, the fundamental circuit is opened at the armature and back contact of this relay and as soon thereafter as the brush 532 engages the next insulating portion of commutator segment 530, relay 518 deenergizes, opening the circuit of updrive magnet 526 to arrest the upward movement of the switch shaft and closes at its left-hand armature and back contact a circuit for driving sequence switch 500 out of position 2 and into position 3. This circuit may be traced from battery through

the winding of sequence switch magnet 500, the upper right-hand contact of cam 512 (2), the left-hand armature and back contact of relay 518 and thence to ground at the 5 upper contact of cam 508. The fifth set of brushes has now been positioned in relation to the tripping finger of the tripping spindle 534 so that upon a second upward movement of the switch shaft, this set of 10 brushes will be tripped for engagement with the bank of one hundred terminals with which this brush set is associated. With sequence switch 500 in position 3, a circuit is closed for the trip magnet 535 extending from battery through the winding of magnet 535 and thence to ground at the 15 lower right-hand contact of cam 506 (3 to 5).

Final group or tens selection.

20 When sequence switch 500 reaches position 3, the energizing circuit of relay 518 is again established over the fundamental circuit, and relay 518 and stepping relay 25 804 of the office sender energizes in series. Relay 518, upon energizing, again closes the previously traced circuit for driving sequence switch 500 out of position 3 and into position 4. With switch 500 in position 4, 30 the previously traced circuit for the updrive magnet 526 is again established and the switch shaft is driven upwardly in its group or tens selection movement. Relay 518 also establishes the previously traced locking 35 circuit for itself extending through its right-hand armature and front contact for maintaining itself energized over the fundamental circuit after sequence switch 500 leaves position 3 and opens the initial energizing circuit at the lower left-hand contact 40 of cam 503. During the initial portion of the group selection movement of the switch shaft, the fifth set of brushes is tripped by the tripping spindle 534 and during the re- 45 maining portion of the group selection movement, the tripped set of brushes travels upwardly in contact with the terminals of the bank with which the brush set is associated. As the switch shaft approaches its 50 first group selection position, the brush 538 engages the lowermost conducting portion of segment 537 and a circuit is closed in shunt of the windings of sender stepping relay 804 which may be traced from 55 grounded battery through the left-hand contact of cam 504, the right-hand winding of relay 518, the lower right-hand contact of cam 510, the right-hand armature and front contact of relay 518, the right-hand contacts of 60 cam 503, conductor 536, segment 537, brush 538, conductor 533 and thence to ground through the upper left-hand contact of cam 506 (13 to 11). As the switch shaft continues 65 in its upward movement, the brush 538 engages an insulating portion of segment 537

and the previously traced shunt circuit is opened. Thus, as the switch shaft continues in its upward movement, the previously traced shunt circuit is intermittently established and opened and in consequence 70 thereof, the sender stepping relay 804 is intermittently energized and deenergized.

Stepping relay 804 of the sender when initially energized over the fundamental circuit with sequence switch 800 in position 4 75 closes a circuit for the No. 3 counting relay 861 over a circuit extending from battery through the winding of relay 861, the armature and back contact of the No. 3' counting relay 862, lead 863, lead 1200 Fig. 12 the 80 No. 3 terminal 1201 and brush 1202 of the tens register T, the lower contact of cam 865 (4), conductor 869 and thence as previously traced through the armature and front contact of stepping relay 804 and the lower right-hand contact of cam 819 (4). In the manner previously described, the counting relays energize in succession until the upper No. 0' counting relay 817 energizes in parallel with relay 805. Relay 817, upon energizing, closes the previously traced circuit for driving sequence switch 800 out of position 4 and into position 6. Sequence switch 800, upon leaving position 4, opens the locking circuits of the energized counting relays 90 and these counting relays restore to normal position. Relay 805, upon energizing, opens the fundamental circuit and as soon thereafter as brush 538 engages the next insulating portion of segment 537, relay 518 de- 95 energizes, opening the circuit of the updrive magnet 526 and closing the circuit previously traced for advancing sequence switch 500 out of position 4 and into position 5.

In position 5, the fundamental circuit is again established and relay 518 and the sender stepping relay 804 again energize. Relay 518, upon energizing, closes the previously traced locking circuit for itself and closes the circuit for moving sequence switch 100 500 out of position 5 and into position 6.

Final units selection.

As soon as sequence switch 500 reaches position 6, a circuit is established for the 115 low speed updrive magnet 539 which circuit may be traced from battery through the winding of magnet 539, the lower left-hand contact of cam 507 (6), the left-hand armature and front contact of relay 518 and thence to ground at the upper left-hand contact of sequence switch cam 508. The low speed updrive magnet 539 upon energizing 120 presses the depending portion of the switch shaft 527 against the constantly rotating low speed drum 540 thereby causing the upward movement of the switch shaft in its units selection movement. During this movement of the switch shaft, an intermittent shunt circuit is established in shunt of 125 130

the windings of the sender stepping relay 804 which may be traced from battery through the left-hand contact of cam 504, the right-hand winding of relay 518, the lower right-hand contact of cam 510, the right-hand armature and front contact of relay 518, the lower right-hand contact of cam 503, the upper right-hand contact of cam 502 (5 $\frac{3}{4}$ to 6), conductor 529, the units selection portion of segment 530 of the commutator 531, brush 532, conductor 533 and thence to ground at the upper left-hand contact of cam 506. In response to the intermittent establishment of the previously traced shunt circuit, the sender stepping relay 804 is intermittently energized and de-energized, the relay 518 being maintained energized over the shunt circuit.

The sender stepping relay 804 of the office sender, upon energizing in the fundamental circuit with sender sequence switch 800 in position 6, establishes a circuit for the No. 9' counting relay 846 which circuit may be traced from battery through the winding of relay 846, the armature and back contact of the No. 9' counting relay 847, lead 871, lead 1203, terminal 1204 and wiper 1205 of the units register U, conductor 1206, the left-hand armature and back contact of the wipe-out relay 757, conductor 758, the upper left-hand contact of cam 865 (6) and thence over the circuit previously traced through the armature and front contact of sender stepping relay 804 to ground at the upper right-hand contact of cam 819 (6). In response to the successive energizations and deenergizations of relay 804, the counting relays energize in succession until the No. 5' counting relay 814 energizes when lead 871 is extended through the armature and front contact of this relay, the upper contact of cam 843 (5 to 8) the armature and back contact of the No. 4' counting relay 857 and to the winding of the No. 4 counting relay 856. The remaining counting relays now energize in succession in response to further operations of sender stepping relay 804 until the No. 0' counting relay 817 energizes in parallel with relay 805. Counting relay 817 upon energizing, closes the previously traced circuit for advancing sequence switch 800 out of position 6. When the sequence switch leaves position 6, the locking circuits of the energized counting relays are opened at the left-hand contacts of cam 819 and the counting relays restore to their normal condition. The No. 0' counting relay is maintained energized until the sequence switch 800 leaves position 12 over a circuit which may be traced through the winding of the No. 0 counting relay 816, the winding of the No. 0' counting relay 817, the armature and front contact of relay 816, the lower left-hand and upper right-hand contacts of cam 860 (6 to 12), the lower right-hand and

upper left-hand contacts of class switch cam 940 (4), conductor 872 and thence to ground at the upper left-hand contact of cam 756 (11 $\frac{3}{4}$ to 18). With relay 817 locked up through position 12, sequence switch 800 advances from position 6 into position 14. In position 14 a circuit is established for relay 853 extending from battery through the winding of relay 853, conductor 852 and to ground through the left-hand contacts of cam 851 (14). A circuit is now established for advancing sequence switch 800 into position 16 which circuit may be traced from battery through the magnet winding of sequence switch 800, conductor 854, the upper contact of cam 752, conductor 753, the inner right-hand armature and front contact of relay 853 and thence to ground through the lower left-hand and upper left-hand contacts of class switch cam 938 (4).

A circuit is also established upon the energization of relay 853 for advancing the translator control sequence switch 700 out of position 13 and into position 14, which circuit may be traced from battery through the magnet winding of sequence switch 700, the left-hand contacts of cam 752, conductor 753, the inner right-hand armature and front contact of relay 853 and thence to ground at the class switch cam 938.

Upon the energization of relay 805 following units selection, the fundamental circuit is opened at the office sender and as soon thereafter as the brushes of the final selector switch are positioned accurately upon the terminals of the selected line and brush 532 is in engagement with an insulating portion of segment 530, relay 518 de-energizes, opening the circuit of the updrive magnet 539 and closing the previously traced circuit for driving sequence switch 500 out of position 6 and into position 9.

Testing the called line.

The brushes of the final selector switch 550 have now been positioned upon the terminals of the desired line and sequence switch 500 upon reaching position 9 closes a circuit for reenergizing relay 518 which may be traced from grounded battery through the left-hand contact of cam 504 (1 to 10), the right-hand winding of relay 518, the lower right-hand and upper left-hand contact of cam 510 and thence to ground at the right-hand armature and front contact of relay 521. Relay 518, upon energizing, closes a locking circuit for itself extending from battery through its right-hand winding and the lower right-hand contact of cam 510, the right-hand armature and front contact of relay 518 and thence to ground through the upper contacts of cam 513. This locking circuit will be maintained through position 10 of sequence switch 500. Relay 518, upon energizing,

also closes a circuit as previously traced for driving sequence switch 500 out of position 9 and into position 12. Upon reaching position 10, a new holding circuit is established for relay 518 extending from grounded battery through the left-hand winding of this relay, the lower right-hand contact of cam 515 (10 to 11), the left-hand armature and front contact of relay 518 and thence to ground at the upper left-hand contact of cam 508. Upon reaching position 11, sequence switch 500 establishes a new holding circuit for relay 518 extending from ground through the winding of test relay 524, conductor 541, the upper left-hand contact of cam 502, the lower left-hand contact of cam 503 (11 to 13), the right-hand winding of relay 518, the upper right-hand contact of cam 510 (11 to 12½), the right-hand armature and front contact of relay 518, the right-hand contacts of cam 513, test brush 542 and thence to battery on the test terminal of the called line if the called line is busy. If the called line is busy as a calling line, battery potential will be connected to test terminal 543 as previously described in connection with the trunk hunting switch 100 through the off-normal contact of the trunk hunting switch, and if the called line is busy as a called line, battery potential will be connected to terminal 543 from battery through the upper right-hand contact of a sequence switch cam corresponding to cam 504 of the final selector switch which is in engagement with the terminals of the called line, the lower contacts of a cam corresponding to cam 513 and the test brush of such final selector switch.

40 *Called line busy.*

If the called line is busy, relay 518 remains energized until the sequence switch 500 reaches position 12 and relay 524 also energizes in the locking circuit previously traced through the right-hand winding of relay 518. The energization of relay 524 opens the previously traced holding circuit of relay 521 which relay thereupon deenergizes, closing a circuit extending from battery through the magnet winding of sequence switch 500, the lower right-hand and upper left-hand contacts of cam 509 and the right-hand armature and back contact of relay 521 for driving sequence switch 500 into position 13. When sequence switch 500 leaves position 12½, the testing circuit traced through relays 524 and 518 is opened, but relay 518 remains locked over a circuit extending through its left-hand winding, the lower right-hand contact of cam 515 (12½ to 14), the left-hand armature and front contact of relay 518 and to ground at the upper contact of cam 508 (12½ to 16). When the sequence switch 500 reaches position 13, relay 521 is again energized over a circuit extending from battery through its left-hand winding, conductor 522 and thence to ground through the upper right-hand contact of cam 506 (13) and upon energizing locks itself to sleeve conductor 525 through the back contact and armature of test relay 524 and closes a circuit for driving sequence switch 500 out of position 13 and into position 14. This circuit may be traced from battery through the magnet winding of switch 500, the lower contacts of cam 509 and thence to ground at the right-hand armature and front contact of relay 521. When switch 500 reaches position 14, a circuit is established for the downdrive magnet 544 which may be traced from grounded battery through the winding of magnet 544, the lower right-hand contact of cam 511 (14), conductor 523, the left-hand armature and front contact of relay 518 and thence to ground through the upper left-hand contact of cam 508.

Upon the energization of downdrive magnet 544, the depending portion of switch shaft 527 is pressed against the constantly rotating downdrive drum 545 thereby causing the downward movement of switch shaft 527 into normal position. When the switch shaft reaches normal position, a circuit is established for driving the sequence switch 500 out of position 14 and into position 17, this circuit extending from grounded battery through the magnet winding of switch 500, the upper right-hand contact of cam 512 (3 to 16), conductor 546, normal segment 547 of commutator 531, brush 538, conductor 533 and thence to ground through the upper left-hand contact of cam 506. Upon leaving position 14, the locking circuit of relay 518 is opened, but in position 17 a circuit is closed which extends from battery through the left-hand winding of relay 518 and thence to ground through the upper left-hand contact of cam 515 (17) and through interrupter 548, whereby relay 518 is intermittently energized. During the intermittent energization of relay 518, a circuit is established for transmitting a busy tone back to the calling subscriber over a circuit which may be traced from the source of tone current 549, the lower right-hand contact of sequence switch cam 508 (17), the left-hand armature and front contact of relay 518, conductor 523, the left-hand contact of cam 511 (17), resistance element 520, the lower right-hand and upper left-hand contacts of cam 505, trunk conductor 519, bank terminal 449 and brush 448 of the incoming selector switch, the upper contact of cam 414 and thence to battery and ground through the lower right-hand winding of repeating coil 458, the sequence switch of the incoming se-

lector switch having at this time advanced into the talking position in a manner to be described hereinafter. The tone current flowing in this circuit is inductively transmitted over the trunk 419, 420 to the right-hand winding of repeating coil 265 at the district selector switch and from thence to the calling subscriber's line over the conductors shown in heavy lines, the district selector switch having been advanced in the manner hereinafter described into the talking selection position following the completion of the units selection movement of the final selector switch. The calling subscriber receiving this busy tone, restores his receiver to the switchhook thereby causing the restoration of the central station apparatus in the manner to be described hereinafter.

Called line idle.

If in testing, the called line is found to be idle, ground potential will be encountered on test terminal 543, this ground potential being supplied through a wiper of the called subscriber's trunk finder switch corresponding to wiper 110 shown in Fig. 1 and the windings of the called subscriber's cutoff relay corresponding to relay 102. Therefore, when the test circuit through test brush 542 is established, the circuit previously traced through the winding of relay 518 and the winding of relay 524 will be without battery potential and relay 518 will therefore become deenergized, as soon as sequence switch 500 leaves position 11 and relay 524 will not therefore energize. When, therefore, relay 518 deenergizes it closes a circuit for driving sequence switch 500 out of position 12 and into position 13, this circuit extending from battery through the upper right-hand contact of cam 512, the left-hand armature and back contact of relay 518, the lower left-hand contact of cam 508 and thence to ground at the right-hand armature and front contact of relay 521. Upon reaching position 13, a circuit is established over the lower contacts of cam 509 and the right-hand armature and front contact of relay 521 for driving sequence switch 500 out of position 13 and into position 14 and in position 14 a circuit is established as previously traced through the winding of magnet of sequence switch 500, the right-hand armature and back contact of relay 518 and to ground at the upper contact of cam 508 for driving sequence switch 500 into the talking position 15, in which position the trunk conductors 517 and 519 are connected respectively to the brushes 552 and 553, over the lower contacts of cam 502 and the upper contacts of cam 505. The testing of a line in a PBX group will not be described herein, this testing feature of the final selector switch being fully described in the Patent

1,395,977, issued to F. A. Stearn and F. J. 65
Scudder, November 1, 1921.

Talking selection.

Following the testing of the called line, assuming that the called line is found to be idle, sequence switch 500 moves into talking position 15. Upon leaving position 8₁, the circuit previously traced through the winding of relay 421 of the incoming selector switch is opened and relay 421 becomes de-energized, closing a circuit for driving sequence switch 400 out of position 8 and into position 9, this circuit extending from battery through the winding of the magnet of the switch 400, the upper left-hand contact of cam 406 (8) and thence to ground at the inner left-hand armature and back contact of relay 421. With sequence switch 400 in position 9, a new fundamental circuit is extended from the incoming selector to the office sender which may be traced from battery through the left-hand winding of relay 421, the lower contacts of cam 415 (9), resistance element 425, the lower contact of cam 404 (1 to 10), bank terminal 337 and brush 335 of the office selector switch, the contact of cam 311 (8), trunk conductor 314, bank terminal 256 and brush 258 of the district selector switch, the upper left-hand and lower right-hand contacts of cam 219, conductor 264, the left-hand armature and front contact of relay 244, wiper 263, conductor 751, the left-hand armature and back contact of relay 750, the upper left-hand contact of cam 749 (13 to 18), the upper contacts of cam 864 (1 to 16), resistance element 931, the lower right-hand contact of cam 929, conductor 840, the lower left-hand and upper right-hand contacts of cam 824, the armature and back contact of relay 805, windings of sender stepping relay 804, the left-hand winding of polarized overflow relay 823, the upper right-hand and lower left-hand contacts of cam 822, the right-hand contacts of cam 744 (13 to 18), the outer armature and back contact of relay 802, conductor 743, wiper 237, the outer right-hand armature and front contact of relay 230, conductor 262, the lower right-hand and upper left-hand contacts of cam 220, brush 259 and bank terminal 257 of the district selector switch, trunk conductor 313, the contact of cam 310 (8), brush 334 and bank terminal 336 of the office selector, trunk conductor 419, the upper contact of cam 403, resistance element 424, the right-hand contacts of cam 408 (9), conductor 429 and thence to ground through the upper contacts of cam 412.

Relay 421 of the incoming selector, sender stepping relay 804 and polarized relay 823 energize in this circuit, the current flowing from the circuit being now in such a direc-

tion as to cause the polarized relay to attract its armature. Relay 823, upon energizing, closes a circuit for relay 873 which may be traced from battery through the left-hand 5 winding of relay 873, the upper left-hand contact of cam 867 and thence to ground at the armature and front contact of relay 823. Relay 873, upon energizing, closes a locking circuit for itself extending through its right- 10 hand winding, its inner right-hand armature and front contact and thence to ground at the upper contact of cam 727 (13/4 to 18). Relay 804, upon energizing with sequence switch 800 in position 16, closes a circuit for the No. 15 0 counting relay 816 which may be traced from battery through the winding of relay 816, the lower contact of cam 836 (11 to 18), conductor 837, lead 838, lead 868, the upper left-hand contact of cam 874, conductor 869, 20 the contact of cam 939 (4) and thence over the circuit previously traced through the armature and contact of relay 804 to ground at the lower right-hand contact of cam 819 (16). Relay 816, upon energizing, locks up 25 through the winding of the No. 0' counting relay 817. At the incoming selector, relay 421 energizes over the fundamental circuit and at its right-hand armature and front contact establishes a circuit for relay 451 30 which may be traced from battery through the winding of relay 451, the right-hand contact of cam 416 (9 to 10), the right-hand armature and front contact of relay 421 and thence to ground through the upper contacts 35 of cam 412. Relay 451, upon energizing, closes a circuit for advancing sequence switch 400 out of position 9, this circuit extending from battery through the magnet winding of sequence switch 400, the armature and front contact of relay 451 and thence to ground through the left-hand contacts of cam 412. As soon as sequence 40 switch 400 reaches position 10, the fundamental circuit is opened and relays 823 and 45 804 at the office sender and relay 421 at the incoming selector switch deenergize, relay 421 opening at its right-hand armature and front contact the circuit of relay 451, which in turn, opens the circuit of sequence 50 switch 400 to arrest the sequence switch in position 10.

Upon the opening of the fundamental circuit, the No. 0' counting relay 817 at the sender locks up in series with counting 55 relay 816 and at its armature and front contact closes a circuit for advancing sequence switch 800 into position 17 which circuit may be traced from battery through the magnet winding of sequence switch 800, the 60 upper left-hand contact of cam 820 (16), the inner front contact of the outer right-hand armature of relay 873, conductor 740 and thence to ground at the armature and front contact of relay 817. A circuit is also 65 closed at this time for energizing advance relays 708 and 750 which may be traced from battery through the windings of the advance relays in parallel, the normally closed contacts associated with the inner right-hand armature of relay 750, conductor 759, the outer front contact associated with the outer right-hand armature of relay 873 and thence to ground at the armature and contact of counting relay 817. Relay 750, upon energizing, opens its initial energizing circuit over conductor 759 and closes a locking circuit for itself and for relay 708 extending through the make contact of its right-hand armature and to ground at the upper contact of cam 727 (13/4 to 18). 70

With sequence switch 800 in position 17, a local circuit is established through the windings of stepping relay 804 for the purpose of depolarizing it and for causing the advance of sequence switch 800 into 75 the talking selection position 18. The circuit of relay 804 may be traced from battery through the winding of relay 853, conductor 852, the right-hand contacts of cam 822 (17), the left-hand winding of relay 823, the winding of relay 804, the armature and back contact of relay 805, the upper contacts of cam 824 and thence to ground through resistance element 807. Relay 804, upon energizing, advances sequence switch 800 into 80 position 18 over a circuit extending through the magnet winding of switch 800, the lower contacts of cam 818 (17), the armature and front contact of relay 804 and thence to ground at the upper right-hand contact of cam 819. Sequence switch 800 in advancing 85 out of position 17 opens the previously traced energizing circuit of relay 804 and in position 18 prepares the circuits of the sender for controlling the talking selection movement of the sequence switch of the district selector. 90

The energization of advance relay 708 opens the shunt around the high resistance right-hand winding of relay 748 and at its right-hand armature and back contact opens the energizing circuit through the left-hand winding of relay 748. Relay 748 deenergizes and at its armature contacts opens the 95 circuit of relay 737. Upon the connection of the high resistance winding of relay 748 in the circuit previously traced extending through the winding of relay 261, the current flowing through the winding of relay 261 is reduced to such an extent that relay 100 105 110 115 120 125 130 135 140 145 150 155 160 165 170 175 180 185 190 195 200 205 210 215 220 225 230 235 240 245 250 255 260 265 270 275 280 285 290 295 300 from battery through the left-hand winding of relay 228, the lower left-hand contact of cam 210 (11), the upper left-hand contact of cam 210 (11 to 14), conductor 262, the 5 outer right-hand armature and front contact of relay 230, wiper 237 of switch SF, conductor 743, the outer armature and back contact of relay 802, the right-hand contact of cam 744 (13 to 18), the lower left-hand and upper right-hand contacts of cam 822, the 10 left-hand winding of relay 823, the windings of sender stepping relay 804, the armature and back contact of relay 805, conductor 806, the right-hand armature and back contact of relay 737, conductor 738 and 15 thence to ground through resistance element 807. Relay 228 energizes in this circuit and closes a circuit as previously traced for driving sequence switch 200 out of position 20 11 and into position 15, unless this circuit is interrupted at the armature contact of relay 228 prior to the sequence switch reaching position 15. As soon as switch 200 leaves position 11, relays 230 and 244 are maintained energized over a circuit which may 25 be traced from battery through the winding of stepping magnet 229, the windings of relays 230 and 244 in parallel, the lower contact of cam 214 (11 to 14), the right-hand 30 armature and front contact of relay 244, the upper right-hand contact of cam 215 (11 to 14), the outer right-hand armature and front contact of relay 228 and thence to ground through the lower contacts of cam 35 216.

During the rotation of switch 200 from position 11 into position 15, an intermittent ground is connected to the fundamental circuit between the windings of relays 804 and 40 228 in such a manner as to hold relay 228 energized and to shunt out relay 804. This shunt circuit may be traced from battery through the left-hand winding, left-hand armature and front contact of relay 228 and 45 thence to ground through the left-hand contacts of cam 216 and is closed in positions 11 $\frac{5}{8}$, 12 $\frac{5}{8}$ and 13 $\frac{5}{8}$.

With the sender sequence switch 800 in 50 position 18 and the sender relay 804 energized, a circuit is closed for the No. 0 counting relay 816, it being assumed that the talking selection relays have been so set by the code letters dialed by the calling subscriber as to energize talking selection relay 1410. 55 The circuit of relay 816 may be traced from battery through the winding of relay 816, the lower contact of cam 836 (11 to 18), conductor 837, lead 838 lead 1436 Fig. 14, the right-hand armature and back contact of relay 1326, conductor 1327, the outer left-hand armature and back contact of zone relay 911, conductor 941, the right-hand contacts of cam 870 (18), the left-hand contact of cam 746 (13 to 18), conductor 811, 60 the normally closed contacts associated with

the inner left-hand armature of relay 812, the upper contacts of cam 818 (18), the armature and front contact of relay 804 and thence to ground through the lower right-hand contact of cam 819 (18). Relay 816 70 energizes in this circuit and closes a locking circuit for itself extending through its winding, the winding of the upper No. 0' counting relay 817, the armature and front contact of relay 816 and thence to ground 75 through the upper left-hand contact of cam 819 (18). Upon the first deenergization of relay 804 when sequence switch 200 is passing through position 11 $\frac{5}{8}$, counting relay 817 energizes in parallel with relay 805. 80 Relay 805, upon energizing, opens the circuit previously traced extending through the windings of relays 804 and 228 and relay 228, upon deenergizing, opens the previously traced circuit extending through the winding of sequence switch magnet 200 for arresting the sequence switch in position 12. Relay 817, upon energizing, closes a circuit for driving the translator control sequence switch 700 out of position 14 and 85 into position 15 which circuit may be traced from battery through the magnet winding of sequence switch 700, the upper right-hand contact of cam 728 (12 to 14), the lower contacts of cam 864 (18), conductor 740 and 90 thence to ground at the armature and front contact of counting relay 817. Sequence switch 700 upon reaching position 15 closes a circuit for advancing the sender sequence switch 800 out of position 18 and into normal position 1. This circuit may be traced from battery through the winding of sequence switch magnet 800, conductor 854, the contacts of cam 755 (15) and thence to 95 ground through the lower right-hand contact of cam 855 (15 to 18). Sequence switch 800 upon moving out of position 18 opens the locking circuit of counting relays 816 and 817 at the upper contact of cam 819 and these relays thereupon deenergize. 100

Ringing the called substation.

At the time the fundamental circuit was established through the winding of relay 421 at the incoming selector switch and the 115 windings of relays 804 and 823 at the office sender for advancing the district selector sequence switch out of position 10, relay 421 was energized to advance sequence switch 400 of the incoming selector switch out of 120 position 9 and into position 10. As soon as sequence switch 400 reaches position 10, if at this time sequence switch 200 of the district selector is advanced to the selected talking position, a circuit is established for relay 421 extending through the left-hand winding of this relay, the upper contacts of cam 402 (10), conductor 423, resistance element 424, the upper contact of cam 403 (1 125 to 10), conductor 419, bank terminal 336 and 130

brush 334 of the office selector switch contact of cam 310 (8), conductor 313, bank terminal 257 and brush 259 of the district selector switch, the left-hand contacts of sequence switch cam 220, the upper right-hand winding of repeating coil 265, the lower contacts of cam 221, the windings of polarized relay 266, the upper left-hand contact of cam 222, the lower right-hand 5 winding of repeating coil 265, the upper contacts of cam 219, brush 258 and bank terminal 256 of the district selector switch, conductor 314, the contact of cam 311 (8), brush 335 and bank terminal 337 of the office selector switch, conductor 420, the lower contact of cam 404 (1 to 10), resistance element 425, conductor 426 and thence through the lower contact of cam 405 (10) to ground. Relay 421, upon energizing, locks to ground 10 on sleeve conductor 464 over a circuit extending from battery through its right-hand winding, the armature and back contact of relay 455, the upper left-hand contact of cam 409, conductor 431, the outer left-hand 15 armature and front contact of relay 421, conductor 427 and thence to conductor 464 through the upper contact of cam 407 (2 to 18). The current flowing through the winding of polarized relay 266 at the district selector switch is not in the proper direction to effectively energize this relay at this time. 20

Relay 421, upon energizing, again establishes the previously traced circuit for relay 451 which relay upon energizing, establishes a circuit for driving sequence switch 400 into position 11. As soon as the switch 400 leaves position 10, relay 451 de- 25 energizes, but when switch 400 reaches position 11, relay 451 reenergizes over a circuit which may be traced from battery through its winding, the upper left-hand contact of cam 416 (11) and the upper contact 452 of interrupter cam 453, as soon as the cam 453 has advanced to such a position as to close the upper contact 452. A circuit is also established in position 11 for applying a steady flow of ringing current to the called line over a circuit which may be traced from the source of ringing current 454, through the lower left-hand and upper right-hand contacts of cam 417, through the winding of ringing cut-off relay 455, the lower contacts of cam 402 (11 to 13), the right-hand 30 armature and front contact of relay 421, conductor 429, the lower right-hand contact of cam 414, brush 448 and terminal 449 of the incoming selector switch, trunk conductor 519, the upper contacts of cam 505, brush 553 and terminal 557 of the final selector switch, thence over the called subscriber's line loop through the bell 558 and back over terminal 559 and brush 552 of the final selector switch, the lower contacts of cam 502, conductor 517, bank terminal 447 and brush 35 446 of the incoming selector switch and thence to ground at the upper right-hand contact of cam 413. As soon as relay 451 energizes in position 11 of sequence switch 400, the circuit previously traced through the outer armature and front contact of relay 451 is again established for driving sequence switch 400 out of position 11 and into position 12. Upon leaving position 11, relay 451 deenergizes, but is again energized 40 as soon after sequence switch 400 reaches position 12 as the cam 453 advances to such a position as to engage cam spring 452 with its lower contact, the circuit of relay 451 then being established over the lower contact of spring 452 and the lower contact of cam 416 (12). Relay 451, upon energizing, drives switch 400 out of position 12 and into position 13. In position 13, the source of ringing current 454 is connected to the circuit previously traced through the interrupter 456 and the right-hand contacts of cam 417 and the called subscriber's bell 558 is operated intermittently until the called subscriber responds. During the intermittent application of ringing current, a ringing tone is transmitted back to the calling subscriber through the lower left-hand contact of cam 414, condenser 457, the lower right-hand and upper left-hand contacts of cam 418. 45

Response of the called subscriber.

In response to the ringing of bell 558, the called subscriber removes his receiver 50 from its switch-hook thereby cutting the bell 558 from the line loop and connecting a direct current bridge across the line loop at the substation through the transmitter. Current flowing over the subscriber's line 55 from the source 454 now causes the operation of marginal ringing cut-off relay 455 which upon energizing opens at its armature and back contact the locking circuit previously traced extending through the left-hand winding of relay 421. Relay 421 thereupon deenergizes and opens the circuit over which ringing current has been applied to the called line at its right-hand armature and front contact, and at its inner left-hand armature and back contact closes a circuit extending through the upper left-hand contact of cam 406 for driving sequence switch 400 out of position 13 and into the talking position 16. When the sequence switch 400 passes through position 14, relay 421 again energizes over a circuit extending from battery through its right-hand winding and the lower left-hand and upper right-hand contacts of cam 411 and closes a locking circuit for itself extending through its right-hand winding, the armature and back contact of ringing cut-off relay 455, which relay becomes deenergized as soon as switch 400 leaves position 15. 60

Relay 421, upon energizing, again establishes the previously traced circuit for relay 451 which relay upon energizing, establishes a circuit for driving sequence switch 400 into position 11. As soon as the switch 400 leaves position 10, relay 451 de- 65 energizes, but when switch 400 reaches position 11, relay 451 reenergizes over a circuit which may be traced from battery through its winding, the upper left-hand contact of cam 416 (11) and the upper contact 452 of interrupter cam 453, as soon as the cam 453 has advanced to such a position as to close the upper contact 452. A circuit is also established in position 11 for applying a steady flow of ringing current to the called line over a circuit which may be traced from the source of ringing current 454, through the lower left-hand and upper right-hand contacts of cam 417, through the winding of ringing cut-off relay 455, the lower contacts of cam 402 (11 to 13), the right-hand 70 armature and front contact of relay 421, conductor 429, the lower right-hand contact of cam 414, brush 448 and terminal 449 of the incoming selector switch, trunk conductor 519, the upper contacts of cam 505, brush 553 and terminal 557 of the final selector switch, thence over the called subscriber's line loop through the bell 558 and back over terminal 559 and brush 552 of the final selector switch, the lower contacts of cam 502, conductor 517, bank terminal 447 and brush 75 446 of the incoming selector switch and thence to ground at the upper right-hand contact of cam 413. As soon as relay 451 energizes in position 11 of sequence switch 400, the circuit previously traced through the outer armature and front contact of relay 451 is again established for driving sequence switch 400 out of position 11 and into position 12. Upon leaving position 11, relay 451 deenergizes, but is again energized 80 as soon after sequence switch 400 reaches position 12 as the cam 453 advances to such a position as to engage cam spring 452 with its lower contact, the circuit of relay 451 then being established over the lower contact of spring 452 and the lower contact of cam 416 (12). Relay 451, upon energizing, drives switch 400 out of position 12 and into position 13. In position 13, the source of ringing current 454 is connected to the circuit previously traced through the interrupter 456 and the right-hand contacts of cam 417 and the called subscriber's bell 558 is operated intermittently until the called subscriber responds. During the intermittent application of ringing current, a ringing tone is transmitted back to the calling subscriber through the lower left-hand contact of cam 414, condenser 457, the lower right-hand and upper left-hand contacts of cam 418. 85

tion 13, the upper left-hand contact of cam 409, conductor 431, the outer left-hand armature and front contact of relay 421, conductor 427, the upper contact of cam 407 5 and thence over the sleeve conductor of the trunk to ground connected as previously described to this conductor.

As soon as switch 400 reaches position 14, a direct current path is established 10 through the right-hand winding of repeating coil 458 and thence over the called subscriber's line loop for supplying the calling subscriber with talking current. This path may be traced from the non-grounded pole 15 of battery through the lower right-hand winding of coil 458, the winding of relay 459, the upper left-hand contact of cam 414, thence over the circuit previously traced through the called subscriber's substation 20 loop and returning through the lower contact of cam 413 and upper right-hand winding of coil 458 to the grounded pole of battery. Relay 459 energizes in this circuit and connects the terminals of central station battery between the left-hand 25 windings of repeating coil 458 in such a manner as to cause current to flow over the trunk line extending through the office selector switch to the district selector switch 30 in such a direction as to effectively energize the polarized relay 266 at the district selector. This circuit may be traced from the non-grounded pole of battery over conductor 460, the upper left-hand contact of 35 cam 405 (11 to 16), conductor 426, resistance element 425, the upper contacts of cam 415 (11 to 16), the lower left-hand winding of coil 458, the upper contact of cam 404 (11 to 16), conductor 420, bank terminal 337 and brush 335 of the office selector switch, the contact of cam 311 (8), trunk conductor 314, bank terminal 256 and brush 258 of the district selector switch, the upper contacts of cam 219, the lower right-hand 40 winding of coil 265, the upper contact of cam 222, the winding of relay 266, the lower right-hand and upper left-hand contacts of cam 221, the upper right-hand winding of coil 265, the left-hand contacts of cam 220, brush 259 and bank terminal 257 of the 45 district selector switch, trunk conductor 313, the contact of cam 310, brush 334 and bank terminal 336 of the office selector switch, conductor 419, the lower contact of cam 403 (11 to 16), the upper left-hand winding of coil 458, resistance element 424 and thence through the armature and front contact of relay 459 to ground.

Relay 266, upon energizing in the previously traced circuit, closes a circuit for relay 267 as soon as cam 268 has rotated to such a position as to close cam spring 269. This circuit may be traced from battery through the contact of cam spring 269, the winding of relay 267, the left-hand contacts

of cam 217, the contact of polarized relay 266 and thence to ground at the right-hand contact of cam 209. Relay 267, upon energizing, closes a locking circuit for itself extending from battery through its right-hand armature and front contact and thence to ground over the circuit previously traced independent of cam spring contact 269. As soon as cam 268 rotates to such a position as to open the spring contact 269 and close 75 spring contact 270, a circuit is established for relay 261 which may be traced from battery through the winding of relay 261, the left-hand armature and front contact of relay 267 and thence to ground at spring contact 270. Relay 261, upon energizing, closes a locking circuit for itself independent of cam spring 270 which may be traced from battery through the winding of relay 261, the left-hand contact of cam 218 (12 80 to 18) and thence to ground through the right-hand armature and front contact of relay 261. At its left-hand armature and front contact, relay 261 prepares a call charging circuit which is effective to charge 85 a call against the calling subscriber following the termination of the conversation and the advancement of switch 200 into position 17. With sequence switch 200 in position 12 for talking, talking current is supplied 90 to the calling subscriber over a circuit which may be traced from the non-grounded pole of battery through the lower left-hand winding of repeating coil 265, the upper right-hand contact of cam 213, the winding of supervisory relay 234, conductor 116, wiper 111, the innermost lower armature and front contact of relay 102 conductor 103, 95 thence over the subscriber's line loop, conductor 104, the upper armature and front contact of relay 102, wiper 113, conductor 117, the lower right-hand contact of cam 212 and thence to the grounded pole of battery through the upper left-hand winding of repeating coil 265. Relay 234 energizes in this circuit and at its armature and front contact closes a locking circuit to maintain relay 227 energized, which circuit may be traced from battery through 100 the left-hand winding of relay 227, the armature and front contact of relay 234 and thence to ground at the right-hand armature and front contact of relay 227. The calling and called subscribers are now connected over a talking circuit shown in the drawings by the heavy conductors, the calling subscriber receiving talking current over the circuit just traced and the called subscriber receiving talking current through 105 the right-hand windings of repeating coil 110 458.

Restoration of the office sender.

It will be recalled that following the completion of the dialing of the seven digits 115 120 125

designating the number of the called line, the register steering switch RS advanced its wipers into contact with the No. 7 terminals of the banks to which the wipers have access. Since the calling subscriber has caused the setting of the class switch into position 4 for a full mechanical connection, then as soon as the translator control sequence switch reaches position 9, in which 5 position the sender first functions to set the district selector switch, and with the time measure switch TM in position 11, a circuit is established for advancing the register steering switch out of position 7 and into 10 position 8. This circuit may be traced from battery through the winding of stepping magnet 1113, wiper 1143, terminal 1144, conductor 1145, the contact of class switch cam 942 (13 to 11), conductor 943, the right- 15 hand contacts of cam 760, terminal 761 and thence to ground through terminal 761 and wiper 714 of switch TM. Upon reaching position 8 a similar circuit is established for advancing the register steering switch into position 20 25 which circuit may be traced through the winding of stepping magnet 1113, wiper 1143, terminal 1146, conductor 1147 and thence to ground through the lower right-hand contact of class switch cam 944. Upon reaching position 9, the register circuit switch is advanced into position 10 by a circuit extending through the winding of magnet 1113, wiper 1143, terminal 1148, conductor 1149 and thence to ground at the 30 35 upper contact of class switch cam 944 (13 to 11). Upon reaching position 10, a circuit is established over wiper 1103 and terminal 1150 for advancing monitoring switch M out of position 7 through the energization of relay 610. The circuit for relay 610 40 may be traced from battery through the right-hand winding of relay 610, wiper 617, the No. 7 terminal of the bank with which this wiper is in engagement, conductor 628, 45 terminal 1150, wiper 1103 and thence to ground at the right-hand armature and front contact of relay 1102. Upon the energization of relay 610, a circuit is established for stepping magnet 610 which may be 50 traced from battery through the winding of magnet 618, the armature and contact of magnet 618, the right-hand armature and front contact of relay 610 and thence to ground at the right-hand armature and front 55 contact of relay 802 over the circuit previously traced. Magnet 618 advances the wipers of switch M until the wiper 617 leaves the No. 8 terminal of its bank, when relay 610 deenergizes and opens the circuit of magnet 618. A new stepping circuit for 60 switch M is now established from battery through the winding of magnet 618, the right-hand armature and back contact of relay 610, slow interrupter 619, the inner left-hand armature and back contact of relay 65

620, the No. 9 terminal of the bank with which wiper 677 is in engagement, wiper 677, the inner left-hand armature and back contact of relay 610 and thence to ground at the intermediate right-hand armature and front contact of relay 605. Under the influence of interrupter 619, switch M is advanced into position 11. 70

As the wipers of switch M pass through positions 9 and 10, a circuit is established 75 for relay 600, which may be traced from battery on conductor 611, through the winding of relay 629, the winding of relay 600, the outer left-hand armature and front contact of relay 616, wiper 623, outer left-hand armature and back contact of relay 610 to ground at the intermediate right-hand armature and contact of relay 605. Relay 600 locks through its inner right-hand armature and front contact, conductor 630, the contacts 80 of cam 762 and thence to ground at the outer right-hand armature and front contact of relay 706. 85

At the back contacts of its outer right-hand and outer left-hand armatures, relay 90 600 opens the circuit previously traced extending from the subscriber's line through the windings of register stepping relay 1100 and retardation coil 716 and connects the subscriber's line with the windings of marginal differential relays 614 and 631. The disconnection of the winding of relay 1100 from the subscriber's line loop does not cause the release of relay 1100, since this relay is maintained over a locking circuit which may 95 be traced from battery through the winding of relay 1100, conductor 1101, the inner left-hand armature and front contact of relay 600, conductor 632 and thence to ground through the right-hand armature and front contact of relay 1102. The energizing circuit of relays 614 and 631 may now be traced from the source 660 of negative current through the left-hand armature and front contact of relay 629, the inner right-hand armature and back contact of relay 612, the outer right-hand armature and back contact of relay 615, the left-hand windings 100 of marginal differential relays 614 and 631, 105 bank terminals Nos. 9, 10 and 11 to which the wiper 606 has access, wiper 606, the outer right-hand armature and front contact of relay 600, the outer right-hand armature and back contact of relay 601, conductor 603, 110 thence as previously traced through the subscriber's line and returning over conductor 602, the outer left-hand armature and back contact of relay 601, the outer left-hand armature and front contact of relay 600, 115 wiper 633, the Nos. 9, 10 and 11 terminals 120 to which this wiper has access, the right-hand windings of relays 631 and 614, the inner left-hand armature and back contact of relay 615 and thence to ground at 125 the outer right-hand armature and front 130

contact of relay 605. Relays 614 and 631, being differentially wound, do not energize in this circuit.

It has been assumed in tracing the establishment of the connection to the called subscriber's line L that the calling subscriber deposited the required coin or token either before dialing the number or immediately following the dialing of the number and that, therefore, at the time dialing was completed and the switch M reached position 9, an effective energizing circuit for relay 614 is established which may be traced from the source 660 of negative current over the path 15 previously traced to the subscriber's line, conductor 104 and thence to ground through the winding of coin collection magnet 126 and the contacts 127 which are operated by the deposit of the coin. Relay 614 energizes in series with the winding of magnet 126, but relay 631 being marginally wound does not receive sufficient current to energize at this time. Relay 614, upon energizing, opens the previously traced locking circuit 25 of relay 609 at the armature and back contact of relay 614 and relay 609, upon deenergizing, opens the circuit of relay 616, which in turn, opens the circuit of relay 802 so that when the sender sequence switch 800 reaches position 5 preparatory to controlling units selection, relay 802 will not become energized to hold the fundamental circuit open at the back contact of its outer armature. Since the functioning of the 35 monitor's circuit in connection with the deposit or failure to deposit a coin has been fully described in the copending application of E. H. Mills, Serial No. 433,987, filed December 30, 1920, further description of such operations is considered unnecessary herein.

When the time measure switch M reaches position 9, the calling subscriber having properly deposited the coin and relays 609 and 616 being deenergized, a circuit is closed for advancing the time measure switch M from position 9 into position 15 through the operation of relay 610. The circuit of relay 610 may be traced from battery through the right-hand winding of the relay, wiper 617 and bank terminals 9 to 14 with which it engages during its advancement and thence to ground at the right-hand armature and back contact of relay 616. Relay 610, upon energizing, closes the previously traced circuit for the stepping magnet 618 which circuit is maintained until wiper 617 leaves terminal 14 of its bank when relay 610 deenergizes and opens the circuit of magnet 618. In position 15, relay 610 is again energized over wiper 617, the inner left-hand armature and back contact of relay 615 to ground at relay 605 and drives switch M into position 18. Relay 610, upon deenergizing when switch M reaches position 18, closes a new circuit for advancing

switch M into position 20 which circuit may be traced from battery through the winding of magnet 618, the right-hand armature and back contact of relay 610, interrupter 619, the inner left-hand armature and back contact of relay 620, the bank contacts with which wiper 677 is associated, wiper 677, the inner left-hand armature and back contact of relay 610 and thence to ground at the intermediate right-hand armature and front contact of relay 605. Under the control of interrupter 619, the stepping magnet 618 advances switch M into position 20 when the previously traced stepping circuit is opened at wiper 677. If at the time the wipers of the time measure switch M reach position 20, the sender has not functioned to set up the desired connection, sender monitoring lamp 621 is flickered to denote a stuck sender. The circuit of lamp 621 may be traced from battery through the lamp, the inner left-hand armature and back contact of relay 616, interrupter 635, bank terminal 638, wiper 623, the outer left-hand armature and back contact of relay 610 and thence to ground at the intermediate right-hand armature and front contact of relay 605.

Under the assumption that the establishment of the connection proceeded without interruption in the manner hereinbefore described, as soon following units selection as the sequence switch of the district selector advances out of position 10 for talking selection, the impulse leads 233 and 235 which, up to the time switch 200 leaves position 10 $\frac{1}{2}$ are connected with the windings of stepping relay 1100 and retardation coil 716, are disconnected from the district trunk conductors 116 and 117 at the contacts of cams 212 and 213. Upon the opening of the circuit over impulse leads 233 and 235, stepping relay 1100 deenergizes, opening the circuit of slow releasing circuit 1102, which upon deenergizing, closes a circuit extending from ground through the normal contacts of its right-hand armature, the strapped terminals 1151 and wiper 1152 of the restoring bank of the switch RS, the armature contact and winding of stepping magnet 1113 and thence to battery through the winding of slow releasing relay 1112. Stepping magnet 1113 thereupon causes the restoration of the steering switch from position 10 into normal position.

Upon the completion of talking selection and the deenergization of relay 228 of the district selector switch, relays 230 and 244 become deenergized, since their locking circuit is now opened at the outer right-hand armature and front contact of relay 228 and relay 230, upon deenergizing, opens the circuit of relay 706. Relay 706, upon deenergizing, closes at the normal contacts of its inner left-hand armature, a holding circuit for relay 705 extending from battery

through the winding of relay 705, the contacts of relay 706 and thence to ground at the upper contact of cam 727 (1 $\frac{3}{4}$ to 18). Relay 705 is thus maintained energized to 5 maintain the circuit of relay 704 closed so that busy ground potential is maintained on conductor 702 until the office sender is restored to normal condition. At its outer left-hand armature and back contact relay 10 706 closes a restoring circuit for the time measure switch TM which may be traced from battery through the winding of stepping magnet 711, the armature and back contact of this magnet, wiper 763, the 15 strapped contacts of the restoring bank with which it is associated and thence to ground at the outer left-hand armature and back contact of relay 706. Under the influence of magnet 711, the time measure switch is 20 restored to its normal position. Upon the deenergization of relay 706, the holding circuits of relays 712 and 707 are opened at the outer left-hand armature and front contact of relay 706 and these relays thereupon 25 de- energize.

When the time measure switch TM reaches normal position, a circuit is closed for driving the translator sequence switch 700 out of position 15 and into position 18, which circuit may be traced from battery through the 30 magnet winding of switch 700, the lower left-hand contact of cam 722 (2 to 17) and thence to ground at the normal contact and wiper 719 of switch TM. If the translator 35 switch TS has reached normal position at this time, a circuit is completed for continuing the movement of switch 700 out of position 18 and into normal position. This circuit may be traced from battery through the 40 magnet winding of switch 700, the upper left-hand contact of cam 728, conductor 764 and thence to ground at the armature and back contact of relay 1569.

In the movement of the translator control 45 sequence switch 700 through positions 12 to 18, a circuit was established for restoring the code registers to normal position. As soon as sequence switch 700 reaches position 14, at which time the sender has fully functioned to establish the connection, a circuit 50 is established for relay 1155 which may be traced from battery through the winding of this relay and to ground at the lower left-hand contact of cam 765 (14 to 18). With 55 relay 1155 energized, a restoring circuit is effective for restoring register A which may be traced from battery through the winding and armature contacts of stepping magnet 1105, the strapped terminals 1153 and 60 wiper 1154 of the restoring bank of register A and thence to ground at the outer right-hand armature and front contact of relay 1155. When register A reaches normal position, a 65 similar circuit is established for stepping magnet 1114 of register B extending through

the winding, armature and contact of this magnet, terminals of restoring bank 1157, wiper 1156, the normal contact of restoring bank of register A, wiper 1154 and thence to ground at the outer right-hand armature 70 and front contact of relay 1155. Register B, upon reaching normal position, transfers the restoring circuit extending from the armature contact of relay 1155, through wiper 1154 and the normal contact of its bank, 75 wiper 1156 and the normal contact of its bank, through wiper 1158 and terminals 1159 of the restoring bank of register C, thence through the winding of the stepping magnet 1116 of register C to battery. 80

Simultaneous with the restoration of the code registers, a restoring circuit is established for the thousands register TH which may be traced from battery through the winding, armature and contact of stepping 85 magnet 1160 of this register, terminals 1161 of the restoring bank of this register, wiper 1162 and thence to ground through the left-hand armature and front contact of relay 1155. When register TH reaches normal 90 position, the restoring circuit extending to ground through the armature and contact of relay 1155 is extended through wiper 1162 and the normal contact upon which it is now resting, through wiper 1164 and terminals 1163 of the restoring bank of hundreds register H, through the winding of stepping magnet 1165 of the hundreds register to battery. In a similar manner, when register H reaches normal position, the 95 restoring circuit is extended through wiper 1207 and terminals 1208 of the restoring bank of tens register T and to battery through the stepping magnet 1209 of this register. Upon the energization of relay 100 1155, a restoring circuit is also established for the units register U which may be traced from battery through the winding, armature and contact of stepping magnet 1210 of the units register, contacts 1211 of restoring 105 bank of the register wiper 1212 and thence to ground at the outer right-hand armature and front contact of relay 1155. Upon the restoration of register U, the restoring circuit is extended through wiper 1212 and 110 the normal contact of the bank with which it is associated to the wiper 1213 associated with the restoring bank 1214 of the first stations register ST. Since it has been assumed that the stations registers were not 115 moved from normal position by the line designation dialed by the calling subscriber, the extension of the restoring circuit in succession through the restoring banks of these registers to the windings of the stepping magnets 1215, 1216 and 1217 is without effect at this time. 120

As soon as the translator control sequence switch 700 leaves position 11, battery is removed at sequence switch cam 736 from the 125 130

- locking circuit of the office group register relay 1435, district group register relay 1428, sender delay register relays 1437 and 1438, special service register relay 1439 and 5 skip office register relay 1045, if any of these relays have been energized and locked to control the establishment of the connection. In the case assumed, only relay 1435 is at the time energized. The locking circuit for relay 1435 may be traced from battery through the upper right-hand contact of cam 736 (7 to 11), conductor 945, the lower left-hand, upper right-hand contacts of cam 946 of the route switch, conductor 947 and thence 10 through the left-hand armature and front contact and left-hand winding of relay 1435. Upon the opening of this circuit, relay 1435 deenergizes and returns to its normal condition.
- 15 20 When sequence switch 700 leaves position 13, battery is disconnected from conductor 1311 for unlocking the district brush, office brush, district group and office group register relays which have been locked up, and upon leaving position 14½, battery is disconnected from conductor 1409 for unlocking the class register relays, compensating resistance register relays, route and zone register relays and the talking selection 25 register relay 1410 which were energized, and locked up by the operation of the pulse machine. Upon leaving position 18, sequence switch 700 opens the contact of cam 727 thereby opening the locking circuit of 30 relays 705 and 873 which relays thereupon become deenergized. The circuits of the entire office sender are now restored to normal condition and the office sender may be taken 35 for use in establishing other connections.
- 40 *Restoration of the connection between the calling line and the called line.*
- Upon the termination of the conversation both the calling and called subscribers 45 restore their respective receivers to their switchhooks. At this time relay 261 is energized since this relay was energized as previously described upon the response of the called subscriber. Upon the restoration 50 of the calling subscriber's receiver to its switchhook, supervisory relay 234 deenergizes, opening the holding circuit of relay 227 and since the holding circuit through the right-hand winding of relay 227 is now 55 opened, the sender having been disassociated from the district selector, relay 227 deenergizes, closing a circuit for driving sequence switch 200 out of position 12 and into position 16, this circuit extending from battery 60 through the winding of sequence switch magnet 200, the lower left-hand contact of cam 206 (12 to 17), the left-hand contacts of cam 223 (12 to 15) and thence to ground at the normal contacts associated with the 65 right-hand armature of relay 227. At its left-hand armature, relay 227 opens the previously traced locking circuit for relay 226 extending over the upper contact of cam 203 and establishes a new locking circuit for relay 226 which may be traced through the 70 left-hand winding of relay 226, the normal contacts associated with the left-hand armature of relay 227, the lower right-hand contact of cam 203 and thence over sleeve conductor 118 to ground through the winding 75 of relay 102 as previously traced.
- As soon as sequence switch 200 reaches position 16, a circuit is closed for relay 228 which may be traced from grounded battery through the right-hand winding of relay 228, the upper contacts of cam 204, the right-hand armature and front contact of relay 226, the upper right-hand and lower left-hand contacts of cam 223 and thence 80 to ground at the normal contact associated with the right-hand armature of relay 227. Relay 228, upon energizing, closes a circuit for driving sequence switch 200 out of position 16 and into position 17 which circuit may be traced from grounded battery 85 through the magnet winding of sequence switch 200, the lower right-hand contact of cam 206 (16), the inner right-hand armature and front contact of relay 228 and thence to ground at the right-hand contact of cam 207. Relay 228, upon energizing, establishes a locking circuit for itself extending through its left-hand winding, its left-hand armature and front contact, the lower right-hand contact of cam 210, the lower left-hand contact of cam 211 (16 to 17), the outer left-hand armature and front contact of relay 226, wiper 231 and thence 90 to ground on the contact of the bank with which wiper 231 is then in engagement, if the sender associated with the multiples upon which the wipers of the sender finder SF are then resting is at the time employed. When sequence switch 200 reaches position 17, a circuit is established for the stepping magnet 229 of the sender finder SF extending from battery through the armature contacts and winding of magnet 229, the lower contact of cam 208 (16½ to 17), the inner right-hand armature and front contact of relay 228 and thence to ground at the right-hand contact of cam 207 (7½ to 6). Under the influence of magnet 229, the wipers of switch SF are advanced over the multiples of conductors extending to office senders assigned to the group of district selector switches in which the district selector 250 is located until the test wiper 231 encounters a bank terminal corresponding to an idle office sender, when the previously traced 100 locking circuit of relay 228 is opened and relay 228 becomes deenergized, opening the circuit of stepping magnet 229. A circuit is now established for relays 230 and 244 105 which may be traced from battery through 110 115 120 125 130

the armature and back contact and winding of magnet 229, the windings of relays 230 and 244 in parallel, the lower right-hand and upper left-hand contacts of cam 204, 5 the right-hand armature and front contact of relay 226 and thence to ground at the upper right-hand contact of cam 205 (17 to 15).

Upon the energization of relay 230, the 10 circuit previously traced for relay 706 is established and relay 706 energizes, closing the previously traced circuit for relay 707, which in turn, closes the circuit for advancing switch TM from normal position into 15 position 2. Also, upon the energization of relay 706 and the advance of switch TM out of normal position, relays 705, 712 and 605, energize in the manner previously described in connection with the initial seizure of a 20 sender for establishing the connection. Upon the energization of relay 712, the dialing circuit is again extended through the lower contacts of cams 212 and 213, closed in position 17, through the left-hand armature contacts of relay 230 and wipers 245 and 236 to the windings of the stepping relay 1100 and retardation coil 716. Since the subscriber's receiver has been restored to its switchhook, this circuit is without 25 effect. Upon the advancement of the time measure switch TM to position 6 with relay 1100 deenergized, a circuit is established for wipe-out relays 757 and 766 which may be traced from battery through the windings 30 of these relays in parallel, the No. 6 terminal of bank 767, wiper 768, conductor 769, the normally closed contacts associated with the left-hand armature of relay 1102 and thence to ground at the left-hand armature and back contact of relay 1100.

Immediately upon the extension of the connection from the district selector switch 250 to the office sender, assuming that the established connection has been successful, 45 a circuit is established for the coin collection relay 612 which may be traced from battery through the winding of relay 612, conductor 642, the left-hand contacts of cam 760 (1), the translator control sequence 50 switch being in normal position, the conductor 770, the upper contacts of route switch cam 948, conductor 949, conductor 842, the right-hand contact of cam 749 (1), the left-hand armature and back contact of 55 advance relay 750, conductor 751, wiper 263 of the sender finder switch SF, the left-hand armature and front contact of relay 244, the lower right-hand contact of cam 218 (16 to 60 17) and thence to ground at the right-hand armature and contact of charging relay 261. It is to be noted in this connection that since the subscriber's receiver is upon its switchhook at the time the sender is seized and 65 since no digits have been dialed, the translator control sequence switch 700 and all

other sequence switches associated with the office sender are in normal position.

Upon the energization of relay 605 following the seizure of the sender, a circuit is established for relay 609 extending from 70 battery at the outer right-hand armature and back contact of relay 907, conductor 1401, the right-hand armature and back contact of relay 1400, conductor 611, the winding of relay 609, the normal contact of the 75 bank with which wiper 677 is in engagement, the inner left-hand armature and back contact of relay 610 and thence to ground at the intermediate right-hand armature and front contact of relay 605. Relay 609, upon 80 energizing, closes a locking circuit for itself independent of the wiper 677 extending from battery on conductor 611, through the winding of relay 609, the left-hand armature and front contact of relay 609, the outer 85 right-hand armature and front contact of relay 612 and thence to ground at the armature and back contact of relay 643. At its right-hand armature and front contact, relay 609 establishes a circuit for relay 610 90 which may be traced from battery through the right-hand winding of relay 610, wiper 617 and the normal contact of the bank with which it is associated and thence to ground 95 at the right-hand armature and front contact of relay 609. Relay 610, upon energizing, closes a circuit for the stepping magnet 618 of the switch M which may be traced from battery through the winding of magnet 618, the armature and back contact of 100 this magnet, the right-hand armature and front contact of relay 610, wiper 617 and the normal contact with which it is in engagement and thence to ground at the right-hand armature and front contact of relay 609. 105

As soon as switch M reaches position 1, a circuit is established for relays 615 and 620 which may be traced from battery through the windings of these relays in parallel, conductor 644, the inner right-hand armature and front contact of relay 605, position 1 terminal of bank 640, brush 641, the outer left-hand armature and front contact of relay 605, the normally closed contacts associated with the outer left-hand armature of relay 620, conductor 645, the inner left-hand armature and back contact of advance relay 708, conductor 771, the right-hand armature and back contact of relay 1117, conductor 1166 and thence to ground through the front contact and inner right-hand armature of wipe-out relay 757. Relay 620, upon energizing, establishes a locking circuit for both relays 650 and 620 110 independent of wiper 641 which may be traced through the windings of relays 620 and 615 in parallel, thence through the outer left-hand armature and front contact of relay 620 and to ground at the armature and front contact of relay 757 over the circuit 115 120 125 130

previously traced. Upon the energization of relay 609, a circuit is also established for relay 616 extending from battery on conductor 611, thence through the winding of relay 616 to ground at the right-hand armature and front contact of relay 609.

Upon the energization of relay 615, a circuit is established for relay 600 which may be traced from battery on conductor 611, 10 through the winding of relay 629, the winding of relay 600, the inner left-hand armature and front contact of relay 615 and thence to ground at the outer right-hand armature and front contact of relay 605. 15 Relay 600, upon energizing, closes a locking circuit for itself extending from battery on conductor 611 over the circuit previously traced through the winding of relay 600, the inner right-hand armature and front contact of relay 600, conductor 630, the contacts of cam 762 (1 to 13) and thence to ground at the outer right-hand armature and front contact of relay 706.

As soon as switch M leaves its normal position, the circuit of relay 610 is opened at wiper 617, but when the switch reaches position 1, a new energizing circuit for relay 610 is established extending from battery through the right-hand winding of relay 610, wiper 617, conductor 646, the outer right-hand armature and front contact of relay 629 and thence to ground at the outer right-hand armature and front contact of relay 605. Relay 610, upon energizing, 30 closes a circuit for stepping magnet 618 extending from battery through the winding, armature and back contact of magnet 618, the right-hand armature and front contact of relay 610, wiper 617 and thence to ground at the outer right-hand armature and front contact of relay 605 over the circuit previously traced. Through the operation of magnet 618, switch M is rapidly advanced to position 5, the circuit of relay 610 is 35 opened at brush 617 and the circuit of stepping magnet 618 is opened. With relay 610 deenergized, a new circuit for magnet 618 is established extending from battery through the winding of magnet 618, the right-hand armature and back contact of relay 610, the fast interrupter 647, the inner left-hand armature and front contact of relay 620, thence over position 5 bank terminal with which wiper 677 is in engagement, wiper 677, the inner left-hand armature and 40 back contact of relay 610 and to ground at the intermediate right-hand armature and front contact of relay 605. Under the influence of interrupter 647, the stepping magnet 618 advances the wipers of switch M to position 7, in which position the stepping circuit of magnet 618 is extended over the circuit previously traced through the inner right-hand armature and front contact of relay 620, thence through the right-hand

armature and front contact of relay 620 to the position 7 terminal of the bank with which wiper 677 is in engagement and thence to ground as previously traced. Upon reaching position 8, the circuit of magnet 618 is completed over the circuit previously traced through the inner left-hand armature and front contact of relay 620 for continuing the advance of switch M into position 11.

When the wipers of switch M reach position 5, a circuit is closed for applying coin collection current from the source 661, through the inner right-hand armature and front contact of relay 629, the winding of relay 643, the inner left-hand armature and front contact of relay 612, the outer right-hand armature and front contact of relay 615, thence in parallel through bank terminals 648 and 649, wipers 606 and 633, the outer right-hand armature and front contact and outer left-hand armature and front contact of relay 600, the outer right-hand armature and back contact and outer left-hand armature and back contact of relay 601, thence over conductors 602 and 603 of the circuit previously traced to the subscriber's line K. Current from the source 661 now flows through the coin magnet 126 and through contacts 127 to ground in such a direction as to cause the polarized magnet 126 to energize to collect the deposited coin. Relay 643 also energizes in series with magnet 126 and at its armature and back contact opens the previously traced locking circuit of relay 609, which in turn, opens the circuit of relay 616.

When wipers 606 and 633 of the switch M reach position 7, both conductors of the subscriber's line are connected over the circuit previously traced through wipers 606 and 633, bank terminals 651 and 652 to ground through condenser 650 for the purpose of discharging the subscriber's line from the charge of collection current which was applied for collecting the deposited coin.

When the wipers of switch M reach position 9, the right-hand and left-hand windings of differential relay 653 are connected respectively to the tip and ring conductors of the subscriber's line over the circuit previously traced from the subscriber's line to wipers 606 and 633 and thence through bank terminals 654 and 655 to battery through the windings of relay 653. If the calling subscriber, following the collection of the coin, has immediately removed his receiver from the switchhook to initiate another call, or if the receiver is still on the hook and the coin has been properly collected, relay 653 does not energize over the circuit previously traced. If, however, the coin is stuck in the coin chute and ground is maintained on the tip conductor 104 of the

subscriber's line at coin box contacts 127, relay 653 becomes energized and closes a circuit for relay 609 which may be traced from battery on conductor 611, through the winding of relay 609 and thence to ground at the armature and front contact of relay 653. Relay 609, upon energizing, locks up over the circuit previously traced to ground at the armature and back contact of relay 643, this relay having deenergized as soon as switch M moved out of position 6, and also closes the previously traced circuit for relay 616. When the switch M now reaches position 11, the circuit of stepping magnet 618 is opened at brush 677 and the switch is arrested. A circuit is now established for flashing the coin lamp 634 which may be traced from battery through lamp 634, interrupter 656, the inner right-hand armature and front contact of relay 615, bank terminals 636, wiper 623, the outer left-hand armature and back contact of relay 610 and thence to ground at the intermediate right-hand armature and front contact of relay 605. The flashing of the coin lamp 634 at this time signifies to the monitoring operator that the coin has stuck in the coin chute at the calling subscriber's substation and she will thereupon initiate the necessary steps to clear the trouble.

If the coin is properly collected, relay 653 does not energize, and consequently, relays 609 and 613 do not energize at this time. Therefore, when switch M reaches 9, a circuit is established for rapidly advancing switch M into position 15 through the operation of relay 610 which energizes in a circuit which may be traced from battery through the right-hand winding of relay 610, wiper 617, position 9 terminal of the bank with which wiper 617 is associated and to ground at the right-hand armature and back contact of relay 616. This circuit is maintained until the wipers of switch M advance out of position 14.

As soon as the wipers of switch M reach position 15, a circuit is established for relay 227 of the district selector switch which may be traced from battery through the right-hand winding of relay 227, the upper contact of cam 214 (17), the right-hand armature and front contact of relay 244, the lower contact of cam 215 (17), wiper 232, the outer left-hand armature and back contact of relay 708, conductor 772, position 15 terminal of the bank with which wiper 623 is in engagement, wiper 623, the outer left-hand armature and back contact of relay 610 and thence to ground at the intermediate right-hand armature and front contact of relay 605. This circuit is maintained while the switch M is advancing through positions 16 and 17 under the control of interrupter 647. Relay 227, upon energizing, opens the previously traced locking circuit

of relay 226 at the normally closed contacts associated with its left-hand armature. Relay 226, upon deenergizing, opens the locking circuit over which relays 230 and 234 have been maintained energized and these 70 relays thereupon deenergize. Relay 230, upon deenergizing, opens the circuit of relay 706 which in the manner previously described closes a circuit extending through the restoring bank of switch TM, wiper 763 75 associated therewith and the winding of stepping magnet 711 for restoring the time measure switch TM to normal position. As soon as switch TM reaches normal position, the circuit of relays 757 and 756 is opened 80 and the previously traced locking circuit of relays 615 and 620 is opened. When switch TM reaches normal position, and with relay 706 deenergized, relays 712, 705 and 605 become deenergized. Relay 605, upon deenergizing, closes a circuit for relay 610 which may be traced from battery through the right-hand winding of relay 610, the contacts of bank 640, wiper 641 and thence to ground at the left-hand armature and back contact of relay 605. Relay 610, upon energizing, closes a circuit for stepping magnet 618 which may be traced from battery through the winding, armature and back contact of magnet 618, the right-hand 90 armature and front contact of relay 610, contacts of bank 640, wiper 641 and thence to ground at the outer left-hand armature and back contact of relay 605. As soon as switch M reaches normal position, the circuit of relay 610 is opened and relay 610, upon deenergizing, opens the circuit of stepping magnet 618. As soon as the switch M passes through positions 18 and 19, a circuit is closed for shunting the winding of relay 600 extending from conductor 630 through the inner right-hand armature and front contact of relay 600, position 18 terminal of the bank with which wiper 623 is associated, wiper 623, the outer left-hand armature and back contact of relay 610 and to ground at the intermediate right-hand armature and front contact of relay 605. This circuit is effective prior to the deenergization of relay 605 for insuring the deenergization of relay 600 and the consequent deenergization of relay 629 which is held locked up in series with relay 600. The circuits of the central office sender are now in normal position.

For the purpose of recording each successful call initiated by the calling line, a circuit is closed when the sequence switch of the district selector is in position 17 for increasing the strength of the current flowing through the message register magnet 119. This circuit is established from battery through the lower contacts of cam 299 (17), the left-hand armature and front contact of relay 261, the right-hand non-inductive

winding of relay 226, thence over the circuit previously traced through the winding of magnet 119 and the windings of cut-off relay 102. The current now flowing through 5 the two windings of relay 226 in parallel is of sufficient strength to operate the register magnet 119.

At the district selector switch upon the deenergization of relay 226, a circuit is 10 closed for advancing sequence switch 200 out of position 17 and into position 18 which may be traced from battery through the magnet winding of switch 200, the lower left-hand contact of cam 206 (12 to 17), 15 the right-hand armature and back contact of relay 226 and thence to ground at the upper right-hand contact of cam 205 (17 to 15). As soon as switch 200 leaves position 17, the energizing circuit of relay 227 is 20 opened and relay 227 deenergizes. With sequence switch 200 in position 18, a circuit is closed for the downdrive magnet 271 which may be traced from battery through the winding of magnet 271, the lower contacts of cam 223 and thence to ground at 25 the normally closed contacts associated with the right-hand armature of relay 227. Magnet 271, upon energizing, presses the depending portion of switch shaft 239 against 30 the constantly rotating downdrive drum 272 and in the well-known manner causes the restoration of the switch shaft to its normal position. Upon reaching its normal position, a circuit is established for sequence 35 switch magnet 200 which may be traced from grounded battery through the winding of the sequence switch magnet, the upper right-hand contact of cam 206, normal commutator segment 273, brush 248 and thence to ground at the lower contact of cam 209. The sequence switch magnet is energized 40 in this circuit and advances the sequence switch into normal position. As soon as the sequence switch leaves position 18, the locking circuit of relay 261 is opened at 45 cam 218. The circuits of the district selector are now in normal condition.

Upon the opening of the circuit extending through the winding of sleeve relay 226 and 50 the winding of cut-off relay 102, relay 102 becomes deenergized, and at its lowermost armature and back contact closes the circuit of stepping magnet 105 for restoring the line switch into its normal position. The circuit of magnet 105 55 may be traced from battery through the winding, armature and back contact of magnet 105, conductor 106, the lowermost armature and back contact of relay 102, the right-hand armature and back 60 contact of relay 101, conductor 125, wiper 112 and thence to ground on segment 124. As soon as switch 100 reaches normal position, the circuit of magnet 105 is opened at 65 wiper 112.

As soon as sequence switch 200 leaves position 14½, holding ground potential is removed from the test brush 252 at the lower left-hand contact of cam 216 (8½ to 14½) and the circuit extending over bank terminal 70 255, sleeve conductor 333, the lower right-hand contact of cam 305, the inner right-hand armature and front contact and right-hand winding of relay 312 is opened and relay 312 deenergizes. At the same time the 75 circuit of relay 421 of the incoming selector switch 450 is opened, this circuit extending from conductor 333, through the right-hand contacts of cam 305, brush 330 and bank terminal 334 of the office selector switch, the 80 upper contact of cam 407, conductor 427, the outer left-hand armature and front contact of relay 421, conductor 431, the upper left-hand contact of cam 409, the armature and back contact of relay 455 and thence to 85 battery through the right-hand winding of relay 421.

Relay 312 of the office selector, upon deenergizing, closes a circuit for placing busy ground potential upon the bank terminal 255 90 and its multiples appearing in its banks of all district selector switches which have access to this office selector to prevent the seizure of the office selector until it is completely restored to normal. This ground potential is applied over a circuit extending from sleeve conductor 333 through the lower right-hand contact of cam 305 (6¾ to 18), the inner right-hand armature and back contact of relay 312 and thence to ground 95 through the upper left-hand contact of cam 308 (5½ to 18). At its left-hand armature and back contact, relay 312 closes a circuit for driving sequence switch 300 out of position 100 8 and into position 18, this circuit extending from battery through the magnet winding of sequence switch 300, conductor 324, the lower left-hand contact of cam 307, conductor 325 and thence to ground through the left-hand armature and back contact of 105 relay 312. Upon reaching position 18, a circuit is closed for the downdrive magnet 338 which circuit extends from battery through the winding of magnet 338 and thence to ground through the contacts of 110 cam 306. The energization of magnet 338 presses the depending portion of shaft 317 against the constantly rotating downdrive drum 339, thereby causing the movement of the switch shaft into normal position. As 115 soon as the switch shaft reaches normal position, a circuit is closed for driving sequence switch 300 out of position 18 and into position 1, this circuit extending from grounded battery through the winding of magnet 300, conductor 324, the lower right-hand contact of cam 307, normal segment 340 of commutator 321, brush 329, conductor 323 and thence to ground at the lower left-hand contact of cam 306. As soon as switch 300 120 125 130 135

leaves position 18, the circuit of the down-drive magnet 338 is opened to arrest the downward movement of the switch shaft. The office selector and its associated circuits are now in normal position.

Upon the deenergization of relay 421 of the incoming selector switch 450, busy ground potential is connected to the sleeve conductor of the trunk 420 over the upper 10 contact of cam 407, conductor 427, the outer left-hand armature and back contact of relay 421 and thence to ground through the right-hand contacts of sequence switch cam 411 for preventing the seizure of the trunk 15 until the incoming selector switch has been completely restored to normal. At its inner left-hand armature and back contact, relay 421 closes a circuit extending through the upper left-hand contact of cam 406 for driving 20 sequence switch 400 out of position 16 and into position 18. As soon as sequence switch 400 reaches position 18, a circuit is closed through the winding of the down-drive magnet 461 extending from grounded 25 battery through the winding of magnet 461 and thence to ground through the right-hand contacts of cam 410. Magnet 461, upon energizing, presses the depending portion of the switch shaft 432 against the constantly 30 rotating downdrive drum 462 thereby restoring the switch shaft to normal position. As soon as the switch shaft reaches its normal position, a circuit is closed for driving sequence switch 400 out of position 18 and into normal position. This circuit may 35 be traced from battery through the magnet winding of switch 400, the upper right-hand contact of cam 406, normal segment 463, brush 441, conductor 437 and to ground 40 through the lower contact of cam 410. As soon as the sequence switch 400 leaves position 18, the circuit of downdrive magnet 461 is opened to arrest the downward movement of the switch shaft and busy ground potential is removed from sleeve conductor 464.

When sequence switch 400 of the incoming selector switch leaves position 16 $\frac{1}{2}$, the circuit previously traced through the contacts of cam 412, over brush 442 and terminal 451 of the incoming selector, sleeve conductor 525, the left-hand armature and front contact of relay 521, the armature and back contact of relay 524 and through the left-hand winding of relay 521, over which circuit relay 521 has been energized is opened and relay 521, upon energizing, closes a circuit for energizing relay 518. This latter circuit may be traced from battery through the left-hand winding of relay 518, the upper contacts of cam 509 and thence to ground at the armature and back contact of relay 521. Relay 518, upon energizing, closes a circuit for driving sequence switch 500 out of position 15 and into position 16. 60 This circuit may be traced from battery

through the winding of magnet 500, the lower right-hand contact of cam 512, the left-hand armature and front contact of relay 518 and thence to ground at the upper right-hand contact of relay 508. 70

When sequence switch 500 leaves position 15, the energizing circuit of relay 518 is opened, but relay 518 is maintained locked over a circuit extending from battery through the left-hand contact of cam 504, 75 the right-hand winding of relay 518, the lower contact of cam 510, the right-hand armature and front contact of relay 518, the lower left-hand and upper right-hand contacts of cam 505, brush 553, bank terminal 557, over the subscriber's line loop, bank terminal 559, brush 552, the lower right-hand contact of cam 502 and thence to ground at the upper left-hand contact of cam 503. 80 This locking circuit for relay 518 is maintained until the called subscriber restores his receiver to its switch-hook and the restoration of the final selector does not take place until the called subscriber has hung up his receiver. 85

In order to render relay 518 more sensitive for releasing upon the restoration of the called subscriber's receiver to its switch-hook, a shunt path is closed upon the winding of relay 518 from battery through resistance element 560 and the contact of cam 516 (16). When the called subscriber restores his receiver, relay 518 becomes deenergized and at its left-hand armature and back contact closes a circuit for driving sequence switch 500 out of position 16 and into position 17. This circuit may be traced from battery through the winding of sequence switch magnet 500, the upper right-hand contact of cam 512, the left-hand armature and back contact of relay 518 and thence to ground at the upper left-hand contact of cam 508. Upon reaching position 17, sequence switch 500 is driven into position 18 over a circuit extending through its magnet winding, the lower right-hand and upper left-hand contacts of cam 509 and to ground at the right-hand armature and back contact of relay 521. When sequence switch 500 reaches position 18, a circuit is closed for downdrive magnet 544 extending from battery through the winding of magnet 544, the lower right-hand contact of cam 511 (18), the upper right-hand contact of cam 507 (18) and thence to ground through the upper left-hand contact of cam 506. As soon as switch shaft 527 reaches normal position, a circuit is closed for driving sequence switch 500 out of position 18 and into normal position, this circuit extending from battery through the winding of the magnet of sequence switch 500, the upper left-hand contact of cam 512, conductor 546, normal segment 547 of commutator 531, brush 538, 110 conductor 533 and thence to ground at the

115 conductor 525. As soon as switch shaft 527 reaches normal position, a circuit is closed for driving sequence switch 500 out of position 18 and into normal position, this circuit extending from battery through the winding of the magnet of sequence switch 500, the upper left-hand contact of cam 512, conductor 546, normal segment 547 of commutator 531, brush 538, 120 conductor 533 and thence to ground at the 125 conductor 525. As soon as switch shaft 527 reaches normal position, a circuit is closed for driving sequence switch 500 out of position 18 and into normal position, this circuit extending from battery through the winding of the magnet of sequence switch 500, the upper left-hand contact of cam 512, conductor 546, normal segment 547 of commutator 531, brush 538, 130 conductor 533 and thence to ground at the

upper left-hand contact of sequence switch cam 506. The final selector and its associated circuits are now in normal position. During the restoration of the final selector 5 to normal position, the trunk extending to multiple terminals in banks of all incoming selector switches having access thereto is held busy by ground potential connected to the sleeve conductor 525 of the trunk over 10 the left-hand armature and back contact of relay 521 and the upper left-hand contact of sequence switch cam 514. All apparatus which has been employed in the establishment of the connection has now been restored to normal condition and may be employed for establishing other calls.

If the connection established to the called line had been unsuccessful, that is, the called subscriber failed to respond; then the 20 call charging relay 261 of the district selector would not have energized when sequence switch 200 of the district selector was in position 12, and consequently, no circuit for the coin collection relay 612 would have 25 been established upon the reassociation of the office sender with the district selector upon the termination of the connection by the calling subscriber. Therefore, when switch M reaches position 5, current from 30 the refunding source 660 becomes connected through the left-hand armature and front contact of relay 629, through the inner right-hand armature and back contact of relay 612 and thence as previously traced to 35 the subscriber's line. This current being of negative polarity causes the energization of polarized coin box magnet 126 in such a direction as to refund the coin.

40 *The attempted establishment of a connection outside the local area.*

In order to enable the establishment of message rates for service in large exchanges, it is necessary to divide the exchange into 45 zones and to permit subscribers in certain zones to call subscribers in other zones for the basic message rate or in the case of coin box lines upon the deposit of the satisfied token or coin and to prevent subscribers in 50 a zone at the exchange from establishing connections with subscribers in distant zones of the exchange without first bringing an operator in upon the connection to assess an extra charge. In the preceding description, it has been assumed that the calling subscriber was located in an office of the exchange in zone 1 of the exchange and caused the establishment of the connection with a subscriber's line L in the same office. 55 Accordingly, upon the setting of the register relays of translator switch no zone register relays were operated to prevent the calling subscriber from establishing the desired connection. It will now be assumed 60 that the calling subscriber K attempts to

establish a connection with the subscriber in an office located in zone 3 of the exchange and that the subscriber is not permitted to make such a connection without paying an extra charge for the service. The calling subscriber proceeds to dial the code and numerical digits of the desired number in the manner previously described and in consequence thereof, the sender functions in the manner previously described to set the translator switch TS to a position corresponding to the code of the line designation which the subscriber dialed. The translator switch assumes such a position that a pair of its brush sets engage terminals connected to brushes of the pulse machine, such that when pulses are transmitted from the pulse machine for setting the register relays, two impulses are transmitted over brush 1575 of the pulse machine and brush 1545 of the translator switch to cause the district group register relay 1312 and the zone relay 1424 to become energized and locked up. Other translator register relays for controlling the class switch, district brush, office brush and district group and talking selection are variously operated and locked up in the manner previously described.

Following the setting of the translator switch, the translator control sequence switch 700 is advanced into position 8 as previously described.

Upon the energization of the class relays, the class switch 900 is operated in the manner previously described to set the class switch into a position corresponding to the class of the call and during the setting of the class switch, relay 915 is operated as previously described, closing a circuit for 100 relays 924 and 1523 in the manner previously set forth. Upon the energization of relay 924, with zone relay 1424 energized, a circuit is established for zone relays 907 and 911 which may be traced from battery through the windings of these relays in parallel, conductors 1442 and 1441, the outer right-hand armature and front contact of relay 1424, the right-hand armature and back contact of relay 1423, conductors 1440 and 1003 and to ground at the inner right-hand armature and front contact of relay 924. Upon the energization of relay 907, a circuit is established for driving the route switch 990 into position 3 which may be traced from battery through the magnet winding of sequence switch 990, the upper left-hand contact of route switch cam 954 (4 to 2), the outer left-hand armature and back contact of relay 913 and thence to ground at the outer left-hand armature and front contact of relay 907. During the setting of the route switch, relay 917 is maintained energized in parallel with the driving magnet of the switch. Simultane- 110 115 120 125 130

ously with the setting of the route switch, the class switch 900 is reset into position 13 over a circuit extending from battery through the magnet winding of class switch 900, the upper contact of cam 955 (14 to 12) and thence to ground at the inner left-hand armature and front contact of relay 907. During the setting of the class switch, relay 915 is maintained energized in parallel with the winding of the class switch magnet.

As soon as the route and class switches have been set into positions 3 and 13 respectively, relays 917 and 915 deenergize, relay 915 opening the initial energizing circuit of relay 924, but relays 924 and 1523 being maintained energized over the previously traced locking circuit extending to ground at the lower right-hand contact of cam 727. Upon the deenergization of relay 917, a circuit is established for setting the compensating resistance switch 950 into position 6, it being assumed that in this particular office it is necessary to insert 900 ohms resistance into the fundamental circuit extending to the operator's position. The circuit for setting compensating resistance switch 950 may be traced from battery through the magnet winding of switch 950, the lower contact of cam 957, the lower right-hand and upper left-hand contacts of cam 958 and to ground at the normal contacts of the right-hand armature of relay 917. A circuit is now effective for advancing translator control sequence switch 700 out of position 8 and into position 9, which may be traced from battery through the winding of the magnet of switch 700, the upper right-hand contact of cam 722 (8), conductor 741, the left-hand armature and front contact of relay 1523, the left-hand armature and back contact of relay 917 and to ground at the armature and back contact of relay 915. As soon as the translator control sequence switch 700 reaches position 9 with the register relays energized and locked up, the sender sequence switch 800 is advanced into position 2 preparatory to controlling the brush selection movement of the district switch in the manner previously described.

With the route switch set in position 3 and the class switch in position 13, the counting relay leads which are normally connected to contacts of the translator register relays through the lower contacts of route switch cams 932, 934, 936 and 937 are disconnected from the register relays and the counting relay leads are connected directly through the upper left-hand contacts of these cams and the district brush and district group selections are controlled from the upper contacts of cam 932 and 934 in positions 2 and 4 of the sender sequence switch 800. When sequence switch 800

reaches position 6 following district group selection, the 0' counting relay 817 is maintained locked over a circuit extending through the winding of the 0 counting relay 816, counting relay 817, the armature and front contact of relay 816, the left-hand contacts of cam 870 (4 to 10), conductor 960, the lower left-hand contact of route switch cam 959 and to ground through the lower right-hand contact of route switch cam 946 (21 to 18) and the sender sequence switch 800 is therefore driven directly into position 12. It is thus seen that through the stepping of the route switch into position 3, the routing which the calling subscriber has established on the translator register relays is annulled and that the route switch directly controls the setting of the district to establish a special route to a trunk circuit extending to an operator's position on the special A board of the office. It is noted that since this trunk circuit terminates in the bank of the district selector that office selection is unnecessary and that therefore the sender sequence switch 800 is driven directly through the usual office selection positions 8 and 10.

Upon the setting of brushes of the district selector upon a group of terminals in which trunk circuits leading to the operator's position terminate, the district selector hunts in the manner previously described for an idle trunk and stops upon the terminals 281, 282 and 283 of trunk line 345 and 346 terminating in a jack J at the operator's position.

Upon the extension of the connection to the trunk circuit, the fundamental circuit is established through the stepping relay 804 and the line relay 347 of the trunk circuit which fundamental circuit may be traced from battery through the right-hand winding of relay 347, the inner right-hand armature and back contact of cut-off relay 348, trunk conductor 345, terminal 281 and brush 259 of the district selector, the upper left-hand and upper right-hand contacts of cam 220, conductor 262, the outer right-hand armature and front contact of relay 230, wiper 237, conductor 743, the armature and back contact of relay 802, the left-hand contact of cam 744 (9 to 12), the right-hand contact of cam 834, the left-hand winding of overflow relay 823, the windings of sender stepping relay 804, the armature and back contact of relay 805, the right-hand winding of relay 823, the winding of relay 839, the lower contacts of cam 824, the upper contact of cam 745, conductor 840, the upper contact of cam 929 (6), resistance element 961, it having been assumed that compensating resistance switch 950 was set into position 6 by the operation of the route switch into position 3, conductor 962, the lower left-hand

contact of cam 841, conductor 842, the right-hand contact of cam 749 (9 to 12), the left-hand armature and back contact of advance relay 750, conductor 751, wiper 263, the left-hand armature and front contact of relay 244, conductor 264, the lower right-hand and upper left-hand contacts of cam 219, brush 258 and bank terminal 282 of the district selector switch, trunk conductor 346, the left-hand armature and back contact of relay 348 and thence to ground through the left-hand winding of relay 347. Relay 839 energies in this circuit and at its armature and front contact closes a circuit for relay 845, which in turn, closes a circuit extending through the magnet winding of sequence switch 800 and the upper left-hand contact of cam 820 (12) for advancing sequence switch 800 into position 14. With sequence switch 800 in position 14, a circuit is established for relay 853 and advance relays 708 and 750 which may be traced from battery through the windings of relays 708 and 750 in parallel, conductor 759, the upper contacts of class switch cam 956 (13 to 14), conductor 852 and to ground at the left-hand contacts of cam 851 (14) and from battery through the winding of relay 853 to conductor 852 and to ground at the left-hand contacts of cam 851. Upon the energization of relays 708 and 750, the previously traced fundamental circuit is opened and the sequence switch of the district selector is advanced out of position 10 and into position 11 in the manner previously described.

Talking selection is controlled in the manner hereinbefore described except that the lead 828 is connected to lead 963 Fig. 9 and to ground through the outer left-hand armature and front contact of zone relay 911 instead of through the contacts of talking selection register relays 1410 and 1326 as previously described in connection with a permissible connection. The circuit of the No. 2 counting relay 826 may be traced from battery through the winding of the relay, the armature and back contact of the No. 2' counting relay 827, lead 828, lead 963 Fig. 9, the outer left-hand armature and front contact of relay 911, conductor 941, the upper contact of cam 859 (14), conductor 830, the right-hand contact of cam 746 (9 to 12), conductor 811, the normally closed contacts associated with the inner left-hand armature of relay 812, the upper right-hand and lower left-hand contacts of cam 818 (14), the armature and front contact of relay 804 and thence to ground at the upper right-hand contact of cam 819.

Following talking selection, the No. 0' counting relay 817 energizes and in the manner previously described advances the sender sequence switch 800 into position 16. The sequence switch of the district selector is now in position 14 and a circuit is estab-

lished from battery through the right-hand winding of relay 347, the inner right-hand armature and back contact of relay 348, conductor 345, bank terminal 281 and brush 259 of the district selector, the left-hand contacts of cam 220, the upper right-hand winding of repeating coil 265, the upper left-hand and lower right-hand contacts of cam 266, the upper contact of cam 222, the lower right-hand winding of repeating coil 265, the upper contacts of cam 219, brush 258 and terminal 282 of the district selector, conductor 346, the left-hand armature and back contact of relay 347 and to ground through the left-hand winding of relay 347. Relay 347 energizes in this circuit, but current does not flow through the winding of relay 266 in such a direction as to attract its armature against its lower contact. Relay 347, upon energizing, establishes a circuit for the trunk lamp 349 and a circuit for the slow-to-release relay 390.

When the sequence switch 200 of the district selector leaves position 10½, relays 1100 and 1102 deenergize and the register steering switch is advanced into its normal position. Following the talking selection, relay 228 of the district selector switch de-energizes and opens the holding circuit of relays 230 and 244 as previously described and relay 230, upon its deenergization, opens the holding circuit of relay 706. Relay 706, upon deenergizing, causes the restoration of the time measure switch TM and the restoration of the monitor's time measure switch M in the manner previously described.

When the switch TM reaches its normal position, a circuit is closed for advancing switch 700 into position 18 which may be traced from battery through the magnet winding of switch 700, the lower left-hand contact of cam 722 (2 to 17) and thence to ground through the normal contact and wiper 719 of switch TM. In passing from position 9 into position 18, the locking circuits of the translator register relays are opened in the manner previously described and upon the deenergization of zone relay 1424, the energizing circuit of relays 907 and 911 is opened. Relay 911, upon energizing, closes a circuit for restoring route switch 990 into normal position which may be traced from battery through the magnet winding of switch 990, the upper right-hand contact of cam 954 (2 to 18), the outer right-hand armature and back contact of relay 911, conductor 964 and thence to ground at the upper left-hand contact of cam 742 (12 to 1).

With route switch 990 in normal position, a circuit is established for advancing the sender sequence switch 800 into position 17 which may be traced from battery through the winding of the magnet of switch 800, the lower right-hand contact of cam 820

(2 to 16), conductor 875, the contact of cam 965, conductor 986 and thence to ground at the lower right-hand contact of cam 742

(15 to 1). When sequence switch 800 reaches position 17, a circuit as previously traced is established for sender stepping relay 804, which upon energizing, closes a circuit for advancing sequence switch 800 into position 18. With sequence switch 800 in position 18, the circuit just traced extending through route switch cam 965 is again established for advancing the sender sequence switch into position 1. The office sender is now in normal condition and the connection has been rerouted from the calling subscriber's line to the jack J at the operator's position.

In response to the illumination of lamp 349, the operator at position 0 inserts the plug P of a cord circuit in the jack J, whereupon cut-off relay 348 becomes energized over the sleeve of the plug and jack for disconnecting the line relay 347 from the trunk conductors to extinguish the lamp 349.

25 The slow-to-release relay 390 is maintained energized over the outer right-hand armature and front contact of relay 348 and at its armature and front contact maintains ground potential upon the multiples of test 30 terminal 283 of the trunk to mark the trunk busy to other district selectors. Upon the insertion of plug P in the jack J, battery is connected across the trunk conductors 345 and 346 from the operator's cord circuit and 35 current now flows in such a direction through the winding of polarized relay 266 to cause it to close its lower armature contact. A circuit is now established for line relay 228 extending from battery through 40 the right-hand winding of relay 228, the upper contacts of cam 217, the armature and lower contact of relay 266 and thence to ground at the upper right-hand contact of cam 209 (12 to 14½). Relay 228, upon energizing, closes a circuit for advancing sequence switch 200 out of position 14 and into talking position 15 which may be traced from battery through the winding of sequence switch magnet 200, the lower right-hand contact of cam 206, the inner right-hand armature and front contact of relay 228 and thence to ground at the right-hand contact of cam 207.

With sequence switch 200 in position 15, 55 a full metallic talking circuit over the upper contact of cam 212 and the lower contact of cam 213 is established between the calling line and the operator's position 0, talking current being supplied to the calling subscriber's line from the operator's cord circuit.

From this point, the operator controls the further extension of the connection to the line of the desired subscriber in any well-known manner and supervises the deposit

and collection of the required service charge through the operation of apparatus at her position in the usual manner.

At the time relay 228 of the district selector energized upon the response of polarized relay 266, relay 228 closed a locking circuit for itself extending through its left-hand winding, left-hand armature and front contact, the upper contacts of cam 216, overflow segment 279, brush 251, test brush 252 and bank terminal 283, sleeve conductor 351 and thence to ground at the armature and front contact of relay 390. Upon the termination of the conversation, the calling subscriber restores his receiver to its switchhook and thereby causes the illumination of the usual supervisory lamp in the operator's cord circuit O. The operator noting the illumination of this lamp removes the plug P from the jack J, whereupon the relay 348 deenergizes and opens the circuit of relay 390. Relay 390, upon deenergizing, opens the locking circuit of relay 228 which deenergizes.

Upon the deenergization of relay 228, a circuit is closed for driving sequence switch 200 out of position 15 and into position 16, this circuit extending from battery through the magnet of sequence switch 200, the upper left-hand contact of cam 206, the inner right-hand armature and back contact of relay 228 and thence to ground through the right-hand contact of cam 207. Since supervisory relay 234 deenergized when the calling subscriber restored his receiver to its switchhook and opened the circuit of relay 227, then when sequence switch 200 reaches position 16, a circuit is established for relay 228 which may be traced from battery through the right-hand winding of this relay, the upper contacts of cam 204, the right-hand armature and front contact of sleeve relay 226 which relay is now maintained energized over the lower left-hand contact of cam 203 (12 to 16½), the upper right-hand and lower left-hand contacts of cam 223 and thence to ground at the normal contacts of the right-hand armature of relay 227. Relay 228, upon energizing, closes the previously traced circuit for advancing sequence switch 200 into position 17.

When the sequence switch leaves position 16½, the holding circuit of relay 226 is opened at the lower left-hand contact of cam 203, but the sleeve relay is still maintained energized through the normal contacts of the left-hand armature of relay 227 and the lower right-hand contact of cam 203 (16½ to 17). As soon as sequence switch 200 leaves position 16 the previously traced energizing circuit of relay 228 is opened at the upper right-hand contact of cam 223 (16) and relay 228 thereupon deenergizes. From this point the district selector is restored to normal position in the manner pre-

viously described and in restoring, causes the restoration of the subscriber's line switch 100.

5 *Connection to a manual office equipped with a relay call indicator and having access to less than ten thousand lines.*

If the calling subscriber desires to establish a connection with a subscriber's line 10 terminating in a manual office, he will dial the number of the desired line and cause the code registers and the numerical registers of the office sender to be set in the manner previously described in connection with a mechanical call, and registration, translation and district brush and group and office brush and group selections will take place as previously described except that the class 15 switch 900 is now set in position 6 instead of position 4.

As soon as the translator switch TS has completed its operation, a circuit is established for relay 1004 of the relay call indicator impulser, Fig. 10, which may be traced 20 from battery through the winding of relay 1004, conductor 1005, the upper contact of cam 968 (6 to 7), the outer left-hand armature and back contact of relay 853 and thence to ground through the upper right-hand contact of cam 765 (9). Relay 1004, upon energizing, closes a locking circuit for itself extending through its winding, inner left-hand armature and front contact, the lower contact of cam 1006 (1 to 8), conductor 1038, and thence to ground at the lower left-hand contact of cam 756 (9 to 10 1/2).

When the sender sequence switch 800 reaches position 12 following the group selection 25 movement of the office selector and at which time the office selector is hunting for an idle trunk to the selected manual office, a fundamental circuit is established as soon as an idle trunk extending to the 30 manual office is found which may be traced in part from office brush 334, the contact of cam 310 (8), conductor 313, terminal 257 and brush 259 of the district selector, the upper left-hand and lower right-hand contacts of cam 220, conductor 262, the outer right-hand armature and front contact of relay 230, wiper 237, conductor 743, the outer armature and back contact of relay 802, the left-hand contact of cam 744 (9 to 12), 35 the right-hand contact of cam 834, the left-hand winding of relay 823, the windings of sender stepping relay 804, the armature and back contact of relay 805, the contact of class switch cam 967 (6 to 9), the lower contacts of cam 774 (12 to 4), the winding of relay 839, the lower contacts of cam 824, conductor 840, the lower right-hand contact of cam 929 (4), it being assumed that the 40 compensating resistance switch 950 had been 45 set in position 4, resistance element 931, con-

ductor 962, the left-hand contact of cam 841 (12 to 18), conductor 842, the right-hand contact of cam 749 (9 to 12), the left-hand armature and back contact of relay 750, conductor 751, wiper 263, the left-hand armature and front contact of relay 244, conductor 264, the lower right-hand and upper left-hand contacts of cam 219, brush 258 and terminal 256 of the district selector, conductor 314, contact of cam 311 (8) and thence to brush 335 of the office selector. The fundamental circuit is completed over the trunk extending to the manual office and through the line relay of such trunk in the usual manner. The manual trunk terminating in the manual office may be of the type shown and described in the application of A. E. Lundell and E. H. Clark, Serial No. 387,531, filed June 9, 1920. Since, however, this invention does not involve the circuits at the manual office, it is believed that it is not necessary to encumber this application with a full disclosure and description of such circuits.

Relay 839 and the line relay at the manual office energize over the circuit previously traced, the line relay at the distant office operating the usual trunk signal and relay 839 closing the circuit for relay 845, which in turn, closes the previously traced circuit for advancing the sender sequence switch 800 into position 14.

As soon as sequence switch 800 reaches position 14, a circuit is established for relay 853 which may be traced from battery through the winding of this relay, conductor 852 and to ground through the left-hand contacts of cam 851 (14). As soon as the operator at the manual office presses the assignment key of the trunk to associate the selected trunk circuit with her call indicator, the fundamental circuit is temporarily opened at the manual office and relay 839 thereupon deenergizes, opening the circuit of relay 845. With relay 845 deenergized and relay 853 energized, a circuit is now established for relay 1500 which may be traced from battery through the left-hand winding of relay 1500, conductor 1501, the left-hand contact of cam 720 (9), the outer right-hand armature and front contact of relay 853, the lower contacts of class switch cam 956 (6 to 7), the outer left-hand armature and back contact of relay 812 and thence to ground at the outer left-hand armature and back contact of relay 845.

Since relay 1004 has at this time energized, a circuit is now effective for advancing the relay call indicator impulser 1000 out of position 1 and through a complete revolution. This circuit may be traced from battery through the winding of the driving magnet of switch 1000, the upper left-hand contact of cam 1007 (1 to 8), the outer

right-hand armature and front contact of relay 1004, conductor 1009, the right-hand armature and front contact of relay 1500, conductor 1578 and thence to ground at the 5 upper right-hand contact of cam 730 (9 to 12). The tip conductor 743 of the fundamental circuit is now extended through the outer armature and back contact of relay 802, the left-hand contact of cam 744 (9 to 10 12), the left-hand contact of cam 834 (13 to 14), the outer right-hand armature and back contact of advance relay 750, the outer 15 left-hand armature and back contact of relay 876, the outer right-hand armature and back contact of relay 845, the intermediate right-hand armature and front contact of relay 853, the upper left-hand and lower right-hand contacts of class switch cam 972, conductor 1011, the outer left-hand 20 armature and front contact of relay 1004 and thence to the tip conductor 1012 of the impulser circuit Fig. 10.

The ring conductor 751 of the fundamental circuit is extended through the left-hand armature and back contact of relay 750, the right-hand contact of cam 749 (9 to 12), conductor 842, the left-hand contact of cam 841 (12 to 18), conductor 962, resistance element 931, the lower contact of 30 cam 929 (4), conductor 840, the inner right-hand armature and back contact of relay 845, the inner left-hand armature and front contact of relay 853, the upper contacts of class switch cam 953 (6 to 9), conductor 35 1010, the inner right-hand armature and front contact of relay 1004 and to the ring conductor 1015 of the impulser circuit. As soon as impulser 1000 leaves position 8, the locking circuit of relay 1004 is opened and 40 relay 1004 deenergizes, but the tip and ring conductors 1012 and 1015 are maintained connected to the fundamental circuit over the upper right-hand and lower left-hand contacts of cam 1013 (2 to 20 $\frac{1}{4}$) and the 45 upper left-hand contact of cam 1014 (2 to 20 $\frac{1}{4}$) respectively. It will be assumed that the calling subscriber has set the stations thousands, hundreds, tens and units registers to register the line designation 2345 50 R and that the brushes of the respective registers have been set on terminals 2, 3, 4, 5, and 7. As the impulser switch 1000 rotates from position 1 to 4 $\frac{1}{4}$, a code of impulses is transmitted over the fundamental 55 circuit under the control of the stations register ST for setting the register relays of the relay call indicator at the manual office for registering the party line designation R. The first impulse of the 60 code is transmitted as the switch rotates from position 1 to 1 $\frac{1}{4}$ by the connection of the ring conductor 1015 to ground or positive pole of the battery over a circuit which may be traced from conductor 1015, through 65 the upper left-hand contact of cam 1031

(20 $\frac{3}{4}$ to 1 $\frac{1}{4}$), the fundamental circuit being completed by the connection of the tip conductor 1012 to the negative pole of the battery over the upper contact of cam 1025 (20 $\frac{3}{4}$ to 1 $\frac{1}{4}$), No. 3 lead 1219, No. 3 lead 70 1219 Fig. 12, bank terminal 1239 and wiper 1220 of stations register ST, conductor 1221 and 1016, the lower contact of cam 1017 (20 $\frac{3}{4}$ to 4 $\frac{1}{4}$), conductor 1018 and the normally closed armature contacts of relay 1019, 75 conductor 1020 and to battery through the high resistance element 1053. The impulse thus transmitted is of weak positive polarity. During the rotation of switch 1000 through positions 1 $\frac{3}{4}$ to 2 $\frac{1}{4}$, ring conductor 1015 80 is connected to the negative pole of battery over the contact of cam 1022, conductor 1020, the armature contacts of relay 1019, conductor 1018, the lower contact of cam 1017, thence over the circuit previously traced to the No. 3 lead 1219, the lower contact of cam 1023 (1 $\frac{3}{4}$ to 2 $\frac{1}{4}$) and to the negative pole of battery through the low resistance element 1024, the fundamental circuit being completed back over the tip conductor 1012 85 to ground at the upper right-hand contact of cam 1021. High resistance element 1053 is shunted at this time by the low resistance element 1024 and thus a strong negative impulse is transmitted over the fundamental 90 circuit. As the switch 1000 rotates through positions 2 $\frac{3}{4}$ to 3 $\frac{1}{4}$, ring conductor 1015 is connected to ground at the left-hand contact of cam 1021 (2 $\frac{3}{4}$ to 3 $\frac{1}{4}$), but the tip conductor is open and no circuit is effective. As the switch rotates to positions 3 $\frac{1}{4}$ to 4 $\frac{1}{4}$, ring conductor 1015 is connected 95 through the contact of cam 1022 to the negative pole of battery through resistance element 1053 and since no shunt exists around resistance element 1053 at this time and since the tip conductor 1012 is connected to ground at the right-hand contact of cam 1021, a weak impulse of negative current is transmitted over the fundamental circuit. 100 Thus, during the rotation of switch 1000 from position 1 to position 4 $\frac{1}{4}$, a code comprising a positive, a strong negative, no current and a weak negative impulse is sent over the fundamental circuit and causes the 105 relay call indicator to prepare a circuit for the R stations lamp in the well-known manner. During the rotation of switch 1000 from positions 4 $\frac{3}{4}$ to 8 $\frac{1}{4}$, the relay call indicator at the manual office is controlled in 110 accordance with the setting of the thousands register TH of the office sender. During the rotation of the switch from positions 4 $\frac{3}{4}$ to 5 $\frac{1}{4}$, the ring conductor 1015 is connected to the ground through the left-hand contact of cam 1021 and the fundamental circuit is completed to the negative pole of battery over the tip conductor 1012, the upper contact of cam 1031 (4 $\frac{3}{4}$ to 5 $\frac{1}{4}$), the 115 No. 1 lead, lead 1222, lead 1238 Fig. 12, con- 120

65 125 130

ductor 1169, brush 1168 and terminal 1167 of thousands register TH, conductor 1223, the upper contact of class switch cam 970, conductor 1025, cam 1026 (4 $\frac{3}{4}$ to 8 $\frac{1}{4}$), conductor 1018, the normally closed armature contacts of relay 1019, conductor 1020 and to the negative pole of battery through high resistance element 1053. During the rotation of switch 1000 from positions 5 $\frac{3}{4}$ to 10 6 $\frac{1}{4}$, ring conductor 1015 is connected to negative pole of battery over the contact of cam 1022, through resistance element 1053 and the tip conductor 1012 is connected to ground over the right-hand contact of cam 1021. From positions 6 $\frac{3}{4}$ to 15 7 $\frac{1}{4}$, ring conductor 1015 is connected to ground at the left-hand contact of cam 1021, but tip conductor 1012 is open and no effective fundamental circuit is closed. During the rotation of switch 1000 from positions 7 $\frac{3}{4}$ to 20 8 $\frac{1}{4}$, ring conductor 1015 is connected to the negative pole of battery over the contact of cam 1022, to the negative pole of battery through the high resistance 1053 and a weak impulse of negative current is transmitted over the fundamental circuit. Thus, during the rotation of switch 1000 from position 4 $\frac{3}{4}$ through position 8 $\frac{1}{4}$, a code of impulses comprising a positive, a weak negative, no impulse and a weak negative impulse is transmitted to the relay call indicator office for preparing a circuit for the No. 2 thousands lamp of the indicator.

As the switch 1000 rotates from position 35 8 $\frac{3}{4}$ to position 12 $\frac{1}{4}$, the impulse switch transmits code impulses under the control of the hundreds register H. In rotating from position 8 $\frac{3}{4}$ to 9 $\frac{1}{4}$, ground is connected to the ring conductor 1015 of the fundamental circuit through the left-hand contact of cam 1021 and the fundamental circuit is completed over tip conductor 1012, the upper contact of cam 1025 (8 $\frac{3}{4}$ to 9 $\frac{1}{4}$), the No. 3 lead 1219, lead 1219 Fig. 12, conductor 1224, terminal 1170 and wiper 1171 of the hundreds register H, conductor 1225, the upper contact of class switch cam 973 (6), conductor 1028, contact of cam 1029, conductor 1018, the normally closed armature contacts 40 of relay 1019, conductor 1020 and to the negative pole of battery through the high resistance element 1053. As switch 1000 rotates from position 9 $\frac{3}{4}$ through position 50 10 $\frac{1}{4}$, ring conductor 1015 is connected to the negative pole of battery over the contact of cam 1022, the outer right hand armature and contact of relay 1019, thence as traced to lead 1219, Fig. 10, the lower contact of cam 1023 (9 $\frac{3}{4}$ to 10 $\frac{1}{4}$), low resistance element 1024, and the fundamental circuit is completed over tip conductor 1012 to ground through the right-hand contact of cam 1021. During the advance of switch 1000 from position 55 10 $\frac{3}{4}$ through position 11 $\frac{1}{4}$, ring conductor 1015 is connected to ground through

the left-hand contact of cam 1021, but the tip conductor 1012 being opened at this time, no effective circuit is established. During the advance of switch 1000 from position 11 $\frac{3}{4}$ through position 12 $\frac{1}{4}$, ring conductor 1015 is connected to the negative pole of battery through cam 1022 and the high resistance element 1053. Thus, during the advance of switch 1000 from position 8 $\frac{3}{4}$ through position 12 $\frac{1}{4}$, a code comprising a positive, a heavy negative, no impulse and a weak negative impulse is transmitted over the fundamental circuit for preparing a circuit for the No. 3 hundreds lamp of the indicator.

As switch 1000 advances through positions 12 $\frac{1}{4}$ to 16 $\frac{1}{4}$, code impulses are transmitted under the control of the tens register T. Ring conductor 1015 of the fundamental circuit is connected to ground during the advance of switch 1000 from positions 12 $\frac{1}{4}$ to 13 $\frac{1}{4}$, but the tip conductor 1012 being opened at this time, no effective circuit is established. As switch 1000 advances from positions 13 $\frac{3}{4}$ through 14 $\frac{1}{4}$, conductor 1015 is connected to the negative pole of battery over the contact of cam 1022 and through the high resistance element 1053 and the tip conductor 1012 is connected to ground through the right-hand contact of cam 1021. From positions 14 $\frac{3}{4}$ to 15 $\frac{1}{4}$ the ring conductor 1015 is connected to ground over the left-hand contact of cam 1021 and the tip conductor 1012 is connected to negative battery over the lower contact of cam 1031, lead 1228, lead 1228 Fig. 12, terminal 1226 and wiper 1227 of the tens register T, conductor 1229, the upper contact of class switch cam 971 (6), conductor 1030, the upper contact of cam 1026 (12 $\frac{3}{4}$ to 16 $\frac{1}{4}$), conductor 1018, the normally closed contacts of relay 1019, conductor 1020 and thence to the negative pole of battery through resistance element 1053. As switch 1000 rotates from positions 15 $\frac{3}{4}$ to 16 $\frac{1}{4}$, the ring conductor 1015 is connected to the negative pole of battery over the contact of cam 1022 and through resistance element 1053 and the tip conductor 1012 is connected to ground through the right-hand contact of cam 1021. Thus, during the rotation of switch 1000 from positions 12 $\frac{3}{4}$ through 16 $\frac{1}{4}$, a code of impulses comprising no impulse, a negative, a positive and a negative impulse is transmitted over the fundamental circuit for preparing a circuit at the relay call indicator for the No. 4 tens lamp.

As the switch 1000 rotates from positions 16 $\frac{3}{4}$ to 20 $\frac{1}{4}$, a code of impulses is transmitted over the fundamental circuit under the control of the units register U. From position 16 $\frac{3}{4}$ to position 17 $\frac{1}{4}$, the conductor 1012 of the fundamental circuit is open and no effective circuit is established. During the rotation of switch 1000 from positions 17 $\frac{3}{4}$ to 20 $\frac{1}{4}$, the ring conductor 1015 is connected to ground through

through 18₄, the ring conductor 1015 is connected to the negative pole of battery over the contact of cam 1022 and through resistance element 1053 and the fundamental circuit is completed over tip conductor 1012 to ground through the right-hand contact of cam 1021. From positions 18₄ through 19₄, the tip conductor 1012 is open and no effective circuit is established. During the advance of the switch through positions 19₄ to 20₄, the ring conductor 1015 is connected to the negative pole of battery over the upper contact of cam 1022, conductor 1020, the normally closed armature contacts of relay 1019, conductor 1018, the upper contact of cam 1017 (16₄ to 20₄), conductor 1032, the upper contact of class switch cam 972 (6), conductor 1329, wiper 1230 and terminal 1231 of the units register U, lead 1232 Fig. 12, lead 1232 Fig. 10, the lower contact of cam 1033 and thence to the negative pole of battery through low resistance element 1024. As resistance element 1024 is in shunt of high resistance element 1053, the last negative impulse over the fundamental circuit is a strong impulse. Thus, during the advancement of switch 1000 from positions 16₄ to 20₄, a code of impulses comprising no impulse, a negative impulse, no impulse and a strong negative impulse is transmitted over the fundamental circuit for preparing the circuit of the No. 5 units lamp of the relay call indicator.

Following the preparation of the circuit for the units lamp of the indicator, the prepared lamp circuits are rendered effective in the well-known manner and the designation of line 2345 R is indicated on the lamps before the operator.

When the switch 1000 reaches position 1, its initial driving circuit being open at the outer right-hand armature and front contact of relay 1004, it comes to rest and closes a circuit for advancing the translator control switch 700 from position 9 into position 12. This circuit may be traced from battery through the magnet winding of switch 700, the lower left-hand contact of cam 728, conductor 775, the upper left-hand and lower right-hand contacts of cam 1013 (1), the outer right-hand armature and back contact of relay 1004, conductor 1009, the right-hand armature and front contact of relay 1500, conductor 1578 and thence to ground at the upper right-hand contact of cam 730 (9 to 12).

With the translator control sequence switch 700 in position 12, a circuit is now established through the windings of advance relays 708 and 750 in parallel, over conductor 759, the upper right-hand and lower left-hand contacts of class switch cam 974 and thence to ground at the lower left-hand contact of cam 731 (12). In the manner pre-

viously described, relays 708 and 750 cause the advance of the sequence switch 200 of the district selector out of position 10 and into position 11 and cause the establishment of a fundamental circuit as previously described extending from relay 228 of the district selector, through the windings of the sender stepping relay 804. Talking selection is now controlled in substantially the same manner as described in connection with a call routed to the operator, except that the counting relays are under the control of the talking selection register relays 1326 and 1410 in the manner described in connection with the establishment of a full mechanical connection. Since the call is extended to a manual office, the code dialed by the calling subscriber would in this instance cause the energization of talking selection relay 1326 for establishing a control path for the No. 2 counting relay to set the sequence switch 200 of the district selector into position 14. Following talking selection, the sender is disassociated from the district selector and restores in the manner previously described.

The operator at the manual office, upon noting the illumination of the relay call indicator lamps, extends the connection to the line designated. Since this invention involves only the functioning of the office sender, a further description of the functioning of the district selector upon the response of the called subscriber and the release of the established connection is thought to be unnecessary herein.

Connection to a manual office through a tandem office provided with a relay call indicator.

A subscriber desiring a connection with a district manual office which may be reached only through a tandem office, dials the number of the desired line in the manner previously described and causes the circuits of the sender to function in the described manner except that for this class of calls, the class switch 900 is set into position 17. With class switch 900 in position 17, a circuit is established for tandems relay 1019 as soon as the translator control sequence switch 700 reaches position 9, which may be traced from battery through the winding of relay 1019, conductor 1034, the lower left-hand contact of class switch 968 (17 to 18), the outer left-hand armature and back contact of relay 853 and thence to ground through the upper right-hand contact of cam 765 (9). Relay 1019, upon energizing, closes a locking circuit for itself extending through its winding and its inner left-hand armature and contact, the upper contact of cam 1006 (8 to 1), conductor 1038 and thence to ground at the lower left-hand contact of cam 756 (9 to 10½). At this

time a circuit is also closed for driving the relay call indicator switch 1000 out of position 1 into position 8, this circuit extending through the magnet winding of switch 1000, 5 the lower contact of cam 1007 (1), the right-hand contact of class switch cam 968 (17 to 18) and thence to ground at cam 765 as previously traced. Relay 1019 also closes a circuit for relay 1004 extending from battery through the winding of relay 1004, 10 conductor 1005 and thence to ground at the outer left-hand armature and front contact of relay 1019 and relay 1004 locks over a circuit extending through its inner left-hand armature and front contact, the lower contact of cam 1006 (1 to 8) and to ground at cam 1038, thus insuring that the tip and ring conductors 1012 and 1015 of the impulsive circuit shall be connected to the tip and 15 ring conductors of the fundamental circuit respectively until after the switch 1000 has passed position 8 in its second revolution.

During the movement of the impulser switch 1000 through the last half of its first 20 revolution, relay 1019 being at the time energized, a code of impulses is transmitted over the fundamental circuit under the control of wiper 1171 of code register A, conductor 1172, cam 1035 and conductor 1036, a code 25 of impulses under the control of wiper 1173 of code register B, conductor 1174 and cam 1035 and a code of impulses under the control of wiper 1175 of register C, conductor 1176 and cam 1037. During the second revolution of switch 1000, codes of impulses 30 under the control of the numerical registers ST, SH, H, T and U are transmitted in the manner previously described. Following the transmission of the codes of impulses, the circuits of the office sender function as in the case of a direct call to a 35 manual office. Thus, for calls to a manual office through a tandem office not only the number of the desired line in a distant manual office is transmitted to the relay call indicator of the tandem position, but also the office designation of the terminating office in which the desired line terminates.

50 *Connection to a manual office in which more than ten thousand lines terminate.*

If a call is made to a manual office having more than ten thousand lines, the office code dialed by the calling subscriber causes the 55 class switch to be set in position 6 and the thousands register TH is employed to register the ten thousands digit of the desired line, the hundreds register H the thousands digit, the tens register T the hundreds digit, the units U the tens digit and the station 60 registers ST the units digit. The thousands register is therefore positioned on the No. 1 terminal and the hundreds register on the No. 0 terminal. As soon as the calling

subscriber dials the fifth numerical or stations digit, a circuit is established for the stations relay 1233 which may be traced from battery through the winding of stepping magnet 711 of switch TM, wiper 715, conductor 773, the left-hand winding of relay 1233, conductor 1234, the outer right-hand armature and back contact of sender delay register relay 1438, conductor 1445, wiper 1235 and the strapped terminals of the bank with which it is associated of stations register ST, conductor 1236, wiper 1177 and the No. 0 terminal 1178 of hundreds register H and thence to ground through the No. 1 terminal 1179 and wiper 1180 of the thousands register TH. Relay 1233 locks to ground on conductor 1234 through its right-hand winding and inner right-hand armature and front contact and at its outer right-hand armature and front contact closes a circuit extending from battery through the magnet winding of class switch 900, the lower left-hand contact of cam 955 (6) and to ground at the outer right-hand armature and front contact of relay 1233 for advancing class switch 900 into position 7.

The relay call indicator impulser switch 1000 is operated in the manner previously described for a direct connection to a manual office, except that when it passes from positions 20 $\frac{1}{4}$ to 1 $\frac{1}{4}$, a code of impulses is transmitted over the fundamental circuit under the control of thousands register TH, a circuit being established over the No. 1 lead 1238 for this purpose extending over the left-hand armature and front contact of stations relay 1233, conductor 1237, terminal 1181 and wiper 1168 of thousands register TH, conductor 1223, the lower contact of class switch cam 969 (7), conductor 1016 and through the upper contact of cam 1017 (20 $\frac{1}{4}$ to 4 $\frac{1}{4}$). As switch 1000 passes through positions 4 $\frac{1}{4}$ to 8 $\frac{1}{4}$, the register H exercises no control over the impulser since the hundreds register H was set in position No. 0 and therefore the code of impulses transmitted by the switch 1000 is unaltered and causes the relay call indicator to register the thousands digit 0. As switch 1000 passes through positions 8 $\frac{3}{4}$ to 12 $\frac{1}{4}$ and 12 $\frac{3}{4}$ to 16 $\frac{1}{4}$, codes of impulses are transmitted under the control of registers T and U, the control circuits extending in this instance through the lower contacts of class switch cams 970 and 971 and in position 16 $\frac{3}{4}$ to 20 $\frac{1}{4}$ the switch 1000 transmits a code of impulses under the control of stations register ST, the control circuit extending over the lower contact of class switch cam 972 and wiper 1238 of stations register ST. It is to be noted that by the movement of class switch 900 from position 6 to 7, switch 1000 first transmits a code of impulses over the

- fundamental circuit under the control of the thousands register which operates the stations lamps of the relay call indicator to register the ten thousands digit 1 and that the switch is controlled thereafter by the hundreds, tens, units and stations registers in succession. It is, of course, obvious that in mechanical offices having access to offices of this type, no party line numbers between 10 the 1000 and 1099 may be employed as the registers TH and H when set to positions 1 and 0 respectively indicate that a connection is being extended to an office having more than ten thousand lines.
- 15 If the manual office is to be reached through a manual tandem office or a mechanical tandem office, the class switch which is set in positions 15 and 17 for such class is advanced in the manner just described to 20 positions 16 and 18 respectively for the purpose of causing the impulsing switch 1000 to transmit the codes in succession under the control of the thousands, hundreds, tens, units and stations registers for registering 25 numbers over 10,000.

Connections to automatic branch exchanges reached through the terminal banks of final selectors.

- 30 For calls to automatic branch exchanges, the calling subscriber in addition to dialing three code-impulse series and four numerical impulse series also dials three additional sets of impulses for selecting a subscriber's 35 extension line in the branch exchange and the connection proceeds in the manner previously described for a full mechanical connection, except that the class switch is set into position 12 instead of position 4 and 40 that the additional three sets of numerical impulses are registered on the registers ST, ST', and ST². When the sender sequence switch 800 advances during its second revolution to position 8 following the control of 45 units selection at the final selector switch, the circuit previously traced over class switch cam 940 (4) for locking counting relay 817 energized through positions 6 to 12 is not effective and sequence switch 800 50 stops in position 8. In positions 8, 10 and 12 the sender is controlled by registers ST, ST' and ST² over the contacts of cam 874 for governing the setting of switches in the 55 branch exchange. Following the setting of switches in the branch exchange, the incoming selector 450 is advanced as previously described to position 9 and from that point the sender functions as previously described. Since the contacts of cams 942 and 60 944 of the class switch are opened in position 12 on this class of calls when the time measure switch TM reaches position 11, the register steering switch RS does not advance rapidly as previously described to position 65 10, but advances step-by-step to place the

registers ST, ST' and ST² successively under the control of the impulsing circuit extending to the calling line.

Sender synchronization.

In order to prevent the office sender from functioning faster than is warranted by the speed at which the subscriber sets the sender registers, a synchronizing relay 802 is provided which at different stages in the progress of the connection functions to arrest such progress until after the subscriber has dialed certain digits. This relay functions at the following stages during the establishment of a connection:

1. If the calling subscriber has not finished dialing the third code impulse for setting register C by the time the translator control sequence switch 700 reaches position 5 preparatory to controlling the terminal selection movement of translator switch TS, relay 802 energizes in parallel with relay 1117 over a circuit extending through the intermediate winding of relay 802, conductor 877, the upper left-hand and lower right-hand contacts of cam 776 (4 to 5), conductor 1118, the inner left-hand armature and back contact of zone relay 911, conductor 912, terminal 1119 and wiper 1103 of steering switch RS and thence to ground at the right-hand armature and front contact of relay 1102. Relay 802, upon energizing, opens the circuit of relay 1500 at its inner armature and front contact and holds this circuit open to prevent further operation of the translator switch TS until the subscriber dials the third code digit and advances switch RS into position 3.

2. When the sender sequence switch 800 reaches position 6 and a test is made of the selected office trunk, if the compensating resistance switch 950 has not completed its setting to prepare the fundamental circuit for selection beyond the originating office, relay 802 operates to open the fundamental circuit at its outer armature and back contact. The circuit of relay 802 may be traced through its intermediate winding, the upper right-hand contact of cam 878 (5 to 6), conductor 879 and thence to ground at the armature and front of relay 952 which relay remains energized in parallel with magnet 950 during the setting of the compensating resistance switch.

3. On calls to manual offices equipped with relay call indicators when the sender sequence switch reaches position 11, if all digits have not been dialed, the fundamental circuit is opened by relay 802 so that the fundamental circuit is ineffective when sequence switch 800 reaches position 12. The circuit of relay 802 may be traced from battery through its intermediate winding, the left-hand contact of cam 878 (11 to 12), conductor 882, the upper contacts of cam 975

(6 to 9 and 14 to 18), conductors 976 and 777, the No. 6 terminal and wiper 1103 of switch RS and thence to ground at the right-hand armature and front contact of relay 1102. If the coin has not been deposited when switch RS reaches terminal position No. 5, relay 802 is also held energized over the circuit traced to the upper contacts of cam 975, thence over the lower right-hand contact of cam 975 (6 to 9 and 14 to 18), conductors 977 and 1240, the No. 5 terminal and wiper 1103 of switch RS and thence to ground at the right-hand armature and front contact of relay 802. On calls to a manual office through a tandem office, the fundamental circuit is also held open by relay 802 until the relay call indicator im-pulser switch 1000 reaches position 8 preparatory to sending the tandems code impulses. The circuit of relay 802 in this instance may be traced through its intermediate winding, the left-hand contact of cam 878 (11 to 12), conductor 882, the lower contact of cam 1039 (8½ to 7) of switch 1000, the inner right-hand armature and front contact of tandems relay 1019, conductor 1038 and thence to ground at the lower left-hand contact of cam 756 (9 to 10½).

4. When the sender sequence switch reaches position 15 during its first revolution preparatory to establishing the fundamental circuit for governing incoming brush selection, relay 802 holds the fundamental circuit open if at this time the subscriber has not dialed the thousands and hundreds digits. The circuit of relay 802 may be traced through its intermediate winding, the lower contact of cam 878 (15 and 16), conductor 883, terminals Nos. 3 and 4 and wiper 1103 of switch RS and thence to ground at the right-hand armature and front contact of relay 1102.

5. When the sender sequence switch reaches position 3 during its second revolution preparatory to establishing the fundamental circuit for governing tens selection if the subscriber has not dialed the tens digit, the fundamental circuit is opened at the contact of relay 802 when sequence switch 800 reaches position 4. The circuit of relay 802 may be traced from its intermediate winding, conductor 877, the lower contact of cam 754 (13 to 18), the lower right-hand contact of cam 880 (3 to 4), conductors 881 and 1240, the No. 5 terminal and wiper 1103 of switch RS and thence to ground at the right-hand armature and front contact of relay 1102.

6. When the sender sequence switch 800 reaches position 5 of its second revolution preparatory to establishing the fundamental circuit for controlling units selection, if the subscriber has not dialed the units digit, the fundamental circuit is opened at the contact of relay 802 when the sequence

switch reaches position 6, relay 802 energizing over a circuit extending through its intermediate winding, conductor 877, the lower contacts of cam 754 (13 to 18), the upper contact of cam 880 (5 to 6), conductor 777, the No. 6 terminal and wiper 1103 of switch RS and thence to ground at the right-hand armature and front contact of relay 1102. Relay 802 is maintained energized after the dialing of the units digit, if the preliminary coin test as hereinbefore described shows that no coin has been deposited, over a branch of the former circuit extending to ground at the right-hand armature and front contact of coin test relay 616. If the coin has been deposited at this time, relay 616 is deenergized and relay 802 deenergizes, completing the fundamental circuit.

7. When the sender sequence switch 800 reaches position 7 preparatory to establishing the fundamental circuit for controlling stations hundreds selection on calls to a private automatic exchange in a full mechanical office if the calling subscriber has not dialed all the station digits, the fundamental circuit is opened at the contact of relay 802 when sequence switch 800 reaches position 8. The circuit of relay 802 extends from battery through its intermediate winding, conductor 877, the lower contact of cam 754 (13 to 18), the lower left-hand contact of cam 880 (7 to 8), conductor 734, terminal 1133 and wiper 1103 of switch RS and thence to ground at the right-hand armature and front contact of relay 1102.

The cancellation of the sender delay imposed by the energization of relay 802 on certain classes of calls.

On full mechanical calls as hereinbefore described, the class switch 900 is set in position 4 and following the dialing of the fifth numerical digit, switch RS is advanced to its No. 7 position. On such calls it is unnecessary to delay the closure of the fundamental circuit by relay 802 which otherwise would occur as switch RS passes through positions 7, 8 and 9 as the subscriber will not dial further impulses for setting switches in the automatic branch exchange. Therefore, instead of advancing switch TM by the slow interrupter 733 to position 11 in which position circuits are effective as previously described for buzzing switch RS directly into position 10, switch TM is advanced rapidly to position 11 by the self-interrupting circuit through its stepping magnet 711 extending over wiper 715, terminals 6 to 11 of the bank with which wiper 715 is associated, conductors 773, 1218, 1328, the lower contacts of class switch cam 953 (4), conductor 954 and thence to ground at the lower right hand contact of cam 756 (9 to 13).

If the call is for a manual office having relay call indicator apparatus, the functioning of the sender is delayed by the operation of relay 802 as previously described dependent, 5 however, upon whether the manual office is arranged to extend connections to more than ten thousand lines or less than 9999 lines and whether the party lines in such offices are arranged upon a jack per line or a jack 10 per station basis.

When the code of a manual office having more than ten thousand lines with party lines arranged upon a jack per station basis is dialed, sender delay register relay 15 1437 is energized, but register relay 1438 is not energized. If the subscriber then dials a numerical number less than ten thousand, it is then apparent that no fifth or stations 20 digit may be dialed and therefore it is not essential to delay the closure of the fundamental circuit to await such fifth digit. The time measure switch TM is therefore rapidly advanced to position 11 over a circuit extending through the stepping magnet 25 711, wiper 715, conductors 773 and 1218, the right-hand armature and front contact of sender delay relay 1437, the outer left-hand armature and back contact of relay 1438, conductor 1443, wiper 1241 and terminal 30 bank of the tens register T as soon as the tens register is set, conductor 1242 and to ground at wiper 1180 of the thousands register TH. This circuit would not be effective if the first numerical digit had been 35 1, indicating an intended connection to a line numbered above ten thousand. As soon as switch TM reaches position 11, the steering switch RS is advanced at once to position 10 and the circuit of relay 802 is opened 40 cancelling the delay in the functioning of the sender.

When the code of a manual office having more than ten thousand lines with party lines arranged upon a jack per line basis is called, both sender delay register relays 45 1437 and 1438 remain deenergized. In this case the subscriber may dial five digits to indicate a line numbered above ten thousand, the first two digits being 1 and 0, or may 50 dial a four digit number less than ten thousand whose first two digits are 1 and 0. If five digits are dialed, the stations relay 1233 is energized as soon as the fifth digit is dialed over a circuit extending from battery 55 through the winding of stepping magnet 711 of switch TM, wiper 715, conductor 733, the left-hand winding of relay 1233, conductor 1234, the outer right-hand armature and back contact of relay 1438, conductor 60 1445, wiper 1235 of stations register ST, conductor 1236, wiper 1177 and terminal 1178 of the hundreds register H and thence to ground through terminal 1179 and wiper 1180 of the thousand register TH and the 65 class switch 950 is thereby set into a posi-

tion for an office having more than ten thousand lines. Magnet 711 energizes in the previously traced circuit and advances the time measure switch TM immediately into position 11 in which position the switch 70 RS advances as previously described into position 10 to cancel the sender delay imposed by the energization of relay 802.

If the code of an office having less than ten thousand lines with party lines arranged on a jack per line basis is dialed, both sender delay register relays 1437 and 1438 are energized since it is not known whether the subscriber will dial a stations digit and since all circuits for magnet 711 80 over switch TM are now open except the circuit previously traced through the slow interrupter 733, time is counted by the time measure switch TM to enable the calling subscriber to dial further stations digits before the fundamental circuit is closed by the deenergization of relay 802.

If the code of an office having less than ten thousand lines with party lines arranged on a jack per station basis is called, relay 90 1437 is not energized, but relay 1438 is energized and the time measure switch TM is advanced at once to cancel the sender delay imposed by relay 802 since it is now known that no stations digits will be dialed. 95 The circuit for advancing time measure switch TM may be traced through the winding of magnet 711 to conductor 773 and thence over conductor 1218, the right-hand armature and back contact of relay 1437, 100 the inner right-hand armature and front contact of relay 1438, conductor 1444 and to ground at the armature and front contact of the class relay 924.

Abandonment of a connection.

If the calling subscriber abandons a connection prior to its establishment by restoring his receiver to its switchhook, the previously traced circuit of relay 1100 is 110 opened and after an interval, the slow-to-release relay 1102 deenergizes, closing the previously traced circuit for the wipe-out relays 757 and 766 in parallel, these relays locking to ground at the upper contact of cam 727 over the inner left-hand armature and front contact of relay 757. Upon the energization of relay 757, a circuit is established as previously traced over conductor 115 645 for advancing the switch M into normal position, from which position this switch continues in a second revolution in the same manner as hereinbefore described in connection with coin collection on a successful call.

As the switch M passes through the positions 15, 16 and 17, direct ground potential is connected over wiper 623 to conductor 772 in shunt of the left-hand winding of relay 707 whereupon the current flowing 120 125 130

through the right-hand winding of differential relay 227 is increased to such an extent that relay 227 is differentially balanced and retracts its armatures. Upon retracting its 5 left-hand armature, the holding circuit extending through the windings of relays 226 and 102 is opened and these relays thereupon deenergize. The deenergization of relay 102 causes the restoration of the line switch 10 100 and the deenergization of relay 226 closing a circuit for advancing sequence switch 200 into position 7 if at this time the establishment of the connection has not progressed beyond the district group selection 15 stage. The circuit for sequence switch magnet 200 may be traced through the winding of the magnet, the lower left-hand contact of cam 206 (2 to 6), the right-hand armature and back contact of relay 226 and thence to ground at the upper right-hand contact of cam 205.

When sequence switch 200 reaches position 7, a circuit is closed for the downdrive magnet 271 of the district selector which 25 may be traced from battery through the winding of magnet 271, the lower right-hand and upper left-hand contacts of cam 223, the right-hand armature and back contact of relay 226 and thence to ground at the upper right-hand contact of cam 205. As soon as the switch shaft reaches normal 30 position, the brush 248 engages the normal commutator segment 273 and a circuit is closed for advancing sequence switch 200 into normal position, which circuit may be 35 traced from battery through the magnet winding of switch 200, the upper right-hand contact of cam 206 (5 to 18), segment 273, brush 248 and thence to ground at the lower 40 contact of cam 209 (9 to 7). When the sequence switch leaves position 11, the holding circuit of relays 230 and 244 is opened at the upper left-hand contact of cam 209 and the relays deenergize, relay 230 opening the 45 holding circuit of relay 706. Upon the deenergization of relay 706, the restoration of the circuits of the office sender proceeds in the manner hereinbefore described. All apparatus which has been utilized up to the time 50 the call is abandoned is now in normal condition.

If, however, the connection has progressed beyond the district group selection stage and 55 sequence switch 200 of the district selector has advanced beyond position 7, then it becomes necessary to set up a connection through an office, incoming and final selector switch in order that a releasing circuit may be established for releasing the district selector and through the release of the district selector for releasing the office sender. In 60 this case the office selector is set by the office sender in the same manner as previously described for a successful connection and the incoming selector is controlled in its

brush selection movement by a No. 0 counting relay connection rather than by the connection set up by the calling subscriber in order to limit the selecting movement of the switch to a minimum to increase the speed of release. The No. 0 counting relay connection may be traced from the No. 0 counting relay lead 838 to the No. 0 lead 778 Fig. 7, the left-hand armature and front contact of relay 766, conductor 1137, the 70 lower right-hand contact of cam 859 and thence as previously traced through the winding of the No. 0 counting relay to battery. In a similar manner, the incoming selector is controlled in its group selection movement by the No. 0 counting relay over a connection traced from the No. 0 lead 838 to the No. 0 lead 779 Fig. 7, the outer right-hand armature and front contact of relay 757, conductor 1142, the lower left-hand contact of cam 859 (18) and thence to the No. 0 counting relay 816 as previously traced. The final selector is also controlled in its brush and group selection movements by the No. 0 counting relay 816, relay 816 being controlled over the No. 0 lead 838, lead 780 Fig. 7, the inner right-hand armature and front contact of relay 766, the right-hand contact of cam 865 (2) and thence over the circuit previously traced during final brush selection and over lead 780 Fig. 7, the outer right-hand armature and front contact of relay 766, the lower left-hand contact of cam 865 (4) and thence over the circuit previously traced during final group selection. When the sequence switch of the final selector reaches position 6 preparatory to controlling the switch in its units selection movement and the fundamental circuit is closed through the sender stepping relay 804, the fundamental circuit is not controlled by counting relays since the circuit which normally controls the counting relays for units selection is open at the outer left-hand armature and back contact of relay 757 and therefore the final selector switch is driven without interruption to the upper extent of its movement or to the telltale position. When the final selector switch reaches the telltale position, a circuit is closed for advancing sequence switch 500 into position 13 which may be traced from battery through the magnet winding of switch 500, the lower left-hand contact of cam 512 (1 to 12), conductor 581, telltale segment 580, shaft wiper 538, conductor 533 and thence to ground at the upper left-hand contact of cam 506 (13 to 11). Since at this time the sleeve relay 521 is energized, a circuit is closed over its right-hand armature and front contact and the lower contacts of cam 509 (13) for advancing sequence switch 500 into position 14. With the sequence switch 500 in position 14, the final selector is restored to normal position in the same manner as pre- 130

viously described in connection with an attempted connection with a busy subscriber's line. As sequence switch 500 leaves position 8½, the sequence switch 400 of the incoming selector 450 is advanced to position 9 in the manner hereinbefore described thereby reversing the direction of current flowing through the overflow relay 823 of the office sender, which as previously described, 5 causes the advance of the district selector sequence switch 200 into position 11. With sequence switch 200 in position 11, talking selection takes place in the manner previously described, the sequence switch being advanced out of position 11. Since at this time 10 relay 226 is deenergized as soon as sequence switch 200 reaches position 12, a circuit is closed for advancing the sequence switch directly into position 16, which circuit may be traced from battery through the magnet winding of switch 200, the lower left-hand contact of cam 206 (12 to 17), the right-hand armature and back contact of relay 226 and thence to ground through the upper right-hand contact of cam 205. Upon reaching position 16, the advance of switch 200 is continued into position 17 over a circuit as previously traced through the right-hand armature and back contact of relay 226, the upper 15 right-hand and lower left-hand contacts of cam 223 and thence to ground at the normally closed right-hand armature contact of relay 227. From position 17, sequence switch 200 is advanced into position 18 over the circuit traced through the right-hand armature and back contact of relay 226 and the upper right-hand contact of cam 205 (17 to 15). In position 18, the restoration of 20 the district selector is effected in the manner hereinbefore described.

As sequence switch 200 leaves position 14½, the circuit over sleeve conductor 333 is opened and the restoration of the office selector is initiated. The restoration of the office selector followed by the restoration of the incoming selector is effected as previously described. When talking selection is completed and relay 228 deenergizes, the locking circuit of relays 230 and 244 is 25 opened and the circuits of the office sender are thereupon restored as described in connection with the establishment of a successful connection.

What is claimed is:

1. In a telephone exchange system, a calling subscriber's line, a plurality of called subscribers' lines located in different areas of said exchange, automatic selector switches for extending connections from said calling line, a central office register sending mechanism common to said switches and under the control of said calling subscriber for controlling said switches and effective to cause the complete establishment of connections 30 to called lines in certain of said areas, an

operator's position and means effective upon the attempt of the calling subscriber to establish connections with other of said called lines to extend such connections to said operator's position. 70

2. In a telephone exchange system, a calling subscriber's line, a plurality of called subscribers' lines located within the local area of said exchange, a plurality of called lines located in the outlying areas of said exchange, automatic switches for extending connections from said calling line, a central office register sender mechanism common to said switches and under the control of said calling subscriber for controlling said switches and effective to cause the complete establishment of connections within the local area, an operator's position and means effective when the calling subscriber attempts to establish connections with called lines in said outlying areas to cause said mechanism to control the extension of a connection from said calling line to the operator's position. 80

3. In a telephone exchange system, a calling subscriber's line, a plurality of called subscribers' lines located within the local office areas of said exchange, a plurality of called lines located in the outlying areas of said exchange, automatic switches for extending connections from said calling line, means for controlling the setting of said switches comprising a plurality of registers adapted to be selectively operated in accordance with the office designation of the desired line, said controlling means operating to complete the establishment of a desired connection when said registers have been operated in accordance with the office designation of a called line in the local area, 90 an operator's position, means operative when said registers have been operated in accordance with the office designation of a called line in an outlying area to render said registers ineffective for controlling the routing of 95 said connection and to cause the extension of the connection to said operator's position. 100

4. In a telephone exchange system, a calling subscriber's line, a plurality of called subscribers' lines located within the local office areas of said exchange, a plurality of called lines located in the outlying areas of said exchange, automatic switches for extending connections from said calling line, means for controlling the operation of said switches comprising a plurality of registers adapted to be selectively operated in accordance with the office designation of the desired line and a plurality of locking relays selectively operated in accordance with the adjustment of said registers, said controlling means operating to effect the complete establishment of a desired connection when said relays have been selectively operated 110 115 120 125 130

- to extend the connection to a desired line in the local area, an operator's position and means controlled by certain of said relays operative when said registers are operated 5 in accordance with the office designation of a called line in an outlying area to render said relays ineffective for controlling the routing of the connection and to cause the extension of the connection to said operator's position.
5. In a telephone exchange system, a calling subscriber's line, a plurality of called subscribers' lines located within the local office area of said exchange, a plurality of 15 called lines located in the outlying areas of said exchange, automatic switches for extending connections from said calling line, means for controlling the setting of said switches comprising a plurality of registers adapted to be selectively operated in accordance with the office designation of the desired line, said controlling means operating to effect the complete establishment of a 20 desired connection when said registers have been operated in accordance with the office designation of a called line in a local area, an operator's position and means operative when said registers have been operated in accordance with the office designation of a 25 called line in an outlying area to render said registers ineffective for controlling the routing of the connection and to cause the extension of the connection to said operator's position.
- 30 6. In a telephone exchange system, a calling subscriber's line, a sending mechanism, a plurality of selector switches successively under the control of said sending mechanism for extending a connection from said calling line, a control circuit adapted to be extended over said connection successively from said mechanism to said switches and means for maintaining the electrical characteristics of 35 said control circuit substantially constant regardless of the amount of its extension.
- 40 7. In a telephone exchange system, a calling subscriber's line, a sending mechanism, a plurality of selector switches successively under the control of said sending mechanism for extending a connection from said calling line, a control circuit adapted to be extended over said connection successively from said mechanism to said switches and means for maintaining the resistance of said control circuit substantially constant regardless of the amount of its extension.
- 45 8. In a telephone exchange system, a calling subscriber's line, a called subscriber's line, a plurality of selector switches adapted to be operated in succession for extending a connection from said calling line to said called line, a sending mechanism for governing the operation of said switches, a switch controlling circuit adapted to be extended in succession from said mechanism to each
- of said switches and means associated with said sending mechanism for maintaining the resistance of said circuit substantially constant regardless of the length of said circuit.
9. In a telephone exchange system, a calling subscriber's line, a called subscriber's line, a plurality of selector switches adapted to be operated in succession for extending a connection between said lines, a sending mechanism for governing the operation of 70 said switches, a switch controlling circuit adapted to be extended in succession from said mechanism to each of said switches, resistance means in said circuit at said sending mechanism and means associated with said sending mechanism for progressively removing said resistance from said circuit during the extension of said circuit.
- 75 10. In a telephone exchange system, an originating office, a distant office, a subscriber's line terminating in said originating office, a selector switch in said originating office for extending a connection from said line to said distant office, selector switches in said distant office for further extending said connection, a sender mechanism for governing the operation of said switches, a switch controlling circuit adapted to be extended in succession from said mechanism to each of 80 said switches, resistance means in said circuit at said sending mechanism and means associated with said mechanism for removing a portion of said resistance from said circuit upon the extension of said connection to said distant exchange whereby the resistance of said control circuit is maintained substantially constant regardless of its length.
- 85 11. In a telephone exchange system, an originating office, other offices, a subscriber's line terminating in said originating office, a selector switch in said originating office for extending a connection from said line to any one of said other offices, means in said other offices for further extending said connection, a sending mechanism for controlling the extension of said connection, a control circuit adapted to be extended in succession from said sending mechanism to said switch and to the extending means in any one of 90 said other offices and means associated with said sending mechanism for maintaining the resistance of said circuit substantially constant regardless of the length of said circuit dependent upon the office designation of said connection.
- 95 12. In a telephone exchange system, an originating office, other offices, a subscriber's line terminating in said originating office, a selector switch in said originating office for extending a connection from said line to any one of said other offices, means in said other offices for further extending said connection, a sending mechanism for controlling the extension of said connection, a control circuit 100
- 105
- 110
- 115
- 120
- 125
- 130

adapted to be extended from said sending mechanism to said switch and thence to the extending means in any one of said other offices and a switching means associated with 5 said mechanism adapted to be variously operated in accordance with the office designation of said connection for maintaining the resistance of said circuit substantially constant regardless of the amount of extension 10 of said circuit.

13. In a telephone exchange system, an originating office, other offices, a subscriber's line terminating in said originating office, switching means in said originating office 15 for extending a connection from said line to any one of said other offices, means in said other offices for further extending said connection, a sending mechanism for controlling the extension of said connection, a 20 control circuit adapted to be extended from said sending mechanism to said switch and thence to the extending means in any one of said other offices, a plurality of resistance elements for inclusion in said control circuit during the control of the switching 25 means of said originating office, a plurality of resistance elements for inclusion in said circuit during the control of the extending means beyond said originating office and 30 means associated with said sending mechanism adapted to variously select one of each of said plurality of resistance elements in accordance with the office designation of said connection whereby the resistance of 35 said control circuit is maintained substantially constant.

14. In a telephone exchange system, a calling subscriber's line, an impulse sending mechanism for said line, a plurality of selector switches for extending a connection from said line, a register sending mechanism responsive to a plurality of operations of said impulse mechanism for controlling said switches and relay means for delaying the 40 switch controlling functions of said sending mechanism at certain stages until after the subscriber has completed certain operations of said impulse mechanism.

15. In a telephone exchange system, a calling subscriber's line, an impulse mechanism for said line, a plurality of selector switches for extending a connection from said line, a register sending mechanism responsive to a plurality of operations of said 50 impulse mechanism for controlling said switches and relay means for preventing said mechanism from functioning in its switch controlling operations more rapidly than is warranted by the operation of the subscriber's impulse mechanism.

16. In a telephone exchange system, a calling subscriber's line, an impulse mechanism for said line, a plurality of selector switches for extending a connection from 55 said line, a register sending mechanism for

controlling said switches, the registers of said sending mechanism being successively under the control of said impulse mechanism and relay means for delaying the switch controlling functions of said sending mechanism at certain stages of its operation until after the calling subscriber has caused the setting of certain of said registers. 70

17. In a telephone exchange system, a calling subscriber's line, an impulse mechanism for said line, a plurality of selector switches for extending a connection from said line, a register sending mechanism for controlling said switches, means for placing the registers of said sending mechanism successively under the control of said impulse mechanism; a switch control circuit extending from said sending mechanism to said switches and a relay for opening said circuit at certain stages in the progress of said connection until after the calling subscriber has caused the setting of certain of said registers. 75 80 85

18. In a telephone exchange system, a calling subscriber's line, an impulse mechanism for said line, a plurality of selector switches for extending a connection from said line, a register sending mechanism responsive to a plurality of operations of said impulse mechanism for controlling said switches, a switch control circuit extending from said sending mechanism to said switches and a relay for opening said circuit at certain stages in the progress of said connection until after the subscriber has completed certain operations of said impulse mechanism. 90 95 100

19. In a telephone exchange system, a calling line, an impulse mechanism for said line, a plurality of selector switches for extending a connection from said line, a register sending mechanism for controlling said switches, means for placing the registers of said sending mechanism successively under the control of said impulse mechanism, a switch control circuit extending from said sending mechanism to said switches, a relay for opening said circuit at certain stages in the progress of said connection and timing means for determining the duration of the 105 110 115 operation of said relay.

20. In a telephone exchange system, a calling subscriber's line, an impulse mechanism for said line, a plurality of selector switches for extending a connection from said line, a register sending mechanism responsive to a plurality of operations of said impulse mechanism for controlling said switches, means for delaying the switch controlling 120 125 functions of said sending mechanism at certain stages until after the subscriber has completed certain operations of said impulse mechanism and means for rendering said delaying means ineffective.

21. In a telephone exchange system, a call- 130

- ing subscriber's line, an impulse mechanism for said line, a plurality of selector switches for extending a connection from said line, a register sending mechanism for controlling 5 said switches, the registers of said sending mechanism being successively under the control of said impulse mechanism, means for delaying the switch controlling functions of said sending mechanism at certain stages of 10 its operation after the calling subscriber has caused the setting of certain of said registers and means for rendering said delaying means ineffective.
22. In a telephone exchange system, a calling 15 subscriber's line, an impulse mechanism for said line, a plurality of selector switches for extending a connection from said line, a register sending mechanism responsive to a plurality of operations of said impulse 20 mechanism for controlling said switches, a switch control circuit extending from said sending mechanism to said switches, means for opening said circuit at certain stages in the progress of said connection until after 25 the subscriber has completed certain operations of said impulse mechanism and means for rendering said circuit opening means ineffective.
23. In a telephone exchange system, a calling 30 subscriber's line, an impulse mechanism for said line, a plurality of selector switches for extending a connection from said line, a register sending mechanism for controlling said switches, means for placing the registers 35 of said sending mechanism successively under the control of said impulse mechanism, a switch control circuit extending from said sending mechanism to said switches, a relay for opening said circuit at certain stages in the progress of said connection until after the calling subscriber has caused the setting of certain of said registers and means for preventing the operation of 40 said relay.
24. In a telephone exchange system, an originating office, a subscriber's line terminating therein, an impulse mechanism for said line, a plurality of other offices, selector 45 switches for extending a connection from said line to any one of said latter offices, line extending means in said latter offices, a register sending mechanism for controlling said switches and line extending means, registers for said sending mechanism for controlling 50 said switches in accordance with the office designation of a desired connection, other registers for controlling the operation of said line extending means, means for placing said registers successively under the control 55 of said impulse mechanism, means for delaying the switch controlling functions of said sending mechanism at certain stages of its operation until after the calling subscriber has caused the setting of certain of 60 said registers and means for rendering said 65 registers ineffective when said first named registers have been operated to register certain office designations.
25. In a telephone exchange system, an originating office, a subscriber's line terminating 70 therein, an impulse mechanism for said line, a plurality of other offices, selector switches for extending a connection from said line to any one of said latter offices, line extending means in said latter offices, a register sending mechanism for controlling 75 said switches and line extending means, registers for said sending mechanism adapted to be operated in accordance with the office designation of a desired connection, other offices adapted to be operated in accordance with the numerical designation of said connection, means for placing said registers successively under the control of said impulse mechanism, register relays under the control of said registers, means for delaying 80 the switch controlling functions of said sending mechanism at certain stages of its operation until after the subscriber has caused the operation of certain of said registers and means comprising certain of said register relays for rendering said delaying means ineffective when said first named registers have been operated to register certain office 85 designations.
26. In a telephone exchange system, an originating office, a subscriber's line terminating 90 in said office, an impulse mechanism for said line, a plurality of other offices, selector switches for extending a connection from said line to any one of said latter offices, line extending means in said latter offices, a register sending mechanism for controlling 95 said switches and line extending means, registers for said sending mechanism adapted to be operated in accordance with the office designation of a desired connection, other registers adapted to be operated in accordance with the numerical designation of said connection, means for placing 100 said registers successively under the control of said impulse mechanism, register relays under the control of said registers, a control circuit extending from said sending mechanism to said switches and line extending means, a relay for opening said control circuit at certain stages in the operation of said sending mechanism until after the subscriber has caused the operation of certain of said registers and means comprising 105 certain of said register relays for rendering said circuit opening relay ineffective when said first named registers have been operated to register certain office designations.
27. In a telephone exchange system, a calling subscriber's line, an impulse mechanism for said line, a plurality of selector switches for extending a connection from said line, a register sending mechanism for controlling 110 said switches, means for placing the registers 115 of said sending mechanism successively under the control of said impulse mechanism, register relays under the control of said registers, a control circuit extending from said sending mechanism to said switches and line extending means, a relay for opening said control circuit at certain stages in the operation of said sending mechanism until after the subscriber has caused the operation of certain of said registers and means comprising 120 certain of said register relays for rendering said circuit opening relay ineffective when said first named registers have been operated to register certain office designations.
28. In a telephone exchange system, a calling subscriber's line, an impulse mechanism for said line, a plurality of selector switches for extending a connection from said line, a register sending mechanism for controlling 125 said switches, means for placing the registers 130 of said sending mechanism successively under the control of said impulse mechanism, register relays under the control of said registers, a control circuit extending from said sending mechanism to said switches and line extending means, a relay for opening said control circuit at certain stages in the operation of said sending mechanism until after the subscriber has caused the operation of certain of said registers and means comprising certain of said register relays for rendering said circuit opening relay ineffective when said first named registers have been operated to register certain office designations.

registers of said sending mechanism successively under the control of said impulse mechanism, a switch control circuit extending from said sending mechanism to said switches, a relay for opening said circuit at certain stages in the progress of said connection, a timing means for determining the duration of the operation of said relay and means for cancelling the relay operating time as imposed by said timing means.

28. In a telephone exchange system, a calling subscriber's line, an impulse mechanism for said line, a plurality of selector switches for extending a connection from said line, a register sending mechanism for controlling said switches, means for placing the registers of said sending mechanism successively under the control of said impulse mechanism, a switch control circuit extending from said sending mechanism to said switches, a relay for opening said circuit at certain stages in the progress of said connection, a time measuring switch for determining the duration of the operation of said relay and means for rapidly advancing said latter switch to cancel the relay operating time imposed thereby.

29. In a telephone exchange system, an originating office, a subscriber's line terminating therein, an impulse mechanism for said line, a plurality of other offices, selector switches for extending a connection from said line to any one of said latter offices, line extending means in said latter offices, a register sending mechanism for controlling said switch and line extending means, registers for said sending mechanism for controlling said switches in accordance with the office designation of a desired connection, other registers for controlling the operation of said line extending means, means for placing said registers successively under the control of said impulse mechanism, a control circuit extending from said sending mechanism to said switches and line extending means, a relay for opening said control circuit at certain stages in the operation of said sending mechanism, a time measuring switch for determining the duration of the operation of said relay and means for rapidly advancing said latter switch to cancel the relay operating time imposed thereby when said first named registers have been operated to register certain office designations.

30. In a telephone exchange system, an originating office, a subscriber's line terminating therein, a manual office, selector switches for extending a connection from said line to said latter office, a register sending mechanism for controlling said switches, means under the control of said subscriber for registering the office and numerical designation of a desired line on the registers

of said sending mechanism, means associated with said sending mechanism for transmitting a plurality of series of code impulses to said manual office corresponding to the registered numerical designation of said desired line and means for changing the order of transmission of said series of impulses.

31. In a telephone exchange system, an originating office, a subscriber's line terminating therein, a manual office, selector switches for extending a connection from said line to said latter office, a register sending mechanism for controlling said switches, means under the control of said subscriber for registering the office numerical and party line designation of a desired line upon the registers of said sending mechanism, means associated with said sending mechanism for transmitting a plurality of series of code impulses to said manual office corresponding to the registered numerical and party line designation of said desired line and means for changing the order of transmission of said series of impulses.

32. In a telephone exchange system, an originating office, a subscriber's line terminating therein, a second office, selector switches for extending a connection from said line to said latter office, a register sending mechanism for controlling said switches, means under the control of said subscriber for registering the designation of a desired line on the registers of said sending mechanism, means associated with said sending mechanism for transmitting a plurality of series of impulses to said second office corresponding to the registered numerical designation of said desired line, and means for changing the order of transmission of said series of impulses.

33. In a telephone exchange system, an originating office, a subscriber's line terminating therein, a second office, selector switches for extending a connection from said line to said latter office, a register sending mechanism for controlling said switches, means under the control of said subscriber for registering the office, numerical and party line designation of a desired line upon the registers of said sending mechanism, means associated with said sending mechanism for transmitting a plurality of series of impulses to said second office corresponding to the registered numerical and party line designation of said desired line, and means for changing the order of transmission of said series of impulses.

34. In a telephone exchange system, an originating office, a subscriber's line terminating therein, a second office, selector switches for extending a connection to said line from said latter office, a register sending mechanism for controlling said switches, means for registering upon said registers the designation of a desired line, means asso-

- ciated with said sending mechanism for transmitting a plurality of series of impulses to said second office corresponding to the registered numerical designation of said 5 desired line, and means for changing the order of transmission of said series of impulses.
35. In a telephone exchange system, an originating office, a subscriber's line terminating therein, a manual office, selector switches for extending a connection from said line to said latter office, a register sending mechanism for controlling said switches, means under the control of said subscriber 10 for registering the office numerical and party line designation of a desired line on the registers of said sending mechanism, means associated with said sending mechanism for transmitting a plurality of series of code impulses 15 to said manual office corresponding to the numerical and party line designation of said office line and means for changing the order of transmission of said series of impulses in accordance with the operated positions of certain of said numerical registers.
36. In a telephone exchange system, an originating office, a subscriber's line terminating therein, a manual office, selector switches for extending a connection from 20 said line to said latter office, a sending mechanism for controlling said switches, office numerical and stations registers associated with said sending mechanism, means under the control of said subscriber for registering 25 the office numerical and party line designation of a desired line on said registers respectively, means associated with said sending mechanism for transmitting a plurality of series of code impulses of said 30 manual office corresponding to the numerical and party line designation of said desired line and means for changing the order of transmission of said numerical and party line series of impulses in accordance 35 with the operated positions of two of said numerical registers.
37. In a telephone exchange system, an originating office, a subscriber's line terminating therein, a manual office, selector switches for extending a connection from 40 said line to said latter office, a sending mechanism for controlling said switches, office, numerical and stations registers associated with said sending mechanism, means under the control of said subscriber for registering 45 the office, four numerical and the party line designations of certain lines, or the office and five numerical designations of other lines on said registers respectively, means 50 associated with said sending mechanism for transmitting a plurality of series of code impulses to said manual office corresponding to the numerical and party line designations of desired lines and means for 55 changing the order of transmission of said 60 impulses.
38. In a telephone exchange system, a calling subscriber's line, a plurality of selector switches for extending a connection from said line, a sending mechanism for controlling said switches and means associated with said sending mechanism comprising a plurality of relays for causing the restoration of said sending mechanism and the release of said selector switches when the calling subscriber abandons an initiated connection prior to its completion. 70
39. In a telephone exchange system, a calling subscriber's line, a plurality of selector switches for extending connections from said line, means for controlling the operation of said switches in accordance with the designations of desired connections comprising a plurality of registers, means under the control of said calling subscriber to operate said registers and means for controlling said switches independently of said registers when the calling subscriber abandons an initiated connection prior to its completion. 75
40. In a telephone exchange system, a calling subscriber's line, a plurality of selector switches for extending connections from said line, means for controlling the operation of said switches in accordance with the designations of desired connections comprising a plurality of registers, means under the control of said calling subscriber to operate said registers to register the designations of desired connections and means comprising a plurality of relays for controlling said switches in a predetermined manner independently of said registers when the calling subscriber abandons an initiated connection prior to its completion. 80
41. In a telephone exchange system, a calling subscriber's line, a plurality of selector switches for extending connections from said line, means for controlling the operation of said switches in accordance with the designations of desired connections comprising a plurality of registers, means under the control of said calling subscriber to operate said registers to register the designations of desired connections and means comprising a plurality of relays for controlling said switches in a predetermined manner independently of said registers when the calling subscriber abandons an initiated connection prior to its completion. 85
42. In a telephone exchange system, a calling subscriber's line, a plurality of selector switches comprising an incoming and final selector switch for extending a connection from said line, means for controlling the operation of said switches in accordance with the designation of a desired connection 90
43. In a telephone exchange system, a calling subscriber's line, a plurality of selector switches for extending connections from said line, means for controlling the operation of said switches in accordance with the designations of desired connections comprising a plurality of registers, means under the control of said calling subscriber to operate said registers to register the designations of desired connections and means comprising a plurality of relays for controlling the operation of said switches to the minimum extent of their movement independently of said registers when the calling subscriber abandons an initiated connection prior to its completion and means thereupon effective to release all operated apparatus. 95
44. In a telephone exchange system, a calling subscriber's line, a plurality of selector switches comprising an incoming and final selector switch for extending a connection from said line, means for controlling the operation of said switches in accordance with the designation of a desired connection 100
45. In a telephone exchange system, a calling subscriber's line, a plurality of selector switches for extending connections from said line, means for controlling the operation of said switches in accordance with the designations of desired connections comprising a plurality of registers, means under the control of said calling subscriber to operate said registers to register the designations of desired connections and means comprising a plurality of relays for controlling the operation of said switches to the minimum extent of their movement independently of said registers when the calling subscriber abandons an initiated connection prior to its completion and means thereupon effective to release all operated apparatus. 105
46. In a telephone exchange system, a calling subscriber's line, a plurality of selector switches comprising an incoming and final selector switch for extending a connection from said line, means for controlling the operation of said switches in accordance with the designation of a desired connection 110
47. In a telephone exchange system, a calling subscriber's line, a plurality of selector switches for extending connections from said line, means for controlling the operation of said switches in accordance with the designations of desired connections comprising a plurality of registers, means under the control of said calling subscriber to operate said registers to register the designations of desired connections and means comprising a plurality of relays for controlling the operation of said switches to the minimum extent of their movement independently of said registers when the calling subscriber abandons an initiated connection prior to its completion and means thereupon effective to release all operated apparatus. 115
48. In a telephone exchange system, a calling subscriber's line, a plurality of selector switches comprising an incoming and final selector switch for extending a connection from said line, means for controlling the operation of said switches in accordance with the designation of a desired connection 120
49. In a telephone exchange system, a calling subscriber's line, a plurality of selector switches for extending connections from said line, means for controlling the operation of said switches in accordance with the designations of desired connections comprising a plurality of registers, means under the control of said calling subscriber to operate said registers to register the designations of desired connections and means comprising a plurality of relays for controlling the operation of said switches to the minimum extent of their movement independently of said registers when the calling subscriber abandons an initiated connection prior to its completion and means thereupon effective to release all operated apparatus. 125
50. In a telephone exchange system, a calling subscriber's line, a plurality of selector switches comprising an incoming and final selector switch for extending a connection from said line, means for controlling the operation of said switches in accordance with the designation of a desired connection 130

- comprising a plurality of registers, means under the control of said calling line to operate said registers to register the designation of said desired connection, means comprising
 5 a plurality of relays for controlling the operation of said incoming selector to the minimum extent of its movement and the operation of said final selector to the telltale position independently of said registers when
 10 the calling subscriber abandons an initiated connection prior to its completion and means thereupon effective to release all operated apparatus.
43. In a telephone exchange system, a calling subscriber's line, a calling dial for said line, a plurality of called subscriber's lines, automatic switches for interconnecting said lines, controlling equipment for said automatic switches, an operator's position, means
 20 to operate said controlling equipment under the control of said dial to position said automatic switches to establish connection to a called line, and means operative in response to a distinctive act of a subscriber in establishing a call to destroy the effect of the number dialed to position said automatic switches to extend connection to said operator's position.
- 25
 30

44. In a telephone exchange system, a calling subscriber's line, a calling dial for said line, a plurality of called subscriber's lines, automatic switches for interconnecting said lines, controlling equipment for said automatic switches, an operator's position, means to operate said controlling equipment under the control of said dial to position said automatic switches to establish connection to a called line, means operative in response to a distinctive act of a subscriber in establishing a call to destroy the effect of the number dialed to position said automatic switches to extend connection to said operator's position.
- 35
 40
 45

switches to extend connection to said operator's position, and means to independently release said controlling equipment after the extension of said connection to said operator's position.

 55
 60
 65

45. In a telephone exchange system, a calling subscriber's line, a calling dial for said line, a plurality of called subscriber's lines, automatic switches for interconnecting said lines, controlling equipment for said automatic switches, an operator's position, means to operate said controlling equipment under the control of said dial to position said automatic switches to establish connection to a called line, and a relay operative in response to a distinctive act of a subscriber in establishing a call to destroy the effect of the number dialed and to direct said controlling equipment independent of the number dialed to position and automatic switches to extend connection to said operator's position.

70
 75
 80
 85

46. In a telephone exchange system, a calling subscriber's line, a calling dial for said line, a plurality of called subscriber's lines, automatic switches for interconnecting said lines, controlling equipment for said automatic switches, an operator's position, means to operate said controlling equipment under the control of said dial to position said automatic switches to establish connection to a called line, a relay operative in response to a distinctive act of a subscriber in establishing a call to destroy the effect of the number dialed and to direct said controlling equipment independent of the number dialed to position said automatic switches to extend connection to said operator's position, and means to independently release said controlling equipment after the extension of said connection to said operator's position.

In witness whereof, I hereunto subscribe my name this 22nd day of April, A. D. 1921.

FRANKLIN A. STEARN.
